UNITED STATES PATENT OFFICE.

JOHN A. BOYCE, OF SPRINGFIELD, ILLINOIS.

APPARATUS FOR PRINTING AND FOLDING PAPERS.

974,231.

Specification of Letters Patent. Patented Nov. 1, 1910.

Application filed October 1, 1906. Serial No. 336,856.

To all whom it may concern:

Be it known that I, JOHN A. BOYCE, a subject of His Majesty Edward the VII, King of Great Britain and Ireland, residing at Springfield, in the county of Sangamon and State of Illinois, have declared my intention to become a citizen of the United States, as evidenced by the certificate of the county clerk of Sangamon county, Illinois, now on file in the Patent Office. Be it further known that I have invented a certain new and useful Apparatus for Printing and Folding Papers, of which the following is such a full, clear, and exact description as will enable others skilled in the art to which it appertains to make and use my said invention.

My invention relates to the class of apparatuses known as perfecting presses and folders.

Briefly expressed and omitting minor features, the purpose of the present invention is to provide an apparatus for printing and folding newspapers comprising printing, associating, cutting, folding, collecting and delivery mechanisms of such construction and in such relation to each other as to be effective for the following purposes: The use of full width, full speed supplement webs, with either lengthwise or circumferential columns, and with folder mechanisms either parallel or at right angles to the printing couples. The travel of papers and sections in such manner that if plate cylinders with lengthwise columns are used papers in the first fold, or papers in the third fold as the case may be, will run onto the delivery devices with their folded edges in the lead; and if plate cylinders with circumferential columns are used, papers in the second fold will run onto the delivery devices with their folded edges in the lead. Producing with a single machine either papers or magazines, without change in the mechanism. Dropping papers, or magazines one at a time, or two at a time, onto a single delivery device. Producing papers in sections, some with supplement and some without supplement, or all with supplement. Effecting the alternate run of the supplement sheets either with lengthwise or circumferential columns. The deriving of regular pages and supplement pages from a single composite web. Utilizing the entire plate surface of plural plate wide full speed supplement printing couples with either cir-

cumferential or lengthwise columns. The locating of a former in such relation to cutter devices that the cut may be made either before or after the web runs upon the former. The locating of a former in such relation to coöperating cutter and folder mechanisms that it will serve as an associating device if lengthwise columns are used and as a first-folder device if circumferential columns are used. Slitting the web either before or after cutting into sheets. The parting of the webs and the locating the supplement web between the parted main webs. Timing the run of papers from a plurality of first folder devices to arrive successively at a single second folder device and drop onto a single delivery device. Dropping either in the first fold the second fold, or the third fold; in book form, or in sections. Employing a single folder mechanism to fold the maximum number of papers which may be operated upon by a plurality of coöperating folder mechanisms. Stuffing second folded papers and folding them together in the third fold. Producing from a single web a paper entirely in sections, or part in book form and part in sections, and producing in a single paper sections of different numbers of pages say a ten-page section and a fourteen page section.

With these ends in view my invention consists in the novel features of construction and combinations of parts shown in the annexed drawings (twenty two sheets) to which reference is hereby made, and hereinafter particularly described and finally recited in the claims.

This invention relates primarily to the position and relation of the coöperating mechanisms, the drawings are therefore in the nature of diagrams showing the positions and relations of the mechanisms and it will be understood that where precise construction is not shown and described the mechanical elements may be such as are well known in the art, and in common use for the respective purposes set forth.

In the diagrams hereinafter referred to, cylinders and rollers are represented by circles, and gear wheels are represented by the pitch circles of the gears.

In the drawings similar reference letters and characters designate like parts in the several views.

Figure 1 is a diagram illustrating in side elevation a double-end machine five decks:

high and three plates wide and showing the printing couples, the folder cylinders, the formers and means for controlling the run of the webs and sheets through the machine.

5 Fig. 2 is a diagram showing the train of gears operating the printing mechanisms and the folder mechanisms of the machine illustrated in Fig. 1. Fig. 3 is a diagram showing in end elevation the folder mechanisms for making 10 the second and third folds; Fig. 4 is a diagram showing in top plan the gear for driving the folder mechanisms shown in Fig. 3; Figs. 5, 6, 7, 8 and 9 are diagrams illustrating different arrangements and operations of the 15 folder mechanisms illustrated in Fig. 3. Fig. 10 is an enlarged end elevation of one of the slitter devices. Fig. 11 is a vertical section on the line 11, 11 of Fig. 10; Fig. 12 is an enlarged end elevation of a pair of 20 operating supplement carrier and supplement cutter cylinders of the preferred construction; Fig. 13 is an enlarged end elevation of a supplement carrier cylinder and a coöperating supplement cutter cylinder, of 25 a modified construction. Fig. 14 (Sheet 6) is a partial top plan of the mechanism illustrated in Fig. 13. Figs. 15 to 24 inclusive and 57, 58, 59 and 60 are diagrams illustrating different arrangements and runs of the 30 webs and sheets in producing papers having different numbers of pages, in producing papers in which all of the sheets are arranged in book form, in producing papers in sections and dropping the sections separately onto different delivery wheels or assembling or collecting and assembling two or more sections and dropping them together onto a single delivery wheel in producing 35 stuffed papers, that is to say, papers in which two or more sections are brought together and folded together to form a single paper and to produce papers with or without supplements. Fig. 25 is an enlarged detail perspective view of one of the central switches. Fig. 26 is an 40 enlarged detail perspective view of a combined switch and stripper usable with the carrier cylinders and formers. Fig. 27 is a side elevation on an enlarged scale of a modified construction and arrangement of 45 the folder mechanisms, comprising two formers and two carrier cylinders adapted for use in a plural-plate-wide multiple-deck apparatus equipped with plate cylinders having columns lengthwise of the plate cylinders and also adapted for use in a four-plate-wide multiple-deck apparatus equipped with plate cylinders having circumferential columns. Figs. 28 and 29 are respectively a top plan and end elevation of the folder 50 mechanisms coöperating with the formers 12 and 12^a shown in Fig. 27. Figs. 30 and 31, are respectively a side elevation and top plan, on an enlarged scale, of an apparatus embodying swinging-blade folder mechanisms and adapted to deliver papers or sec- 55 tions as the case may be, to an intermediate delivery device upon the completion of either the first fold or the second fold; if plate cylinders having circumferential columns are used; and likewise adapted, if plate cylinders equipped with lengthwise columns are used, to drop papers in the first fold, upon the central delivery device; or to deliver the papers to the packer after the second fold has been made by the swinging-blade folder-devices. Fig. 32 illustrates in detail the combined switch and guide plate shown in Fig. 30. Figs. 33, 34 and 35 are diagrams illustrating different settings of the combined switches and guide-plates. Fig. 36 is an enlarged elevation of one of the carrier cylinders and shows the means for operating the folder blades and the pins of carrier cylinders usable either in magazine or newspaper work. Fig. 37 is a vertical section on the line 37, 37 of Fig. 36 parts of the end of the cylinder being shown as broken away. Fig. 38 is a similar vertical section on the line 38, 38 of Fig. 36. Fig. 39 (Sheet 10) is a diagram illustrating the run of the webs in producing six ten-page papers all printed by the printing couples at one end of the machine, three of the papers going to one folder mechanism and three going to the other. Figs. 40, 41 and 42 are respectively a top plan, side elevation and end elevation of a three-deck single-ender two-plate-wide machine having diverging angle bars, and having folder mechanisms at right angles to the printing couples. Fig. 43 is an enlarged detail of the angle bars shown in Figs. 40-42. Figs. 44, 45 and 46 are respectively a top plan, side elevation and end elevation of a three-deck single-ender two-plate-wide machine embodying a former and having first 105 folder mechanisms at right angles to the printing couples. Figs. 47, 48 and 49 are respectively a top plan, side elevation and end elevation of a three-deck single-ender two-plate-wide machine, embodying a long angle bar and coöperating, diverging shorter angle bars and having folder mechanisms parallel to the printing couples. Fig. 50 is an enlarged isometric projection of the long angle bar shown in Fig. 47. Figs. 51, 52 and 53 (Sheet 14) are respectively an enlarged side elevation, top plan and cross section of the train of gears for operating the supplement cutter cylinders at half speed or at full speed. Fig. 54 (Sheet 6) is an end elevation of the same mechanism that is illustrated in Fig. 13 but shows the parts in a different relation to each other. Fig. 55 (Sheet 9) is an enlarged partial elevation and sectional view of one of the cutter cylinders and shows means for operating the cutter blades; Fig. 56 is a vertical section on the line 56, 56 of Fig. 55. Fig. 61 (Sheet 17) is a central vertical section through a five-deck, four-plate-wide apparatus 110 115 120 125

equipped with plates having lengthwise columns, and shows in elevation the mechanisms for making the second and third folds. Fig. 62 is a partial side elevation of a double-ender machine five decks high and four plates wide, and having formers, also having opposite main carrier-cylinders below the formers and on different levels and at right angles to the printing couples. Fig. 63 is an elevation of one end, viewed from the center, of an apparatus the same as is illustrated in Fig. 62. Fig. 64 is a diagram showing the arrangement of the pages on a four-plate wide supplement web, the columns being transverse to the web. Fig. 65 is a diagram showing the arrangement of the pages on a four-plate-wide supplement web the columns being lengthwise of the web. Fig. 66 is a diagram showing the arrangement of the pages on a four-plate-wide main web, the columns being transverse to the web. Fig. 67 is a diagram showing the arrangement of the pages on a four-plate-wide main web, the columns being lengthwise of the web. Fig. 68 is a diagram showing the run of the members of a two-plate-wide supplement web running over opposite formers. Fig. 69 (Sheet 6) is an enlarged partial perspective view showing the run of a supplement web with columns lengthwise of the plate cylinder, and the alternate run to opposite carrier-cylinders of sheets cut from the supplement web. Fig. 70 is an enlarged perspective view showing the arrangement of tapes on a former. Fig. 71 (Sheet 12) is an elevation of one end of a four-plate-wide apparatus with formers on different levels. Fig. 72 is an isometric diagram of a five-deck double-ender three-plate-wide apparatus of modified construction equipped with plate cylinders having lengthwise columns and first folder devices parallel to the printing couples; and shows means for effecting alternate run of the supplement sheets; means for dropping after the first fold; means for making the third fold; means for stuffing the assembled sections in the third fold and means for delivering the papers after the third fold. In this view the formers and the carrier cylinders folder mechanisms and delivery mechanisms below the formers are the same as are illustrated in Figs. 6 and 9, and the switches between the intermediate cylinders next below the formers are the same as are shown in detail in Figs. 32 to 35, inclusive. Fig. 73 is an isometric diagram of a five-deck double-ender four-plate-wide apparatus of modified construction, with plate cylinders having circumferential columns, and provided with first folder devices at right angles to the printing couples; means for cutting the webs before making the first fold; assembling devices coöperating with the first folder devices; and second folder devices co-
operating with the first-folder device and the assembling devices. In this view all of the webs are shown as running from one end of the machine; one member of the composite web is shown as supplying supplement sheets to one first folder device, and the other member of the same web is shown as supplying supplement sheets to another folder device; and the formers and the carrier cylinders, folder mechanisms and delivery devices below the formers are in the same relation to each other as shown in Figs. 27 and 59; and the switches between the cylinders next below the formers are the same as are shown in detail in Figs. 32 to 35 inclusive. Fig. 74 is an isometric diagram of a three-deck two-plate-wide apparatus, with lengthwise columns, and equipped with angle bars and having first folder mechanisms at right angles to the printing couples also having coöperating cutter and carrier devices adapted to supply supplement sheets alternately to the main carrier cylinders; assembling devices intermediate of the main carrier cylinders and swinging-blade second folder devices. In this view one member of the composite web is shown as running to the supplement cutter and carrier cylinders to be cut into supplement sheets, and the other member of the same web is shown as running to one of the main cutter devices to be cut into main sheets. Fig. 75 is an isometric diagram of a five-deck double-ender four-plate-wide machine with circumferential columns; formers for making the first fold; main cutter devices cutting above the formers and supplement cutter and carrier devices adapted to deliver supplement sheets alternately to the first folder devices. In order that the relation and coöperation of the different mechanisms comprised in the apparatus as a whole may be clearly understood, it is necessary to treat the several printing mechanisms, cutter mechanisms and folder mechanisms of a double-ender apparatus, as separate units comprised in a single apparatus and to this end the reference letters designating like parts in the several views are provided with exponents prime ('), second (''), third (''''), 105 110 115 x, y, etc., to distinguish one from the other. In the drawings I have shown six different kinds of apparatuses embodying my invention, viz: a five deck double-ender apparatus having first folder mechanisms parallel to the printing couples and second folder devices at right angles to the printing couples; a single-ender two-plate wide machine three decks high and having folder mechanisms at right angles to the printing 120 125 couples and equipped with diverging angle bars; a three deck two-plate wide machine having folder mechanisms at right angles to the printing couples and provided with a former; a three deck two-plate wide machine 130

having folder mechanisms parallel to the printing couples and equipped with angle bars; an apparatus equipped with opposite folder mechanisms all on the same level; and an apparatus equipped with folder mechanisms on different levels.

I will first describe in detail the preferable form of the apparatus, illustrated in Figs. 1, 2, 3, 4 and 72, viz: a five-deck three-plate wide double-end apparatus equipped with plate cylinders having lengthwise columns; and will then describe other modified forms of the apparatus. That part of the apparatus including the left-hand printing couples of all of the decks and the left-hand folder and cutter mechanisms will be designated as the left-hand end of the apparatus and that part of the apparatus including all of the right-hand printing couples and the right-hand folder and cutter mechanisms will be designated as the right-hand end of the apparatus. The main frame 1 and the printing couples 2, 2^a, 2^b, 2^c, etc., may be of any usual and approved construction. A revoluble supplement cutter cylinder 4' co-operates with a revoluble supplement carrier cylinder 5' shown in detail in Fig. 13. Main cutter cylinders 6 and 6' coöperate with the main or first carrier cylinders 7 and 7'. The main carrier and the main cutter cylinders may be of any approved construction. The three plate wide five-deck double-end apparatus has two main cutter cylinders 6 and 6', two main carrier cylinders 7 and 7' and two first folder mechanisms coöperating with the cutter cylinders respectively, and an intermediate supplement cutter cylinder 4' and a carrier cylinder 5' supplying supplement sheets alternately to the first folder mechanisms. This position of the parts admits of running the supplement webs at full speed and admits of equipping half of the supplement plate cylinders with four regular pages of matter.

The main carrier-cylinders 7 and 7' are exactly alike. A carrier-cylinder embodying the preferable details of construction is illustrated in Figs. 36, 37 and 38.

A feature of this apparatus which is of great practical advantage is that the machine is adapted either for newspaper work or magazine work, as will now be explained.

A circular central plate M, (Fig. 36), an outer cam-plate M¹ and an inner cam-plate M², preferably integral with each other, are secured on the side piece of the main frame at one end of the cylinder 7. Folder blades M⁴ of the usual well known construction are mounted on shafts m which extend through the cylinder 7 and turn in suitable bearings on the cylinder. Cog pinions m¹ are secured on the shafts m. A circular plate M³, having a circular channel m² adapted to accommodate blocks m³ connected with the shafts m, is secured on the side of

the main frame and has a toothed segment m⁴ with which the pinions m¹ alternately mesh at one stage of the revolution of the cylinder 7, and the pinions meshing with the teeth of the segment cause the blades M⁴ to turn and project the edges of the blades alternately outward through the openings m⁵ each time that an opening m⁵ is adjacent to the folder rollers 8 and 8^a. Shafts M⁶ extend through the cylinder 7 and oscillate in suitable bearings m⁶ within the cylinder. Pins m⁷ of the usual construction are mounted on the shafts M⁶ and are adapted to project through corresponding openings m⁸ in the cylinder 7. Arms M⁷ secured on the shafts M⁶ are provided with rollers m⁹ which run in contact with the circumference of the plates M, M¹ and M² respectively. The arms M⁷ are adapted to slide and turn on the shafts M⁶ and may be slid inward or outward on the shafts and adjusted so that the arms on any one or all of the shafts may be caused to run on the central plate M; or one set of arms may be caused to run on the plate M² and the other set may be caused to run on the plate M¹. When the arms are properly set they may be secured in position on the shaft by means of the set screws m¹².

The shafts M⁶, the arms M⁷ and the plates M, M¹ and M² are in such relation to each other that when the rollers m⁹ of the arms M⁷ run on the central plate M, all of the pins m⁷ will be retracted and when the rollers m⁹ run on the high parts m¹⁰ and m¹¹ of the plates M¹ and M² respectively the pins m⁷ will be retracted, and when the rollers run on the low parts of the plates M¹ and M², the pins operated by the arms respectively will be caused to project through the openings m⁸.

The openings m⁸ are so situated relative to the revoluble blades M⁴ that the sets of pins which are adapted to be operated by the cam plate M² will be removed from the folder blade M⁴ a distance equal to the width of a newspaper page; and the pins which are adapted to be operated by the cam-plate M¹ will be removed from the folder blade a distance equal to the width of a magazine page.

If it be desired to fold newspapers, the newspaper set of pins will be in use and the magazine pins will be in disuse; or if it be desired to fold magazines, the magazine pins will be in use and the newspaper pins will be in disuse. In order to bring the magazine pins into use it is only necessary to set one pair of the arms M⁷ so that the wheels m⁹ of that pair will run on the cam-plate M¹ and set the other pair of arms M⁷ so that the wheels m⁹ will run on the central circular plate M. The pins operative by the arms with which the rollers running on the central plate are connected will be in

dis-use, while the pins operated by the arms with which the rollers running on the cam-plate M^2 are connected will be in use; or the arms M^7 may be set so that the rollers 5 m^9 connected with one pair of arms, will run on the cam-plate M^1 , and in that case the magazine pins will be in use and the newspaper pins will be in dis-use.

In operating the carrier-cylinders 7 and 10 $7'$ to fold newspapers, the pair of arms M^7 actuating the pins remote from the folder blades will be in use and the arms operating the pins near the folder blades will be in dis-use; and in operating the cylinders to 15 fold magazines the arms operating the pins nearest to the folder blades will be in use and the arms operating the pins remote from the folder blades will be in dis-use.

In order to avoid premature cutting of 20 the webs the cutter mechanisms must be so constructed and arranged that the blades will be effective to cut the sheets at the instant required, but at all other times will be retracted within the circumference of the 25 cutter cylinder so that they cannot injure the sheets traveling on the cylinder.

The cutter cylinders 6 and $6'$ are both alike and a description of one will suffice for both. The cylinder 6 (shown in detail 30 in Figs. 25 and 26) is secured on a shaft 6^p which turns in suitable bearings on the main frame. A circular plate 6^d co-axial with the cylinder is secured on the main frame near one end of the cylinder and has a channel 6^e 35 adapted to guide a little roller 6^g running in the channel. A shaft 6^k extends lengthwise through and oscillates in suitable bearings on the cylinder. Arms 6^h are secured on the shaft 6^k and have a hinge connection with 40 the blades 6^m . An arm 6^l is secured to the shaft 6^k and has a little roller 6^f fitting in the channel 6^e of the plate 6^d . Rubber strips 6^m extend lengthwise on each side of the blade and are held in place by plates 6^a ; and 45 the blade, the plates and the strips are connected with each other by bolts 6^c . When the cylinder 6 revolves, the little roller 6^f running in the channel 6^e and traveling on the cam 6^g imparts a reciprocating movement to the arm 6^l which causes the blades 6^m to be projected at the proper instant to cut against a suitably placed cutting-wood on the main carrier-cylinder and after the cutting to cause immediate retraction of the blade. The paster devices 45^b and $45^b'$ (Fig. 50 1) apply paste to the uppermost main webs running on the cylinders 6 and $6'$ respectively. Folder rollers 8 and $8'$ and a slitter roller 9 all of the usual construction, 55 operate with the folder cylinder 7 and similar folder rollers $8'$ and $8''$ and a slitter roller $9'$ co-operate with the folder cylinder $7'$.

Formers 12 , 12^a and 12^b (Figs. 2, 3) are 60 in operative relation to the folder rollers 8

and $8'$ and the slitter roller 9 and similar formers $12'$, $12^a'$ and $12^b'$ are in operative relation to the folder rollers $8'$ and $8''$ and the slitter roller $9'$. Suitably mounted tape wheels 13 , 13^a and 13^b (Figs. 1, 3 and 70) 70 carry tapes 14 , 14^a and 14^b running on the rollers 8^a and 9 and extending downward along the formers 12 , 12^a and 12^b respectively. Similar wheels $13'$, $13^a'$ and $13^b'$ carry tapes $14'$, $14^a'$ and $14^b'$ which run on and rollers $8'$ and $9'$, and extend downward along the formers $12'$, $12^a'$ and $12^b'$ respectively. The formers are all exactly alike so that a description of one will suffice for all.

The formers 12 , 12^a , etc., (Figs. 1 and 3) 75 are of the usual construction except that each of the formers has a downwardly extending wedge-shaped member 12^x called the nose, which serves to guide downward and crease the webs or sheets, as the case may be, 80 and change the direction of travel of the webs or sheets from a horizontal to a vertical direction.

Carrier cylinders 19 , 19^a , 19^b , $19'$, $19^a'$ and $19^b'$, of suitable construction, clearly shown 90 in Figs 3, 4 and 27, and hereinafter described, are situated below and receive papers from the formers 12 , 12^a , 12^b , and $12'$, $12^a'$ and $12^b'$. The carrier cylinders 19 , 19^a , etc., revolve parallel to each other, and 95 at right angles to the printing couples. Delivery wheels 67 and 67^a , receive papers running from the carrier cylinders 19 , 19^a , 19^b ; and similar delivery wheels receive papers running from the carrier cylinders $19'$, $19^a'$ and $19^b'$. Suitable switches 23 (Fig. 1) co-operate with the carrier cylinders 7 and $7'$, and the formers 12 and $12'$, to control the run of the first-folded sheets from the carrier cylinders to the intermediate dropper 105 device 67^x , or to the formers 12 , $12'$, etc., as hereinafter described, and equivalent switches co-operate with the carrier cylinders 19 , 19^a ; and the carrier cylinders $19'$, $19^a'$.

In the drawings I have shown four different kinds of switches effective for controlling the run of the sections and the papers viz: the switch 23 shown in Figs. 1; 15-24 and Fig. 39; the combined oscillative switch blades and strippers 81 , 81^a , shown in Figs. 5 to 9 inclusive; switches comprising co-operating oscillative members N^1 and N^2 , shown in detail in Figs. 25 and 27; and double switches comprising oscillative members 69 and 69^a and a fixed shield-member 69^e , 120 shown in Figs. 30, 32-35 inclusive, and Figs. 72 to 75 inclusive. I prefer to use switches of the kind shown in detail in Figs. 30 and 32-35 inclusive but it is to be understood that switches of any of the kinds shown, or equivalent switches may be used within the scope of my invention.

I will hereinafter describe the operation of a machine employing the switches 23 shown in Figs. 1; 15-24; and Fig. 39 and 130

will also describe the operation of switches of the other forms.

Folder rollers 20, 20^a and 20^b of the usual construction, coöperate with the carrier cylinders 19, 19^a, 19^b, 19', 19'^a, 19'^b. Tapes 15, 15^a and 15^b (Figs. 3 and 70) run around the rollers 9, 17 and 17^a and tapes 16 run around the rollers 17, 17^a and 18. The rollers 17 and 18 are close to and parallel to the sides of the noses 12^x of the formers and the tapes 15 and 16 running thereon cause the sheets to hug the sides of the formers so that the sheets will be centrally creased and folded during their passage downward along the formers. The sets of pinch-wheels and slitters (Figs. 10 and 11) are all alike, so a description of one set will suffice for all. The slitter roller 9 turns in suitable bearings on the main frame.

20 A disk 9^a (shown in detail in Figs. 10 and 11) having a knife edge turns in the fork of an arm 9^b which may be turned and set in different positions on the stationary shaft 9^c parallel to the roller 9. An arm 9^c is turnable on the shaft 9^c. A collar 9^d may be slid and turned on the shaft 9^c and may be secured in different positions on the shaft to control the tension of the spring 9^e. A spring 9^e surrounds the shaft 9^c and one end of the spring is connected with the collar 9^d and the other end is connected with the arm 9^c in such manner that the spring acts to turn the arm downward and the torsion of the spring may be changed by changing the setting of the collar 9^d. Forked plates 9^a are longitudinally adjustable on the arm 9^c. Pinch-wheels 9^e turn in the forks of the plates 9^a and run in contact with the circumference of the roller 9.

40 In practice the webs to be slitted run on the roller 9 and under the wheels 9^e and the pressure of the wheels on the webs may be controlled by setting the collar 9^d to give to the spring 9^e the torsion necessary for the desired pressure and the arm 9^b may be in like manner set in position to most effectively slit the webs running on the roller 9. The mechanisms are driven by twin motors 30-30', (Fig. 2) of any suitable construction placed in suitable position relative to the apparatus and operating separately or together to drive the different trains of gears as hereinafter explained. Spur wheels 31-31' secured on the motor shafts mesh with an intermediate spur wheel 32. The motors run in the same direction and when both motors are running they will both operate to turn the wheel 32. Either motor alone may be used to drive the machine by disconnecting the spur wheel on the shaft of the motor which is to be in dis-use. The spur wheel 33 is secured on the same shaft and turns with the wheel 32. Spur wheels 35 and 35' slide on the shafts 40 and 40' transverse to the machine and are secured

by set screws 40^a and 40^{a'} respectively. The wheel 33 meshes with and drives the wheel 35'. An intermediate spur wheel 34 meshes with the wheels 33 and 35. Intermediate spur wheels 36 and 37, driven by the wheel 35 communicate motion to one of the wheels 38 and similar wheels 36' and 37' driven by the wheel 35' communicate motion to one of the wheels 38'. The intermediate spur wheel 37 is slidable on its spindle 37^a and 75 when pulled outward will throw out of gear the printing couples of the left-hand end of the machine, and the wheel 37' is slidable on its spindle 37'^a and when pulled outward will throw out of gear the printing couples 80 of the right-hand end of the machine. Intermeshing spur wheels 38 are secured on the shafts of the plate cylinders and blanket cylinders at one end of the machine and similar spur wheels 38' are secured on the 85 shafts of the plate cylinders and blanket cylinders at the other end of the machine. Intermediate spur wheels 39 connect the wheels 38 of the different decks at one end of the machine and similar spur wheels 39' 90 connect the wheels 38' of the different decks at the other end of the machine.

Bevel cog wheels 41-41' (Fig. 4) secured on the shafts 40-40' mesh with and drive bevel cog pinions 43-43' secured on revolute vertical shafts 42-42' (Fig. 2). Bevel cog wheels 44-44' secured on the upper end of the shafts 42-42' mesh with and drive combined bevel cog pinion and spur wheels 45-45' secured on the paster shafts 45^a-100 45^{a'}, see Fig. 1. Spur wheels 48 and 50 are secured on the shaft of the main cutter cylinder 6 and the main carrier cylinder 7 and similar wheels 48' and 50' are secured on the shaft of the main cutter cylinder 6' and the 105 main carrier cylinder 7'. Pinions 51 and 51' secured on the shafts of the folder rollers 8^a and 8^{a'} mesh with and are driven by the wheels 50 and 50' respectively. Spur wheels 54 and 55 (shown in enlarged detail in Figs. 51 and 52) are secured on the shaft of the supplement carrier cylinder 5'. The wheel 54 meshes with and drives a pinion 58 secured on the shaft of the supplement cutter-cylinder 4'. Integral spur wheels 56-57 (Figs. 51, 52, 53) are slidable on a short revolute shaft 57^a. The wheel 56 meshes with and is driven by the broad faced wheel 45'. When the parts are in the position shown in Fig. 52 the wheel 57 meshes with the wheel 54 and drives the supplement carrier cylinder and the supplement cutter-cylinder at half speed and when the wheel 56 is slid outward and secured in proper position the wheel 56 meshing with the pinion 55 drives the supplement carrier-cylinder and supplement cutter cylinder at full speed.

The vertical shaft 42 shown in Figs. 2 and 4, runs at full speed and through the instrumentality of the gears 45, 49, 48, 50 and 110

95

105

115

120

125

51 drives the main cutter-cylinder 6, the main carrier-cylinder 7, and the folder rollers 8 and 8^a at full speed; and in like manner the shaft 42' through the instrumentality of the wheels 45', 49', 48', 50' and 51' drives the main cutter-cylinder 6', the main carrier-cylinder 7' and the main folder rollers 8' and 8^a at full speed. The wheel 49 is slideable on its spindle 49^a and may be pulled to place in dis-use the left-hand main cutter cylinder, main carrier-cylinder, tape rollers, and first folder rollers; and the wheel 49' is slideable on its spindle 49^a' and may be pulled to place in dis-use the right-hand main cutter cylinder, main carrier cylinder, tape rollers and first folder rollers.

In practice webs from both ends of the machine may be led to one end to be operated upon by the main cutter, carrier, and folder devices of that end of the machine; but in that case all of the webs from both ends of the machine must be controlled just the same as if all of the main cutter, carrier, and folder mechanisms were in use and in order that all of the webs may be properly controlled it is desirable that the web controlling and slitting devices 24 and 24' (Fig. 1) remain always in operation. To accomplish this result the web controlling devices are actuated by the intermediate wheels 47 and 47' driven by the wheels 45 and 45'. The wheels 45 and 45' also drive the main cutter cylinders by means of the intermediate wheels 49 and 49'. If the wheels 49 and 49' be pulled the main cutter cylinders will stop but the web controlling devices will continue in operation.

If it be desired to operate both the printing mechanisms and the folder mechanisms of the left-hand end of the apparatus and place both the printing mechanisms and the folder mechanism of the right-hand end in dis-use it will only be necessary to slide the wheel 35' on the shaft 40' to place it out of mesh with the driving wheel 33; and if it be desired to place the left-hand end in dis-use it will only be necessary to pull the wheel 35 out of mesh with the drive wheel 34. Intermeshing pinions 52 and 53 are driven by the wheel 50 and operate the tape rollers adjacent to the cylinder 7 and the intermeshing pinions 52' and 53' are driven by the wheel 50' and drive the tape rollers adjacent to the cylinder 7'. Bevel cog wheels 60 and 60' (Figs. 1 and 4) secured on the shafts 40 and 40' drive bevel cog pinions 63 and 63' secured on horizontal revoluble counter shafts 59 and 59'. Spur wheels 62, 62^a and 62^b are connected with the shafts of the cylinders 19, 19^a and 19^b and similar spur wheels 62' and 62^a' and 62^b' are connected with the shafts of the cylinders 19', 19^a' and 19^b'. Spur wheels 61^a and 61^b on the shafts 59 and 59' drive the trains of gears connecting the cylinders.

In Figs. 1, 15-24 inclusive and 39, 60 and 72 I have shown supplement cutter and carrier cylinders 4' and 5' of the type illustrated in detail in Fig. 13; but the supplement cutter and carrier cylinders of the construction illustrated in detail in Fig. 12, and shown in Figs. 42, 46 and 48, may be used within the scope of my invention, and without material change in any of the other mechanisms.

I will first describe the supplement cutter and carrier mechanisms of the type shown in Fig. 12 and will then describe the supplement cutter and carrier mechanisms of the type illustrated in Fig. 13. The supplement cutter cylinder 4 and the co-operating supplement carrier-cylinder 5 (Fig. 12) turn in suitable bearings on the main frame 1 and are equipped with pins 4^b and 5^b and means for operating the pins as hereinafter described. A radial blade 4^c is secured on and extends the full length of the cylinder 4. A shaft 4^a extends the full length of and is mounted to oscillate within the cylinder 4. Pins 4^b are connected with the shaft 4^a. Diametrically opposite arms 4^d are secured on the shaft 4^a by set screws 4^m. Little rollers 4^e turn on pins on the arms 4^d and travel on the circumference of a stationary circular plate 4^k coaxial with the cylinder 4. Diametrically opposite arms 4ⁿ are suitably secured on the shaft 4^a. Brackets 4^f are secured on one end of the cylinder 4. Rods 4^g connected with the arms 4ⁿ slide in holes in the brackets 4^f. Springs 4^h surround the rods 4^g and normally act to keep the pins 4^b retracted. The plate 4^k has an integral cam 4^k one-half the thickness of the plate. By loosening the set screws 4^m the arms 4^d may be placed in such position that either or both of the little rollers 4^e will run entirely around on the circumference of the plate 4^k, or may be set in such position that one will run entirely around on the circumference of the plate 4^k and the other will run part way around on the plate 4^k and part way on the cam 4^k; or may be set in such position that both will run part way around on the plate 4^k and part way on the cam 4^k. During the time the little rollers 4^e are running on the circumference of the plate 4^k the pins 4^b will be retracted and during the time that the little rollers 4^e are running on the cams 4^k the pins 4^b will be projected. This construction and arrangement of the parts admits of the use of either set, or both sets, of the pins 4^b as may be desired.

The cylinder 5 has diametrically opposite cutting-woods 5^c having suitably spaced holes 5^e accommodating the pins 5^b and also has holes 5^f (Fig. 14) adapted to accommodate the projecting ends of the pins 4^b of the cylinder 4, during the time that the blades 4^c are cutting the sheets upon the cutting-

woods 5^c. The cylinder 5 is equipped with shafts 5^a, pins 5^b, arms 5^d and 5^e, little rollers 5^e, brackets 5^f, rods 5^g and springs 5^h, exactly the same as like parts of the cylinder 4. 5 The stationary circular plate 5^k is concentric with the cylinder 5 and has an integral raised cam 5^{k'} one half the thickness of the plate and the little rollers 5^e are adjustable to run on the circumference of the plate 5^k 10 and the cam 5^{k'} in the same manner that the little rollers 4^e are adjustable to run on the plate 4^k and cam 4^{k'}. The cylinders 4 and 5 turn toward each other and two sheets are cut off for each revolution of the cylinders. 15

Fig. 13 illustrates a modified construction and arrangement of the cutter and carrier cylinders. A segmental plate 4^{k''} is secured on the main frame adjacent to the cylinder 4' and in such position that when the free end of the arm 4^v is pushed inward by the slotted plates 5^t or 5^v acting on the little roller 4^e, the pins 4^b will project through suitably placed holes (not shown) in the circumference of the cylinder and will hold the leading end of the web traveling on the cylinder 4', and the little roller 4^e running in contact with the inner surface of the plate 4^{k''} will keep the arm 4^d in such position that the pins will remain projected as long as the little roller 4^e runs in contact with the plate 4^{k''} and when the little roller runs off the plate the spring 4^h will immediately act to retract the pins. The cylinder 5 or 5' 20 as the case may be, is equipped with two sets of pins and pin-operating devices clearly shown in Figs. 12 and 13. Shafts 5^a oscillate within the cylinder 5'. Pins 5^b are connected with the shafts and are adapted to project through suitably placed holes, not shown, extending through the shell of the cylinder 5'. Arms 5^d are slideable on the shafts 5^a and may be secured in different positions on the shafts by means of set 25 screws 5^m and are equipped with little rollers 5^e. Arms 5ⁿ are suitably connected with the shafts 5^a. Rods 5^g are connected with the arms 5ⁿ and slide in holes in stationary brackets 5^f. Springs 5^h surround 30 the rods 5^g and act to hold the little rollers 5^e in contact with the surfaces of the stationary cam 5^k.

Slotted segmental cam-plates 5^t and 5^v are connected with one end of the cylinder 5' by bolts 5^{t''}. By loosening the nuts on the bolts 5^{t''} the plates may be slid inward or outward to cause the cam-surfaces of the plates to project beyond or lie within the circumference of the cylinder as may be deemed desirable during the operation of the machine as hereinafter explained. The diameter of the cylinder 4' is half the diameter of the cylinder 5'. If the plates 5^t and 5^v be set to project beyond the circumference of the cylinder 5' they will alter-

nately act on the little roller 4^e to depress the arm 4^v and cause the pins 4^b to project beyond the circumference of the cylinder 4'; and as the cylinder 4' continues to revolve the little roller 4^e will reach the point of the cam 4^{k''} at the instant before the plate 5^t or 5^v, as the case may be, begins to turn away from the roller (see Fig. 54, Sheet 6) and the roller traveling on the inner surface of the cam 4^{k''} will, while the roller is running on the cam, prevent the spring 4^h from acting to cause the retraction of the pins, and the pins 4^b will hold the leading end of the web upon the cylinder until it is stripped from the cylinder by the strippers 76^a and upon being stripped from the cylinder the cut sheets will fall upon the tapes 75^a and be carried downward on the tapes and under the strippers 76^a during the time that the cylinder 4' is completing its revolution, and upon the completion of the revolution the part of the web carried on the tapes will be cut, and thus a sheet will be cut off for each revolution of the cylinder 4' and all of the cut sheets will be carried downward on the tapes 75^a so long as both of the plates 5^t and 5^v remain in use. 70 75 80 85 90 95

If only one of the plates 5^t, or 5^v be in use the pins 4^b of the cylinder 4' will be brought into action only once during each revolution of the cylinder 5'; and since the cylinder 4' makes two revolutions to one revolution of the cylinder 5', the pins 4^b will be in use during one revolution of the cylinder 4' and in dis-use during the next revolution of the cylinder 4' and in that case the leading end of the web will be alternately carried around on the cylinders 4' and 5' as I will now explain. 100 105

When the web is to be carried around on the cylinder 4' the pins 4^b must hold the leading end of the web and when the web is to be carried around on the cylinder 5' the pins 5^b must hold the leading end of the web. If the web is to run always on the cylinder 4' the pins of that cylinder must always be effective to hold the leading end of the web on that cylinder; if the web is to run always on the cylinder 5' the pins of that cylinder must always be effective to hold the leading end of the web on the cylinder 5'; and if the web is to run alternately on the cylinders 4' and 5', the pins 4^b and 5^b respectively must be alternately effective to hold the web first on one cylinder and then on the other. 110 115 120

The cylinder 5' has plates 5^t and 5^v adapted to bring into action the pins 4^b, and also two corresponding sets of pins 5^b and means for projecting and retracting the pins 5^b. When one of the plates 5^t or 5^v is in use the adjacent set of pins 5^b must be in dis-use; for the reason that the plate 5^t in use causes the projecting of the pins 4^b and if the

5 pins 5^b adjacent to the effective plate 5^t , or 5^v were also in use there would be two sets of pins operating on the web at the same time and neither set would be effective for controlling the run of the web.

10 I will now describe the means for making both sets of pins 5^b effective, the means for making one set effective and the other set ineffective and the means for making both sets ineffective.

15 When the arms 5^a are set on the shafts 5^a respectively in the position shown in Fig. 13 both of the little rollers 5^e will run on the surface of the cam 5^k , one roller being on the high part of the cam while the other is on the low part. The rollers 5^e are constantly held against the cam by the springs 5^h acting on the arms 5^a .

20 During the travel of the rollers 5^e respectively, the high part of the cam 5^k will cause each arm in succession to move outward, thereby turning the shafts 5^a in succession so as to cause the projecting of the pins and the pins will remain projected and effective so long as the rollers 5^e continue 25 to run upon the high part of the cam and when the rollers run on to the low part of the cam the arms 5^a will move inward and will thereby turn the shafts 5^a to cause the 30 retraction of the pins 5^b through the holes 5^c and the pins will continue retracted and ineffective so long as the rollers continue to run on the low part of the cam. The 35 circular plate $5^{k''}$ is integral and concentric with the cam 5^k and the diameter of the plate $5^{k''}$ is equal to the diameter of the low part of the plate 5^k (Fig. 14). If the arms 5^a be slid inward and set in such position that the little rollers 5^e will run on the 40 circumference of the plate $5^{k''}$ and will be held in constant contact therewith by the springs 5^h , the pins 5^b will be retracted, and since the running of the rollers 5^e on the circular plate $5^{k''}$ will not cause any 45 movement of the arms 5^a , the pins will remain retracted and ineffective so long as the rollers continue to run on the circular plate $5^{k''}$. If one of the arms 5^a is set so that its roller 5^e will run on the circular 50 plate $5^{k''}$ and the other arm 5^a is set so that its roller 5^e will run on the cam 5^k the pins operative by the first named arm 5^a will remain constantly retracted and ineffective, and the pins operative by the last 55 named arm 5^a will be alternately projected and retracted and will be alternately effective and ineffective.

From the foregoing it will be seen that when both sets of pins 5^b are effective both 60 plates 5^t and 5^v and the pins 4^v will be ineffective and the web will be held only by the pins 5^b .

65 If one set of pins 5^b is effective and the other set is ineffective, the plate 5^t , or 5^v adjacent to the effective set of pins will be

ineffective and the plate adjacent to the ineffective set of pins will be effective to bring into action the pins 4^v of the cylinder $4'$, and the web passing between the cylinders $4'$ and $5'$ will be alternately held by the pins 4^v and the pins 5^b on the cylinders $4'$ and $5'$ respectively; and if both sets of pins 5^b are ineffective both of the plates 5^t and 5^v will be effective to bring into action the pins 4^v and the web will be constantly held by the pins 4^v on the cylinder $4'$ and will not be caught and held by the pins 5^b on the cylinder $5'$. This construction and arrangement of the mechanism admits of running all of the cut sheets to the right on to the 75 tapes 75^a , or all to the left on to the tapes 75^a , or alternately to the right and the left on to the tapes 75^v and 75^a respectively; and also admits of the use of a full width supplement-web running at full speed, a supplement sheet being cut off for each revolution of the cutter cylinder $4'$. This feature is of great practical advantage because all the webs used on the machine are full-width webs and the run of all of the webs is a continuous straight run and hence it is unnecessary to use angle bars or equivalent devices for changing the direction of run of the webs and it is unnecessary to adjust the run of the webs and there is no necessity for 95 changing the spindles, the fountain rollers and the form rollers. Another practical advantage is that when a full-width supplement-web is used the blankets on the blanket cylinder will be evenly beaten down over the entire surface of the cylinders, whereas if a half-width supplement web is used that half of the blanket cylinder $8n'$ on which the half web runs will be beaten down, but the other half will not be beaten down, hence when a full width web is afterward used on the same cylinder the inequality of the blanket resulting from one-half being beaten down and the other half not being beaten down will cause very troublesome irregularity in the run of the full width web.

When the supplement printing couples and the supplement cutter cylinders are operated at full speed with full-width webs and both of the opposite folder mechanisms are in use; these folder mechanisms may be either horizontal or vertical and may be on the same level or on different levels, the supplement printing couples will be equipped with only half as many plates effective in printing the supplement as have heretofore been used in printing on full-width supplement webs and if it is desired to print four additional regular pages running through one of the opposite folder mechanisms concurrently with the supplement, the supplement web will be slotted, one member will be used in printing two two-page supplements for each revolution of the printing couples, the other member will be used in 120 125 130

printing four pages of regular matter for each revolution of the printing couples, and the plate surface of the supplement cylinders, which under the art as practiced prior to my invention has run idle, will be utilized to print four additional regular pages, and a ten-page paper may be run through one folder mechanism and a fourteen page paper may be run through the opposite folder mechanisms; and by this means the number of pages of the product may be increased to the extent of four pages for each and every supplement-deck in operation; that is to say; if five decks are in operation and supplements are running on one deck the gain will be four regular pages, and if supplements are running on two decks the gain will be eight pages, and so on according to the number of supplement decks in operation.

If four-plate-wide webs be used on printing couples of a double-ender machine with columns lying around the plate cylinders, as in Figs. 61, 62 and 63 and a four-plate wide supplement web be used, the main webs will be slit longitudinally to form two web-members, each two pages wide and the supplement web will be slit to form four web-members each one page wide. Two one-page-wide web-members will run over two formers at one end, say the right-hand end of the machine, and two will run over two formers at the opposite or left-hand end of the machine and one two-page wide main web, for each deck in operation, will run over each former and the four supplement web-members will be associated with the four two-page wide web-members on the formers, respectively, and the associated webs and web-members will be cut into sheets one page in length by suitable cutter mechanisms below the former (not shown) and the first-fold of the main sheets will be made while going over the formers. If a two-plate wide double-ender machine having printing couples with columns lengthwise of the plate cylinders, and exactly the same as the machine shown in Figs. 1 to 4 inclusive; except as to width is operated with two-page-wide main webs and two-page-wide supplement webs, the supplement web will be slit longitudinally and each web member will be in width equal to the length of one page plus margins, the supplement web members will be cut into sheets in length equal to the width of one page, and the main webs will be cut into sheets in length equal to the width of two pages plus margins. In either case a two-plate wide supplement web will supply supplements to both of the folder mechanisms and all of the plate cylinders will be run at full speed and the entire surfaces of all the supplement plate cylinders will be used in printing the supplements.

All the webs running from the left-hand end of the machine and which run between the cutter cylinder 6 and the carrier cylinder 7 (Fig. 1) will be associated on the cylinder 7, and the supplement sheets running between the cylinders 4' and 5' will be "inserted" on the carrier cylinder 7; and the sheets from the right-hand end of the machine will run in exactly the same manner and the supplement sheets will be inserted on the cylinder 7'. In this case all the printing couples of all the decks and all the main and supplement cutter and carrier cylinders will run at full speed. The inserted sheets will be carried around the cylinder 7 and the first fold will be made by the rollers 8 and 8', and in like manner the first fold of all the sheets on the cylinder 7' will be made by the rollers 8' and 8''.

If plate cylinders with lengthwise columns be used and it be desired to assemble the first-folded sections with the first-folded edges in the lead, the folder blades of the cylinders 7 and 7' will be timed so that the rollers 8 and 8', and the rollers 8' and 8'' will act to make the first folds, of both sections, at the same instant, and the folded sections will travel with the first-folded edges in the lead to the switch 23, and the switch having been turned to the open position indicated by dotted lines in Fig. 1 both sections will drop together onto the delivery device 67'; or by inclining the switch to the right or left as the case may be the assembled sections, each having a supplement, will run either to the right-hand second-folder device or the left-hand second-folder device as the case may be, and the second-folder device will make the second fold. The switches 69 shown in detail in Figs. 33, 34 and 35 may be used in like manner, and may be set in like manner, to cause the assembled first-folded sections to drop directly onto the delivery wheel 67 or all to run to the left hand formers 12, 12^a, and 12^b, or all to run to the right hand formers 12', 12'^a, and 12'^b; or to cause the sections from the cylinder 7 to run to the formers 12, 12^a and 12^b and the papers from the cylinder 7' to run to the formers 12', 12'^a and 12'^b.

If it be desired to produce a paper comprising one section with a supplement and the other without a supplement, the supplement cutter and carrier cylinders 4' and 5' and one deck of the press carrying the supplement web, will run at half-speed and in that case the complete paper may be either in book form or in sections; and if a paper in sections is produced the insert sheet may be between the inside leaves at the center of the paper or may be between any other two leaves of the paper. After the inserting of the supplement sheet the operation will be exactly as already described. In case of alternate run of the supplement sheets the

carrier cylinders 7 and 7' will both be in use, all mechanism running at full speed, and the supplement sheets will run next to the surface of the carrier cylinders, and if 5 papers comprising collected or assembled sections are produced, each section will have a supplement.

If the product is to be in book form the insert sheet may be placed between any two 10 leaves of the paper, for example (refer to Fig. 21) a web from the right-hand end of the machine running on the carrier cylinder 7', may be led across to and associated on the main carrier cylinder 7 (as indicated by 15 arrow X⁴) with the main web from the left-hand end of the machine, and in that case the supplement sheet will be inserted between the sheets from the right-hand end and the sheets from the left-hand end of the 20 machine; or all of the webs may run from one end of the machine,—one or more of the webs being carried across above the supplement web and run next to the main carrier cylinder 7 or 7' as the case may be—and the 25 supplement sheet may be inserted between the main sheets running on the main carrier cylinder as already described. If it be desired to produce papers in book form without supplements; or papers comprising collected sections, without supplements; the supplement cutter and carrier cylinders will be in 30 disuse but otherwise the run of the webs, the sheets, and the sections, will be the same as already described. If it be desired to print, 35 and fold in book form, a reduced number of pages, with or without supplements, running on the cylinders 6 and 7' and the cylinders 6' and 7'; one set of second-folder devices may be in disuse, or may be entirely dispensed with, without departure from my invention.

I will now describe the operation of a machine equipped with printing couples having lengthwise columns and having in operation only one set, say the left hand set of second folder mechanisms and one third-folder mechanism.

In order that the apparatus may operate as I will now describe, it is necessary that the cylinder 7' be set to run half the length of a main sheet in advance of, or behind, the main sheets running on the cylinder 7; or vice-versa that the cylinder 7 be set to run half the length of a main sheet in advance 55 of or behind the main sheets running on the cylinder 7'. Usually the cylinders 7 and 7' will be timed so that the centers of the sheets receiving the first fold will arrive simultaneously in juxtaposition to the folder rollers 8, 8^a, and the folder rollers 8' and 8'^a.

If it be desired to set the cylinder 7' so that sheets running thereon will arrive at the folder rollers 8, 8^a a half sheet in advance of or a half sheet behind the main 60 sheets running on the carrier cylinder 7 to

the folder rollers 8, 8^a, the gear 49' will be pulled and the cylinder 7' will then be turned by hand, or by any suitable instrument, forward or backward to place it in the desired position, in a manner which is well known. And in like manner upon pulling the wheel 49, the cylinder 7 may be set in any desired position.

In case all of the first folded papers are to run to the left hand second-folder device the 75 cutter and carrier cylinders 6' and 7' will be set to run half the length of a main sheet in advance of, or behind, the main sheets running on the cylinders 6 and 7, and the folder blades of the carrier cylinders 7 and 7' will be set to operate in such time that the first-folded edge of the paper from the folder cylinder 7, will arrive at the assembling device between the first and second folder devices a half sheet in advance of, or a half 80 sheet behind the first folded sheets from the folder rollers 8' and 8'^a and will run in succession to and upon one of the second-folder devices, namely, the former 12, 12^a or 12^b as the case may be and the second fold of all 85 said first folded papers will be made by said former and if a third fold is desired all of the second folded papers will run to the folder rollers 20, 20^a or 20^b as the case may be and the third fold will be made by said 90 folder rollers and in that case the maximum number of papers delivered by a single folder device, in the second fold, or the third fold as the case may be, will be equal to the maximum number of papers which may be 95 delivered by plural second-folder devices and plural third-folder devices co-operating with both of the first-folder devices 8, 8^a, and 8', 8'^a. My invention contemplates any suitable means for making the second fold. 100

It is obvious that a single second-folder device co-operating with plural first-folder devices as set forth, may be used either on a single-end apparatus, or on a double-ender apparatus, and will be equally effective with 105 printing couples having lengthwise columns or circumferential columns and with printing couples parallel to the first-folder mechanism, or printing couples at right angles to the first-folder mechanism. Or one of the 110 second folder devices may be placed in disuse or may be entirely dispensed with, without departure from my invention.

Let it be assumed that the left-hand second folder device (Fig. 30) only is to be 115 used and that the second fold of all the papers is to be made by that folder device. In that case the sheets from the cylinder 7' will arrive at the folder rollers 8' and 8'^a at or about the time that the first-folded paper 120 from the cylinder 7 arrives at the cylinders 64 and 64^a, and the first-folded paper from the cylinder 7' will in like manner travel downward along the tapes 69^a, with the folded edge in the lead, and will arrive at the 125

cylinders 64 and 64^a, a little after the preceding paper from the cylinder 7 leaves the cylinders 64 and 64^a, and in this way papers from the cylinders 7 and 7' will, in alternate succession, be dropped, after the first fold, or will all be carried to the left-hand second folder device and dropped after the second fold, as already described.

Referring to Figs. 1 and 30 it will be seen that if the webs from one end, say the left-hand end of a double-ender machine, such as is illustrated in Fig. 1, equipped with swinging-blade folder-mechanisms such as are shown in Fig. 30, (refer also to Fig. 74, in which is illustrated a similar run of the webs, sheets and papers of a single-ender apparatus), be led to the cutter cylinder 6 and between the cylinders 6 and 7, and cut on the cylinder 7 into sheets and the sheets be thence led downward along the tapes 69^c, and if the webs from the right-hand end of the machine be led to and between the cylinders 6' and 7', and be in like manner cut into sheets on the cylinder 7' and run downward along the tapes 69^c and the cylinders 6 and 7 and 6' and 7' be timed to run in unison, the sheets from the cylinders 7' will arrive at the folder rollers 8' and 8^a coincidently with the arrival of the sheets from the cylinder 7 at the rollers 8 and 8^a and the folded sheets from the cylinders 7 and 7' will coincidently travel downward along the tapes 69^c, with their folded edges in the lead and will simultaneously arrive into position to be seized by the assembling cylinders 64 and 64^a, and may be dropped together in the first fold, or may be run together to the left to the second folder device 68, or run together to the right to the second folder device 68^a; the papers from the cylinders 7 and 7' respectively forming sections of a complete paper, and the complete paper may be folded by the second folder device 68 or 68^a as the case may be; according to the setting of the switches 69. The supplement sheets are delivered next to the main carrier cylinder, and the leading edges of the supplement sheets arrive at the line of contact of the cylinder 6 with the cylinder 7, and the line of contact of the cylinder 6' with the cylinder 7', coincidently with the arrival of the margin between the pages at the line of contact of said pairs of cylinders respectively, and the sheets from the cylinder 7 run between and are folded by the rollers 8 and 8^a and run to the former 12, and the first folded sheets from the cylinder 7' run between and are folded by the rollers 8' and 8^a, and the first folded papers run to the former 12'; or the sheets from both of the cylinders 7 and 7' may drop after the first fold, onto the delivery wheel 67, Fig. 1 or by changing the relative time of the cylinders 7 and 7' as already described, the

first folded papers from both cylinders may pass downward along the former 12; or the first folded papers from both cylinders may pass downward along the former 12' as may be most convenient in practice. This is a very valuable feature of my invention, inasmuch as it admits of the use of a single second-folder device and a single third-folder device in disposing of all the papers derived from all of the webs of a double ender apparatus. This result has not been attained prior to my invention. In other words there are no idle plate surfaces on the supplement plate cylinders having columns lengthwise of the plate cylinders or having columns extending around the plate cylinders.

Referring to Figs. 1 and 72 it will be seen that the pair of cylinders 6' and 7' being timed to run half the length of a main sheet behind the pair of cylinders 6 and 7, the one-leaf supplement sheets from the cylinders 4' and 5' will run alternately to and be inserted between the two leaf sheets running around the cylinders 7 and 7' and will run in succession over the left-hand former 12 and thence will go to the third folder devices 20 and 20^a as has already been explained.

The main cutter cylinders 6 and 6' are so located that they are effective to cut into sheets, in length equal to the width of two pages plus margins, any one or all of the webs running on either end, or both ends, of a double ender machine. It is obvious that in a machine of modified construction organized to use plate cylinders having circumferential columns (such as shown in Fig. 59) the cutter cylinders 6 and 6' may be adapted to cut off one leaf sheets; and may be in operative relation to formers, and carrier cylinders, folder mechanisms and delivery wheels below the formers, and arranged as shown in Figs. 5 to 9 inclusive.

The pair of cylinders 6' and 7' may be set to run approximately a half sheet ahead of or a half sheet behind the pair of cylinders 6 and 7; or conversely, the pair of cylinders 6 and 7 may be set to run a half sheet ahead of or behind the pair 6' and 7', when cutting the sheets, and in that case the cut sheets will run from the cylinders 7 and 7' to the folder rollers 8, 8^a and 8', 8^a' and thence to the formers 12, 12', etc.; according to the setting of the switches, and the timing of the cylinders 7 and 7'. Or the left hand formers 12 and 12' may be situated adjacent to the left hand cutter and carrier cylinders 6 and 7; and the right hand formers 12' and 12^a may be situated adjacent to the right hand cutter and carrier cylinders 6' and 7'; the carrier devices 19 and 19^a and the co-operating folder devices 20 and 20^a may be adjacent to the formers 12, and 12^a; and the carrier devices 19^a and 19^a' may be adjacent to the formers 12', and 12^a'.

and 19' and the coöperating folder devices 20' and 20^a may be situated adjacent to the formers 12' and 12^a; as shown in Figs. 60 and 61; and in that case the cut sheets from the cylinders 6, 7; and 6', 7', will run to the formers 12, 12^a; and 12', 12^a; and the first fold will be made on the formers, and the first-folded sheets will run on the carrier cylinders 19, 19^a; or 19', 19^a as the case 10 may be, to the folder devices 20, 20^a; or 20' and 20^a; and the second fold will be made by said last named folder devices at the option of the operator. In either case supplement sheets will be supplied alternately to 15 the papers running on the cylinders 6, 7 and 6' and 7'.

The diameters of the cylinders 4' and 5'; 6 and 7; and 6' and 7'; may vary according as plates with lengthwise columns, or 20 plates with circumferential columns are used; without departure from my invention; and I claim the relative position and arrangement of the cylinders without regard to the size of the cylinders, the speed at 25 which they are run, or the order in which the plates are laid on the plate cylinders.

An apparatus equipped with main carrier cylinders 7 and 7', main cutter and carrier cylinders 6 and 6', a supplement carrier cylinder 5', tapes 75', and 75^a', or equivalent carrier devices, a supplement cutter cylinder 4', and a slitter device 24^a coöperating with the supplement carrier cylinder 5'; is equally effective for the alternate delivery of the supplement sheets to the cylinders 7 and 7' when plate cylinders having circumferential columns are used, or when plate cylinders having lengthwise columns are used.

40 In an apparatus equipped with plate cylinders having circumferential columns and equipped with a former or equivalent folder device, the main cutter device may be above the former or first folder device as shown in 45 Figs. 1 and 60 and adapted to cut off the main sheets before the first fold is made.

In view of the construction disclosed I claim broadly main cutter devices adapted 50 to cut the main sheets from webs printed on plate cylinders having circumferential columns, before the first fold is made, and equally adapted to cut main sheets from webs printed on plate cylinders having lengthwise columns, before the first fold is made.

The gist of the invention with respect to the cutter mechanisms, lies in the correlation and coöperation of the parts, irrespective of their relative dimensions, or the different speeds at which they may be operated; and it is to be understood that my claims are not restricted to mere combinations of the main carrier cylinders, the main cutter cylinders, the supplement carrier cylinder and the supplement cutter cylinder

with coöperating plate cylinders having lengthwise columns or coöperating plate cylinders having circumferential columns, as the case may be; and inasmuch as the main carrier cylinders, main cutter cylinders, supplement carrier cylinder and supplement cutter cylinder are equally effective with cutter devices adapted to cut off the main sheet before making the first fold, or cutter devices adapted to cut off the main sheet after 75 making the first fold, I do not restrict my claims to the combination of said main, carrier and cutter cylinders and supplement carrier and cutter cylinders with cutter devices adapted to cut the sheets before making the first fold; nor do I limit them to the combination of the cylinders with cutter devices adapted to cut the sheets after making the first fold.

Advertisers in large city papers frequently 85 demand double-page advertisements, and it is desirable to meet this demand as it arises. If the machine is intended to run a twenty-four page paper in book form with a double page advertisement occupying the 12th and 90 13th pages, and an order is accepted for another double page advertisement, the paper may be run in two sections of twelve pages each, one double page advertisement occupying pages six and seven of the first section, 95 and the other double page advertisement occupying pages six and seven of the second section.

City advertisers give the preference to outside pages for advertising. A twenty-four 100 page paper in two sections has two outside sheets for double-page advertisements, whereas a twenty-four page paper in book form has only one outside sheet for double-page advertisements. A paper composed of twenty-four pages may be folded and wrapped for the mails much more conveniently and rapidly than a twenty-four page paper consisting of two sections.

If a machine is running on a mail edition 110 and rapidity of mailing is of first importance, the book-form paper will be preferred. If the machine is running on a city edition in which the demands of advertisers are of first importance, the paper in sections will 115 be preferred. The apparatus herein set forth is constructed and arranged to make the entire product of one preferred form, or to simultaneously make part of the product of one form and part of the other as already 120 described.

A double-ender apparatus three plates wide, with three decks at each end in operation, (six sets of printing couples in all,) and the supplement deck operating at half 125 speed, is adapted to produce three ten-page papers at one end and three twelve-page papers at the other end, or all may be run to one end of the machine to make three twenty-two page papers. The same machine run- 130

ning all the decks at full speed and using a two-plate-wide supplement web on one deck will produce two ten-page papers and four twelve-page papers all in book form. The 5 same machine running all full width webs and all at full speed may produce any one of three different products, viz.: six twelve-page papers; or three fourteen-page papers and three ten-page papers; or two twelve- 10 page papers, two fourteen-page papers and two ten-page papers.

To produce two ten-page papers in sections collected, the practice prior to my invention, has been to use two full width webs 15 on two decks and a half-width supplement web on one deck, and all of the decks running at full speed. When operating in this way only half the surface of the cylinder carrying the supplement plates can be used 20 and the other half of the supplement plate cylinders must run idle; or if the sheets are cut above the former and collected, a half-width half-speed supplement web must be used. It is therefore impossible, under 25 either method of operation to utilize the whole surface of the plate cylinders on which the supplement is printed. The prior practice has also been to use a full-width supplement web running at half-speed; and slit it 30 longitudinally to supply supplement-sheets cut from the web-members and running to two folders side by side. In other words to supply supplement-sheets to both folders, operating simultaneously, it has hitherto 35 been necessary to use a full-width web and eight plates on the supplement printing couples.

I use four plates on the supplement printing couples to supply supplement-sheets to 40 two folders, and may use the other half of the plate surface of the supplement cylinders and the other half of the web from which the supplement is derived, to produce regular pages of the paper. The position of 45 the supplement-cutter device, between the diverging members of the web producing the supplement-sheets, enables me to lead the supplement web-member to the supplement-cutter device, which cuts it into sheets 50 in length equal to the width of one page plus margins, the cut sheets going alternately to the coöperating folder devices; and to lead the other member of the same web to one of the main-cutter devices (which cuts it 55 into sheets in length equal to the width of two pages plus margins,) and deliver said last named sheets to one of said folder devices. In case the columns lie around the plate cylinders, my five-deck two-plate wide 60 machine (see Fig. 39) will have two opposite folders, and the first fold will be made on the formers. Webs from two lower decks will run over the former next to and pointing toward the printing couples. Webs 65 from the two upper decks will run over the

former remote from and pointing away from the printing couples. The central deck will carry the supplement web. The supplement web will be slit longitudinally, one member will run to one former, and the other will 70 run to the opposite former.

A characteristic of this invention is that the relations and coöperations of the mechanisms are such that when printing couples having circumferential columns are used the 75 slitted webs from which supplement-sheets alone, or supplement-sheets in part, and main-sheets in part, are derived, always occupy a position between the main webs with which the slit web from which the supplement is derived is associated and one member of said first-named web always runs to one folder mechanism and the other member of the same web always runs to another folder mechanism; and the supplement web, or composite web, as the case may be, occupies the same position between the parted main webs in case the printing couples have 80 columns lengthwise of the plate cylinders and in case the folder mechanisms are parallel to the printing couples or are at right angles to the printing couples, as the case 85 may be.

The apparatus is adapted either for newspaper work or magazine work. The apparatus is adapted to cut off supplement sheets from a full-speed full width supplement web and insert and fold them in a book-form paper, either when the folder mechanism is 90 at right angles to the printing couples, or 95 parallel to the printing couples. The apparatus is adapted to deliver papers in book-form or in sections at the option of the operator, and the papers may be delivered after the first fold, or after the second fold, 100 or after the third fold, at the option of the operator. The change of delivery may be 105 quickly made, without any change of the mechanism.

Various runs of the webs, cut sheets, sections, and papers are illustrated in Figs. 5-9, inclusive, and will now be described.

Fig. 5 shows parallel formers 12 and 12^a coöperating carrier cylinders 19 and 19^a, folder rollers 20 and 20^a and switches 81 and 81^a in such relation to each other that when the switches are closed the sheets receiving the first fold on the formers will travel downward over the switches respectively and will drop directly onto the delivery wheel 110 67^c, and when the switches 81 and 81^a are open the first-folded sheets from the formers 12 will pass under the switch 81 around the cylinder 19, and the second fold will be made 115 by the folder rollers 20; the first folded sheets traveling downward along the former 12^a will pass under the switch 81^a and around the cylinder 19^a and the second fold will be 120 made by the folder rollers 20^a, and the papers folded by the rollers 20 and 20^a, will 125 130 135

be assembled and dropped together upon the delivery wheel 67^a.

Fig. 6 illustrates parallel formers 12, 12^a, assembling rollers 64—64^a, carrier cylinders 5 19 and 19^a and switches 81 and 81^a such as have already been described. The mechanism shown in this view is adapted to deliver second-folded papers upon two delivery wheels, one adjacent to the cylinder 19 and 10 the other adjacent to the cylinder 19^a; or to assemble the first-folded sections from both formers, run the collected sections to one set of folder rollers 20 or 20^a, as the case may be, and deliver the collected and second- 15 folded papers upon one delivery wheel; or to run the first folded papers over the switches 81 and 81^a and deliver them in the first fold onto the delivery wheels 67^a and 67^b respectively; or to assemble the first 20 folded sections and run them over the switch 81 or 81^a as the case may be, and drop them onto the delivery wheel 67^a and 67^b as the case may be.

Fig. 7 illustrates means for assembling 25 first-folded sheets from two formers and dropping the collected sheets onto a single central delivery wheel 67^a.

Fig. 8 shows a single carrier cylinder 19 in coöperation with two formers 12 and 12^a, 30 assembling rollers 64 and 64^a, a switch 81 and second folder rollers 20. The first folded papers may run over the switch 81 and be dropped in the first fold onto the delivery wheel 67^a; or the first folded sheets from 35 both formers may be run under the switch 81 around the cylinder 19 and be folded by the folder rollers 20; and the second-folded papers with the folded edges in the lead will drop onto the delivery wheels 67^a.

Fig. 9 illustrates an exactly similar arrangement of the carrier cylinder, the switch and the second folder-rollers in coöperation with one former. If plate cylinders with lengthwise columns are used the first fold 45 will be made above the formers by suitable folder mechanisms such as have already been described; the second fold will be made on the former and the third fold will be made by the folder rollers 20 and 20^a; and the second-folded papers or the third-folded 50 papers, as the case may be, will travel with their folded edges in the lead and will drop onto the delivery wheels with their folded edge in the lead.

In a machine organized to use plate cylinders with circumferential columns, as shown 55 in Figs. 59 and 60, formers, carrier cylinders, folder rollers, of suitable size, and delivery wheels, arranged relative to each other 60 as shown in Figs. 5 to 9, inclusive, may be used and in that case the perfected webs will run directly from the printing couples to the formers, the first fold will be made on the formers, and the second fold will be made 65 by the folder rollers, 20 and 20^a.

The arrangement of the formers and assembling rollers in Fig. 71 is the same as that illustrated in Fig. 7 and already described, except that the formers instead of being on one level are on two levels one 70 above the other.

Figs. 47 to 50 inclusive illustrate a three-deck single-ender, two-plate-wide apparatus having plate cylinders with lengthwise columns, and equipped with angle bars for associating and guiding the webs and web members. The first-folder devices are parallel to the printing couples and second-folder devices are at right angles to the printing couples. The printing couples 2, 2^a, 2^b, the cylinders 4, 5, 6, 7, 6', and 7', the folder rollers 8, 8^a; 8', 8'^a, the folder rollers 20, 20^a, the coöperating swinging blades 68 and 68^a and the diverging angle bars P are the same as shown in Figs. 40 and 43. 85 The difference between the apparatuses is merely a matter of the relative arrangement of the mechanisms and a matter of the control of the run of the webs.

If formers or angles are used, purely as 90 associating devices, and plate cylinders having lengthwise columns are used; the apparatus may be one, two, three, or four pages wide, and in either case the sheets will be cut off after passing over the former, the 95 angle-bars, or equivalent associating device.

The apparatus shown in Fig. 40 has diverging angle-bars to cause the web members to travel at right angles to the original line of travel of the webs, whereas the apparatus shown in Fig. 47 has a long angle bar to cause the webs to travel at right angles to their original line of travel, and shorter angle bars to cause the members of the slitted webs to travel in opposite directions, as already explained. The long angle bar consists of a bar P^a having upwardly extending lugs p^a, and feet p having slots p^b to receive bolts p^c connecting the angle bar with the frame. The spindles p^d of the 100 rod R^a turn freely in suitable bearings on the lugs p^a.

The operation is the same as that of the 105 form of the apparatus illustrated in Figs. 40 to 43.

A double-ender four-plate-wide apparatus equipped with plate cylinders having circumferential columns and running at full speed with four decks in operation at one end and three decks in operation at the 110 other end (Fig. 57) will produce four fourteen-page papers. The supplement web from the cylinder 2^a will be slitted by the slitter device 24^a to form four web-members which will go to four formers as already 115 described. The two-page-wide web members from the cylinders 2^b, 2^c, and 2^d will run over the rollers 78 to the formers 12 and 12^a, and the two-page-wide web members from the cylinders 2^b, 2^c and 2^d will run over 120

the rollers 78' to the formers 12' and 12^a. The associated web members on the formers may be cut into one-page-long sheets by cutter-devices of any approved construction 5 (not shown) situated below the formers and the second fold may be made by coöperating folder devices of any suitable construction, not shown.

A double-ender four-plate-wide apparatus 10 equipped with plate cylinders having circumferential columns and running at full speed with three decks in operation at each end may produce from the webs at one end of the machine two ten-page papers and may 15 produce from the webs at the other end of the machine two fourteen-page papers. The supplement web from the cylinder 2^b (Fig. 58) will be slotted by the slitter devices 24^x to form four one-page-wide web-members 20 which will go to four formers, 12, 12', 12^a and 12^a'. The main webs from the cylinders 2^c and 2^d will run over the rollers 78 and will be slotted into two-page-wide members by the slitter devices 25 and will run 25 upon the formers 12 and 12^a respectively. The webs from the cylinders 2^b, 2^c and 2^d will run over the rollers 78' and will be slotted into two-page-wide members by the slitter devices 25' and the web members will 30 go to the formers 12' and 12^a' respectively. Sheets may be cut off below the formers by any suitable cutter mechanism and the second fold may be made by any suitable co-operating folder mechanism. One end of a 35 five deck four-plate-wide machine equipped with plate cylinders having circumferential columns and two-plate-wide formers and operated at full speed will use eighty plates and may be employed as shown by diagram 40 (Fig. 59) to print four ten-page papers. Four supplement sheets will be printed on the web running on the middle deck 2^b.

Two eight-page papers will be printed on each of the webs running on the decks 2^c 45 and 2^d and two eight-page papers will be printed on each of the webs running on the decks 2 and 2^a. The supplement web will be slotted by the slitter devices 24^x to form four web members and the first web member 50 will run to the former 12 and the second web-member will run to the former 12' the third web-member will run to the former 12^a in line with the former 12 and the fourth web member will run to a former 12^a in line 55 with the former 12'. The main webs from the cylinders 2 and 2^a will be slotted by the slitter devices 24 or 24' and run to the formers 12' and 12^a' and will be associated on the formers with the supplement web members 60 running on those formers. The webs from the cylinders 2^c and 2^d will be slotted by the slitter devices 24 and run to the formers 12 and 12^a upon which the main web-members will be associated with the supplement web- 65 members running on those formers respec-

tively. The associated web members on the formers 12, 12^a; 12', 12^a' will be cut (above the formers) into one-page-long sheets by the cutter cylinders 6 and 6' respectively.

The first fold will be made upon the formers and the second fold will be made by suitable coöperating folder mechanisms. If it be desired to paste the supplements, paste will be applied to the uppermost main sheets by paster devices 79 and 79'. Or the webs 75 2, 2^a, 2^c and 2^d may all be run across to and slotted by the slitter devices 24' and all of the main web members and supplement web members associated upon two formers 12' and 12^a, and in that case the supplement 80 web will be only two plates wide and the product will be two eighteen-page papers, and if the sections are collected or assembled and folded together in the second fold the product will be two thirty-six page 85 papers.

A double-ender four-plate-wide apparatus equipped with plate-cylinders having circumferential columns and running at full speed with five decks in operation at one end 90 and four decks in operation at the other end (Fig. 60) will produce from the webs from each end of the machine four eighteen-page papers in book form with supplements. The supplement web from the cylinder 2 will be 95 slotted by the slitter devices 24^x to form four web-members one-page-wide. The slotted supplement web will run between the co-operating cylinders 4' and 5' and will be cut into one-leaf supplement-sheets which, 100 led by the tapes 75^a and 75^a', will go alternately to the carrier cylinders 7 and 7'. The webs from the cylinders 2^b, 2^c, 2^d and 2^a will be slotted longitudinally by slitter devices 24 to divide each web into two members, each two-pages-wide and will go to the cylinder 7. The webs from the cylinders 2^a, 2^b, 2^c and 2^d will be slotted in like 105 manner by the slitter devices 24' and will go to the cylinders 7'. The webs running to 110 the cylinders 7 and 7' will be cut by the main cutter-cylinders 6 and 6' into sheets one-page long and two pages wide. The supplement sheets from the cylinders 4' and 5' will be inserted with the sheets running 115 on the cylinders 7 and 7' respectively. Strippers 80 and 80' will strip the associated or collected sheets from the cylinders 7 and 7' and the associated or collected sheets will travel downward along the formers with the 120 supplement sheets next to the face of the formers and the first fold will be made as the associated or collected sheets pass downward along the formers. The second fold 125 may be made by any suitable coöperating mechanism.

If two-plate wide webs are used and the machine is operated as I have just described, the webs run as shown in Fig. 57, will produce two fourteen-page papers; the webs 130

run as shown in Fig. 58, will produce one ten-page and one fourteen-page paper; the webs run as shown in Fig. 59 will produce two ten-page papers, and the webs run as shown in Fig. 60 will produce two eighteen page papers if the papers are dropped after the first fold; or if the sections are collected after making the first fold, the product will be two thirty-six page papers, from webs running from both ends of the apparatus. The sheets from the webs run as shown in Fig. 60 will be collected on the carrier cylinders 7 and 7'; the supplement sheets will be inserted and the product will be two thirty-four page papers in book form from each end of the apparatus.

A double-ender apparatus three decks high and three plates wide equipped with a full complement of plates will carry seventy-two plates; and when all of the decks are in use and all of the formers and folder-devices are operating at full capacity, these seventy-two plates may be used to print papers of different numbers of pages, which may be dropped after either the first, the second or the third fold, viz: six twelve-page papers; or three twenty-four page papers; or one forty-eight page paper and one twenty-four page paper; or one forty-eight page paper and two twelve-page papers; or four twelve page papers and one twenty-four-page paper; or one seventy-two page paper in three sections after the second fold, or in two sections after the third fold.

Fig. 60 illustrates an apparatus equipped with plate cylinders having circumferential columns and adapted for alternate run of the supplement sheets when producing papers in book form. In order to produce a paper comprising collected sheets and supplements in book form the collecting of the sheets may obviously be done either on the cylinders 6, 6', or on the cylinders 7, 7'. In case the collecting is done on the cylinders 6 and 6', they will be equipped with suitable pins such as have already been described. The supplement sheets running alternately to the cylinders 6, 7, and 6' and 7' will be inserted between two cuts. If the collecting is done on either the cylinder 6 or the cylinder 7 the supplement sheet may be inserted between the leaves; or may run next to the surface of the former 12, and the collected sheets may run downward over the former and the first fold be made on the former. Any suitable mechanism may be used to make the second fold below the former. To make one section with supplement and another section without supplement the sheets will not be collected above the former, but each cut will run directly downward over the former and one cut running downward over the former will have a supple-

ment and the next succeeding cut will be without a supplement. The first fold of both cuts will be made on the former and the first-folded sections will be collected by any suitable collecting or assembling device below the former, such as the assembling device shown in Fig. 27.

If all the webs from both ends of a double-ender apparatus are run to one set of cutter and carrier devices (say the cutter device 6 and the carrier device 7 shown in Fig. 60) the supplement web or sheet may run next to the face of the former 12, or may run between the main sheets running on the former 12.

If plate cylinders having circumferential columns be used, the supplement cutter and carrier cylinders 4' and 5' will in most cases, run at full speed, and the supplement sheets cut off by the cylinder 4' will be alternately delivered to the pair of cylinders 6 and 7, and the pair of cylinders 6' and 7', such as are shown in Fig. 1, or Fig. 59, or Fig. 60, but there are cases in which the supplement cutter and carrier cylinders may run at half speed, for example if it be desired to operate only one end of a double-ender apparatus to produce say a twenty-two-page paper in sections, viz: one section of twelve pages and one section of ten pages including a two-page insert sheet) the supplement cutter and carrier cylinders will run at half-speed, the first fold of the cut sheet will be made on the former 12 and a supplement sheet will be folded with the first section, the second section will be folded without a supplement sheet, the third section will be folded with a supplement sheet and so on, a supplement being included in every second section.

The cylinders 6 and 7; and 6' and 7'; shown in Fig. 59, are half the diameter of the plate cylinders and are adapted to make two revolutions and two cuts for each revolution of the plate cylinders. The cylinders 6 and 7; and 6' and 7'; shown in Fig. 60, are the same diameter as the plate cylinders and are adapted to make one revolution and two cuts for each revolution of the plate cylinders. In the first case the cylinders are adapted to cut one-page-long sheets, and in the second case the cylinders are adapted to cut either one-page-long sheets, or two-page-long sheets; and in that case the supplement sheets will be inserted between the two-leaf sheets associated or collected on the cylinders 7 and 7' respectively.

I have heretofore described an apparatus adapted to collect or assemble sections after making the first fold or the second fold, as the case may be, and using full-width full-speed webs and I prefer to operate the apparatus in that way, but in case plate cylinders equipped with plates having circumferential columns are used it is possible to oper-

- ate the machine so that the main sheets and the supplement sheets may be collected before the first fold is made. In that case the supplement web will run at full speed if 5 both folder devices are in use, or at half speed if one folder device is in use and the supplement web will be only half the width of the main web and the apparatus will be arranged substantially as shown in Fig. 60.
- 10 The carrier cylinders 7 and 7' will be equipped with diametrically opposite sets of pins of usual construction and the strippers 80 and 80' will be arranged to be effective upon each second revolution of the cylinders 15 7 and 7'. The sheets of the main web will be cut off by the cylinders 6 and 6' co-operating with the cylinders 7 and 7' and the supplement sheets will run to and around the cylinders 7 and 7' alternately as already 20 described.
- In operation, upon the first revolution of the cylinders 7 and 7' the pins will seize the leading edge of the main sheet and the supplement sheet and carry them together 25 around the cylinders and upon the second revolution of the cylinders the pins will seize the next succeeding sheet and the collected main sheets and supplement sheets carried upon the cylinders 7 and 7' will at 30 each second revolution of the carrier cylinders be stripped off by the strippers 80 and 80' and will run downward along the formers 12 and 12' and the first fold will be made upon the formers. In case the sheets are 35 collected before making the first fold the supplement sheets from the one-plate-wide supplement web will be cut off in succession and will go alternately to the formers 12 and 12' as already described.
- 40 It will be observed that in all the different forms and modifications of the apparatus the supplement sheets always go to opposite folder devices; in case plate cylinders with lengthwise columns are used, in case 45 plate cylinders with circumferential columns are used, and in case full-speed supplement webs are used. In case the supplement sheets are cut off before inserting them with sheets derived from the main web, the supplement sheets will run alternately to the 50 opposite folder devices; whether the columns are lengthwise or circumferential to the plate cylinders. In case half-speed supplement webs are used, and in case half- 55 width and half-speed supplement webs are used; the supplement sheets will all go to the folder mechanism, or mechanisms, at one end of the machine. It will also be observed that the columns on the supplement printing 60 couples are invariably arranged in such manner that the plates are in pairs circumferential to the plate cylinder, regardless of the direction of the columns of the plate cylinders, that is to say; if plate cylinders

with lengthwise columns are used the pairs 65 of plates will lie side to side around the cylinders, and if circumferential columns are used the plates will lie end to end around the cylinders.

It is obvious that if the plate cylinders 70 have circumferential columns the circumference of the plate cylinders will be greater than if they have lengthwise columns, and if the plate cylinders have circumferential columns, two-plate wide formers will be 75 used in place of the one-plate wide formers which are used in co-operation with plate cylinders having lengthwise columns, but the relative position of the mechanisms will be exactly the same in either case. This 80 arrangement of the plates on the supplement printing couples, in conjunction with the alternate run of the leaves cut from the supplement web members in case the matter is printed by plates with lengthwise columns; or in conjunction with the same run 85 of leaves cut from web members which have been printed by plates with circumferential columns, in case the sheets are collected before making the first fold; enables me to 90 produce a product with insert sheets from a less number of plates on the supplement cylinders than have heretofore been used to produce the same product.

The prior practice has been to produce 95 from a pair of supplement cylinders, each two plates in circumference a: plate wide, either when the columns are circumferential to or lengthwise of the plate cylinders, two two-page supplement sheets for 100 each revolution of the printing couples at half-speed; whereas I produce two two-page supplement sheets; or one two-page supplement sheet and one two-page sheet of regular matter; for each revolution of full-speed 105 printing couples; one one-leaf sheet going to a two-leaf sheet (or sheets) and forming part of one paper and the other one-leaf sheet going to another two-leaf sheet (or sheets) and forming part of another paper. 110

In my apparatus the supplement cylinders run at full speed and the surface of the cylinders not used for supplement plates may be equipped with regular plates and the pages printed on said regular plates may 115 constitute regular pages of the paper. If full-speed plural plate wide supplement cylinders with circumferential columns are used the supplement plates will occupy the whole surface of the cylinders in all cases 120 except when there is alternate run of the supplement sheets the sheets are collected in book form. If plate cylinders with lengthwise columns are used the first-folded edges always travel in the lead while making the 125 second fold.

The product of a double-ender three-plate-wide machine with lengthwise columns, such

as is shown in Figs. 1 to 8 inclusive, may be brought together in seven different ways, viz:

(a) The sheets cut from the web running from the left hand end of the machine may be run between and be folded by the rollers 8 and 8^a to produce three papers in book form; the sheets cut from the webs running from the right hand end of the machine may 10 run between and be folded by the folder devices 8' and 8'^a to produce three first-folded book form papers and the first-folded papers from the folder devices 8, 8^a; and 8', 8'^a may be timed to drop in succession onto the delivery wheel 67^x, the product in that case being six first-folded papers.

(b) The first-folded papers from the folder devices 8, 8^a, and 8' and 8'^a may be timed to drop together upon the delivery 20 wheels 67^x, to produce three papers each comprising two sections.

(c) The three first-folded papers running from the folder devices 8, 8^a, may receive the second fold on the formers 12, 12^a and 12^b respectively; and the first folded sheets from the folder devices 8' and 8'^a, may receive the second fold on the formers 12', 12'^a and 12'^b, and the product will be six second-folded papers.

(d) The second-folded papers from the formers 12, 12^a and 12^b, may run directly to the third-folder devices 20, 20^a and 20^b; and the product from the left hand end of the apparatus will be three third-folded papers; 35 and in like manner the second-folded papers from the formers 12', 12'^a and 12'^b may run directly to the third-folder devices 20', 20'^a and 20'^b, and the product from the right hand end of the machine will be three third-folded papers.

(e) The second-folded sections running from the formers 12^a and 12^b may be associated and dropped together upon the delivery wheel 67^x, to form a single second-folded 45 paper, in sections; and the second-folded paper running from the former 12 may run to the folder rollers 20, and the third fold may be made by said folder rollers; and in that case the product of all the folder mechanisms of the left-hand end of the apparatus will be one second-folded paper in two sections, and one third-folded paper; and operating in the same way, an exactly similar 50 product may be produced by the folder mechanisms of the right-hand end of the apparatus.

(f) The second-folded sections running from the formers 12 and 12^a, may be assembled by the assembling devices 64, 64^a (Fig. 6), and said assembled sections may run to and be folded together by the third folder mechanism 20 or 20^a as the case may be, and the second-folded paper from the former 12^b may be run to and the third fold thereof 55 may be made by the folder rollers 20^b; and

in that case the product of all of the folder mechanisms of the left hand end of the machine will be one third-folded paper in book form, and one paper comprising two sections folded together in the third fold; and exactly the same product may be produced by the folder mechanisms of the right hand end of the machine, operating in the same manner.

(g) If webs from both ends of the machine are led to the folder mechanisms at one end of the machine the number of pages of the various products above enumerated, will be increased in proportion to the number of webs in use.

Any of the above described products may have supplements, or may be without supplements; or some of the papers may have supplements, and some may be without supplements; and a composite web may be used 85 to furnish, in the different products, supplement sheets only; or supplement sheets in part, and main sheets in part; at the option of the operator.

The supplement web (except as herein-after explained) runs at full speed and is slitted the same as the other webs. When the columns are circumferential to the plate cylinders and a full-width full-speed composite, or supplement web, is used, one supplement web-member will run to the right hand first folder device (in this case a former), and the other will run to the opposite or left-hand first folder device as shown in Fig. 68; or if a plural-plate-wide 90 full-speed composite web, and intermediate cutter and carrier devices, as shown in Figs. 1 and 60, are used, the supplement sheets will run alternately to the opposite first folder devices; and if plate cylinders with 95 lengthwise columns are used, as shown in Figs. 1 and 74, the supplement sheets will run alternately from the intermediate supplement cutter and carrier devices to the 100 main carrier devices and thence to the first 105 folder devices.

One half the length of the plate cylinders printing the supplement web may be used to print two two-page supplements and the other half of the same cylinders may 115 be used to print four regular pages of the paper. For example: with three decks, two-plates wide, lengthwise columns (Fig. 40, 42) and all running at full speed, one deck (say the lower deck) may be used to print 120 the supplement. In that case the supplement plates will occupy one-half (say the left-hand half) of the printing couples of the lower deck, and regular plates will 125 occupy the other half of the same printing couples. Arranged in this way the products may consist of fourteen pages in book form folded on the left hand second-folder mechanism and ten pages in book form folded on the right hand second-folder 130

mechanism: or it may consist of twenty-four pages in book form running through a single folder mechanism: or one-half of the supplement deck may be used to print the 5 supplement and the other half may be run without plates: and in that case the product will be two ten-page papers in book form, one ten-page paper running through one second-folder mechanism and the other running 10 through the other second-folder mechanism.

In case circumferential columns are used and the sheets are cut and collected on the cylinders 6 or 7, or 6' or 7' as the case may 15 be (see Figs. 1 and 60), before making the first fold, the supplement sheets will run at full speed alternately to the right-hand and left-hand main carrier cylinders the same as when lengthwise columns are used, 20 and in that case the first fold will be made on the formers and the first folder rollers will not be used, but the collected sheets will be stripped from the carrier cylinders by suitable strippers, not shown.

25 Prior to my invention printing and folding apparatuses have been constructed and arranged to produce papers in equal sections, that is to say, sections each comprising the same number of pages, including a 30 supplement, which may be part of each section, but said prior apparatuses are not adapted to collect in a single paper two sections of different numbers of pages, with or 35 without supplements, or one section with a supplement and the other without a supplement.

My apparatus is adapted to produce papers 40 in sections of different numbers of pages with or without supplements, or one section with a supplement and the other without: or the entire product of the printing couples may be brought together in a single paper in book form: or two sections each having 45 a different number of pages, say a ten-page section and a fourteen-page section, may be collected, or assembled to form a single paper of twenty-four pages.

A double-ender machine five-decks high and three-plate wide, is capable of producing 50 papers as described below viz: Three twelve-page papers and three ten-page papers, at the same time and all in book form, three twelve-page papers running to the folders at one end and three ten-page 55 papers running to the folders at the other end of the machine: or the twelve-page and ten-page papers may be collected and all run to one end and may be folded together to make three twenty-two page papers: or ten 60 page and fourteen-page papers, or twelve-page and fourteen page papers, or fourteen-page and sixteen-page papers, or fourteen-page and eighteen-page papers, or sixteen-page and eighteen-page papers, or eighteen-page and twenty-page papers may all be run 65

in like manner: that is to say, papers with even number of pages may be run on both ends of the machine and full rolls of paper may be used to produce papers of all the different even-numbers of pages.

I have hereinbefore described an apparatus provided with printing couples with columns lying lengthwise of the plate cylinders, in coöperation with various slitter, cutter, and folder mechanisms and have particularly described means whereby the supplement web may be caused to run at full speed during the producing of papers of different numbers of pages.

I am the first to devise and use supplement 80 cutter devices in coöperation with folder devices adapted to cut off the supplement sheets from a full-speed full-width supplement web and insert them alternately into book-form papers running on different fold- 85 ers regardless of the direction of the columns of the printing couples.

Prior to my invention, machines in which the columns of the printing couples extend 90 around the plate-cylinders have been so constructed that when a supplement sheet is used it is necessary to collect on the collecting cylinders and cut above the former and in order to do this it has heretofore been necessary to run the supplement web at half-speed. The slow travel of the half-speed supplement-web, necessarily incident to the collecting, materially reduces the speed of 95 production, and the speed of final delivery of the folded papers into the packers.

If printing couples with columns extending around the plate cylinders are used, in my apparatus, the coöoperating former adjacent to the printing couples serves to make the first fold of the paper lengthwise of the 105 web and the webs may be cut into sheets either before or after passing over the formers: in practice it is preferable to cut the webs into sheets after the first fold has been made on the formers and then cut into sheets 110 in length equal to the length of a single leaf.

A prime purpose of my invention is to provide means whereby a full speed supplement web may be used either with printing couples having columns lengthwise of the 115 plate cylinders or with printing couples having columns extending around the plate cylinders. This result is attained by means of oppositely inclined formers 12, 12' etc., or equivalent devices in coöperation with a 120 slitter device or slitter devices situated intermediate of the formers, means for leading one member of the supplement web to one former and means for leading the other supplement web-member to the other former 125 and means for delivering the supplement web members, (or the sheets cut therefrom as the case may be,) next to the surface of the formers and in such position that the other webs coincidently running on the 130

formers will lie on top of the supplement web members or sheets, as the case may be; or if the supplement web is slotted and one web member is led to one former and the other web member is led to the other former, the main webs running on the formers respectively will overlie the supplement web members and the supplement web-members will occupy one-half of the surface of the 10 formers respectively, and the associated full-width web or webs and supplement-web members will, by means of cutter devices situated above or below the formers, be cut into papers in length equal to the length of 15 one leaf and in width equal to the width of two pages plus margins and the supplement sheet will lie between the leaves of the main sheets.

The oppositely inclined formers and co-operating folder mechanisms may, within 20 the scope of my invention, all be situated on the same level as shown in Fig. 3 or may be situated on different levels as shown in Fig. 62.

25 The oppositely inclined formers, or formers on different levels, between the printing couples of a double ender apparatus and a slitter device adapted to slit the supplement web, or a slitter device and a cutter device 30 adapted to slit the supplement web and cut it into sheets one leaf long, or two leaves long, according as the columns of the printing couples lies lengthwise of the plate cylinders or circumferential to the plate cylinders, are of the essence of my invention.

If plate cylinders with lengthwise columns are used the main cutter device will be parallel to the printing couples, and if plate cylinders with circumferential columns are used the main cutter device may be 40 above the first folder device and parallel to the printing couples; or may be below the first folder device and at right angles to the printing couples; and this arrangement admits of cutting off the main sheets either before or after making the first fold.

The opposite inclination of the formers, either on the same level or different levels, and their relation to slitters centrally situated relative to all of the formers, is necessary to bring the supplement web-members, or sheets cut therefrom, always next to the surface of the formers, regardless of the direction of the columns of the plate-cylinders; and formers and slitters in any other relation will not be effective to accomplish this result.

If the formers are placed so that they will incline toward each other it will be impossible to place the supplement web members or sheets next to the formers and the main webs on top of the supplement web-members or sheets, as the case may be; because the supplement web-members will lie across the path which the main webs would have to

travel to get on to the former, therefore the main web could not reach the former without cutting through the supplement web member and the same would be true if both of the co-operating formers inclined in the same direction.

The construction of the second folder mechanisms and their relation to the other mechanisms adapts this apparatus to produce a paper in two sections, one with an insert sheet and the other without an insert sheet; or both sections may have insert sheets. This result has not been accomplished prior to my invention. The practical advantage of this adaptability to produce different products is that a city edition with insert sheets may be run simultaneously with a fast-mail edition without insert sheets, or the city edition may be run with a greater number of pages than the mail edition, without reference to the insert sheet.

The number of pages of different products which may be produced on a three deck single-ender apparatus two-plates wide such as is shown in Figs. 40, 42 or such as is shown in Figs. 47, 49, is as follows:

(a) Two six-page papers produced from twelve plates, one paper running through each second-folder mechanism; or two six-page papers may be collected and run through one folder to form a twelve-page paper produced from one roll of paper two pages wide and one roll of paper one page wide, requiring one deck carrying the main web and running at full speed, and one deck carrying the half-width supplement-web and running at full speed, and the co-operating supplement-cutter cylinders running at full speed.

(b) With two decks running at full speed 105 with full width rolls of paper, two eight-page papers may be produced, one paper running through each second-folder mechanism; or the two eight-page sections may be collected by suitable means, such as are shown in Fig. 30, and run through a single folder mechanism to produce a sixteen-page paper; or the webs may be slit longitudinally to divide each web into two web-members and the web-members may be associated before cutting into sheets, and the sheets may then be cut off and run through a single-folder device to produce a sixteen-page paper in book form.

(c) With three decks in operation and 120 running at full speed, two decks carrying full width webs and one deck carrying a half width supplement web, two ten-page papers may be produced from twenty plates; in that case the co-operating cutter cylinders will run at full speed and one ten-page section will go through each second-folder mechanism; or the two sections may be run to a single delivery device such as 67, shown in Figs. 30 and 42 to form a single twenty- 125 130

page paper in two sections; or the supplement deck of the press may be run at half speed and the supplement cutter cylinders at half speed and in that case the product 5 will consist of a single eighteen page paper in book form, running through one second-folder mechanism. When the webs are slit into web-members and brought together in a single cutter mechanism, the supplement 10 cutter-cylinder will run at half speed. In all other cases the supplement cutter cylinders will run at full speed.

It will be observed that in producing papers of more than fourteen pages, supplement 15 sheets are rarely used and that the mechanism is operative at full speed to produce papers of the sizes which are most commonly used and it is therefore only occasionally necessary to operate the machine at 20 half-speed to produce papers having unusual numbers of pages. If the web members run to opposite cutter-devices, after the first fold is made, and if a supplement sheet is used, the supplement cutter cylinders will invariably 25 run at full speed and every set of printing couples in use on the press will also run at full speed. If the product is in two parts and a supplement sheet is placed in one part, before the first fold is made, and 30 the other part is without a supplement sheet, the supplement cutter cylinders will run at half speed.

(d) With three decks operating at full speed, with full width webs, and full complements of plates, two twelve-page papers 35 may be produced, one running through each second folder mechanism; or the two twelve-page sections may be run through a single second-folder mechanism to produce 40 a single twenty-four page paper from twenty-four plates without duplicates; or all of the webs may be slit before cutting into sheets, the web members may be associated and cut into sheets and all run through 45 a single folder mechanism to produce a single twenty-four page paper in book form.

All of the full width webs from one end of a double-ender machine may be associated together to form one paper or set of papers. 50 and all of the webs from the other end of the machine may be associated together to form another paper or set of papers; or the webs may be slit; part of the web-members going to one end and the other part going to 55 the other end of the machine; in either case when the webs and web-members are all associated and brought together for good and a paster is used, the paste will be applied on the uppermost main webs after associating 60 them all together, and the supplement web-members will run to opposite formers one side of the supplement running next to the former and the other side running next to the pasted sheet with which it is to be 65 folded.

In case all of the webs from both ends of the machine are associated and run to one end, the supplement web will be in the center of the associated webs from both ends of the machine; and in that case a paster 70 will be used only at one end of the machine. The top web of the associated webs from one end (say the right-hand) of the machine will be pasted and the supplement sheet will run next to the pasted web and 75 all of the associated webs from the left-hand end will come between the supplement web and the former. In case all of the webs from both ends of the machine are associated and run to one end of the machine, and run 80 to and upon two formers side by side, a two-page-wide supplement web will be used at one end of the machine, the supplement web will be slotted and one web member will run to and upon the near side of one former and 85 the other web-member will run to and upon the remote side of the other former. Never more than half of one deck will be run without plates, no matter what the ultimate product may be. The cases in which half-width webs will be used are; when collecting 90 two twenty-two page papers; when collecting a fourteen and an eight-page paper to form a twenty-two page paper and when associating all the webs and running them 95 to one end of the machine over a plurality of formers.

If it is desired to have papers in book form and in sections at the same time, when both ends of the machine are in operation, 100 the webs may be slit by the slitter device 24 and the members of a single web may be run to opposite main cutter devices, and after the first fold is made the intermediate switch may be turned and the papers will 105 run side by side in book form and in sections into folder devices side by side and will drop onto separate delivery wheels; or the two papers may be brought together after the second fold is made, by turning a 110 switch between the formers, and the two papers may be dropped onto the same delivery wheel with the first folded edges in the lead; or the switch co-operating with the collecting cylinder may be turned and the 115 two papers will then be carried around to the folder rollers and the third fold will be made and the folded papers will be dropped onto the same delivery wheel.

Each deck of a three-plate-wide five-deck-high double-ender machine will print twelve pages; the five decks of one end will print sixty pages and the entire machine running at full capacity will print and fold one hundred and twenty pages, which will 120 be delivered in the form of six papers, three from each end of the machine and each paper consisting of twenty pages. Using both ends of the machine to produce twelve-page papers the webs from three decks of 125

each end may be used, or the webs from five decks of one end and one deck of the other end may be used or the necessary number of webs from both ends arranged in 5 any other suitable order may be used.

In producing newspapers the sheets carried upon the carrier-cylinders will be two-leaf newspaper sheets and the fold will be made transverse to the sheets along the central margin between the pages thereof. 10

In producing magazines the sheets carried upon the main carrier-cylinders and operated upon by folder rollers will be two-leaf magazine sheets, each the same length as 15 a one-leaf newspaper sheet and the folder blades will operate to fold the sheets transversely along the center of the sheets.

The main cutter cylinders 6 and 6' are adapted to cut off two-leaf newspaper sheets 20 and the supplement or secondary cutter-cylinder 4' is adapted to cut off two-leaf magazine sheets; hence in producing newspapers the two-leaf sheets will be cut by the cylinders 6 and 6' coöperating with the carrier-cylinders 7 and 7'; and in producing magazines all of the two-leaf sheets will be 25 cut by the secondary cutter-cylinder 4' co-operating with the secondary carrier-cylinder 5'.

In producing magazines the run of the cut sheets from the cylinders 4' and 5' will be alternately to the carrier-cylinders 7 and 7'; if however it is desired to lead all of the 30 two-leaf magazine sheets from the cylinders 4' and 5' to one of the main carrier-cylinders, say the cylinder 7, the cylinders 4' and 5' will be operated at half speed.

When operating to produce newspapers with supplements, the coöperating cylinders 4' and 5' will cut off sheets from the supplement web only; but when operating to produce magazines the cylinders 4' and 5' may coöperate to cut two-leaf magazine sheets from all of the webs. 40

In the description and claims the cylinders 4' and 5' are called "supplement" cutter and carrier-cylinders to indicate their use in producing supplement sheets only, and are called "secondary" cutter and carrier-cylinders to distinguish them from the main carrier cylinders 7 and 7' and to indicate their use for producing two-leaf magazine sheets from one or more of the main webs. 50

The term "sheet carrying devices" hereinafter used in the claims, is hereby defined to mean revoluble carrier cylinders, or equivalent devices, adapted to carry cut main sheets before the first fold is made; and the term "paper-carrying devices" hereinafter used in the claims is hereby defined to mean, tapes or equivalent carrying devices between the first folder devices and the second folder devices and adapted to

carry first-folded papers or sections, folded 65 by said first folder devices.

For the sake of clearness the sets of pins adapted to engage the two-leaf newspaper sheets will be designated in the claims as primary pins and the pins adapted to hold 70 the two-leaf magazine sheets will be designated as secondary pins. Other terms used in the specification and claims are hereby defined as follows: "Composite web," a plural-plate-wide web comprising the printed 75 matter of one-leaf supplement sheets and the printed matter of two-leaf main sheets. "Main web," a web either one-plate-wide or plural-plate-wide comprising the printed matter of two-leaf main sheets only. "Severing device," this term is generic and describes any device such as the slitter devices 24 or 24' or equivalent devices adapted to divide a web longitudinally or any device such as the coöperating cylinders 4' and 5'; 80 or the coöperating cylinders 6 and 7 or equivalent devices, adapted to cut webs or web-members transversely to produce either two-leaf; or one-leaf sheets. In case the plate cylinders have circumferential columns 90 the severing device may be a slitter 24' or equivalent device as shown in Fig. 68; and in case the plate cylinders have lengthwise columns the severing device may be a cutter cylinder 4' or 6 or equivalent device 95 substantially as shown in Fig. 1.

Collecting the sections.—If circumferential columns are used collecting or assembling in sections with cut edges in the lead (see Figs. 27 and 60) consists in running a 100 longitudinally folded web between cutter devices, cutting it into two-leaf sheets and then bringing together said two-leaf sheets; or associating a plurality of webs or web-members longitudinally and then cutting 105 said webs or web-members, running with the cut edges in the lead, into two-leaf sheets and bringing together said two-leaf sheets. The cylinders 6 and 6' (Fig. 1) are timed to make one cut for each revolution of the 110 printing couples and the cylinders 4' and 5' are timed to make two cuts for each revolution of the printing couples; keeping this in view it will be observed that at the instant that the main cutter cylinders 6 and 6' would be effective to cut two-leaf main sheets on the carrier-cylinders 7 and 7', (if main sheets are running thereon,) the two-leaf magazine sheets previously cut by the secondary cylinders 4' and 5' and then running 115 on the main carrier-cylinders 7 and 7' would be on that part of the circumference of the cylinders which is opposite to the cylinders 6 and 6'; hence the blades of the main cutter cylinders 6 and 6' could not cut the short 120 magazine sheets.

In producing newspapers the run of the webs and the sheets cut therefrom will be

- timed so that the leading edge of the short sheets running from the cylinders 4' and 5' onto the cylinders 7 and 7' will match the central margin between the pages of the two-page sheets running on the cylinders 7 and 7' and so that when the folder blades come into action the central margin between the pages of the two-leaf sheets will be adjacent to the coöperating folder rollers 8, 8^a and 8', 8^{a'} and the two-leaf sheets will extend half way around the cylinders 7 and 7', and will be held between the pins m' remote from the folder blades M'.
- In case two-leaf magazine sheets are running on the cylinders 7 and 7' the sheets will be held by the pins m' nearest to the folder blades M' and the blades will operate to fold the short sheets centrally and project them between the folder rollers 8, 8^a and 8', 8^{a'}.
- In order that two-leaf magazine sheets may be delivered upon the cylinders 7 and 7', in position for folding them centrally, the coöperating mechanisms must be so adjusted that the pins m' adjacent to the folder blades will seize the leading edge of the sheets as fast as they arrive upon the cylinders 7 and 7'. This change in the time of the arrival of the short two-leaf magazine sheets from the secondary cylinders upon the main carrier-cylinders may be effected by loosening the set screws securing the wheels 56 and 57 and sliding the wheels outward on the shaft 57^a sufficiently for the inner edge of the wheel 56 to clear the outer edge of the wheel 45', whereupon the supplement carrier-cylinder 5' and supplement cutter-cylinder 4' may be turned backward or forward sufficiently for the proper cutting of the re-adjusted webs.
- When the apparatus is operating upon newspapers, the webs from the ends of the machine may be run over the rollers 72 respectively to the slitter device 24^x, or may be run over the rollers 73 and 73' to the slitter device 24^x. The central slitter devices 24^x are so situated that main web and supplement webs both may be slit by said slitter devices.
- If operating to print and fold newspapers the central slitter devices 24^x may slit the insert or composite web to form a number of web members and one or more of said web members may contain the matter of supplement sheets and one or more of said web members may contain the matter of main sheets. The members containing the matter of supplement sheets will run between the cylinders 4' and 5' and will be cut by the cylinder 4'; and the member or members containing main sheets will run to the cylinders 6 and 7, or 6' and 7' as the case may be, and the cylinder 6 (or 6') will cut main sheets from said web members.
- When operating on magazines the main webs may be slit by the central slitter de-
- vices 24^x. If the webs are running over the rollers 73 and 73' and it is desired to change from newspapers to magazines the webs will be changed to run over the rollers 72 and in that case it will be necessary to correspondingly turn backward the cylinders 4' and 5'; on the other hand if the newspaper webs are running on the rollers 72 and it is desired to change to magazines, the webs will be placed on the rollers 73 and 73' and the cylinders 4' and 5' will be correspondingly turned forward. The turning of the cylinders 4' and 5' forward or backward as the case may be, will necessitate a corresponding changing of the webs so that the blade 80 of the cutter-cylinder 4' will cut off two-leaf magazine sheets along the margin between the sheets, and this change of the webs may be effected by shifting the webs from the rollers 72 to the rollers 73 and 73' or from the rollers 73 and 73' to the rollers 72, according as the original run of the webs was over the rollers 72, or over the rollers 73 and 73'.
- When the webs and the cylinders 4' and 5' have been adjusted as described, the wheels 56 and 57 will be slid on the shaft 57^a (Figs. 51 and 52) and secured in such a position on the shaft that the wheel 56 will mesh with and drive the pinion 55 which is secured on the shaft of the cylinder 5', and the cylinders 4' and 5' will then operate at full speed and the cylinders 4' and 5' and the tapes 75 and 75' will lead the cut magazine sheets alternately to the cylinders 7 and 7'.
- Opposite folder devices in rows transverse to the machine and all on the same level and adapted to coöperate with opposite formers in rows transverse to the machine, have already been described as used in apparatuses equipped with printing couples having plates lengthwise of the plate cylinders; as used in apparatuses having printing couples equipped with plate cylinders with circumferential columns; as used in apparatuses in which folder mechanisms below the formers are at right angles to the printing couples and as used in apparatuses in which the folder mechanisms are parallel to the printing couples.
- There is another modification of the apparatus in which printing couples with circumferential plates may be used and in which the opposite folder devices below the opposite formers may be situated upon different levels. Such construction is shown in Figs. 62 and 63 and will now be described.
- The plate cylinders 2, 2^a, 2' and 2^{a'}, etc., the formers 12, 12^a, 12' and 12^{a'}, the cutter cylinders 6, 6', the carrier cylinders 7, 7^a, the folder rollers 8, 8', the slitter devices 24 and 25, are all constructed substantially as already described, but the folder and cutter mechanisms 12, 6, 7, 8, are on a different level from the mechanisms 12^a, 6^a and 7^a and

the like mechanisms 12', 6', 7' and 8' are on a different level from the mechanisms 12^a', 6^a' and 7^a'. The supplement web or webs and all of the main webs may be slit by the slitter device 24^a, or the supplement web and one or more of the main webs may be slit by the slitter 24^a and the main webs may be slit by the slitters 25 adjacent to the formers respectively, as shown in Fig. 1. 10 A five-deck-high apparatus equipped with plate-cylinders having circumferential columns operating upon four-plate-wide webs, such as is shown in Figs. 61, 62 and 63 will use the webs from the cylinders 2 and 2' as the supplement webs. The slitter devices 24^a will slit each supplement web to divide it into four equal web members, making eight in all from the two webs, which being led around suitable rollers will pass to the formers. The first web-member from the cylinder 2 will pass downward along and next to the near face of the former 12^a, the second web-member will pass downward along and next to the remote face of the former 12^a, 15 the third web-member will pass between the formers and downward along and next to the near face of the former 12^a and the fourth web-member will pass downward along and next to the remote face of the former 12^a and in like manner the several members of the web from the cylinder 2' will be conducted to and along the four corresponding formers, two at each end of the apparatus. The associated main webs from the cylinders 2^a and 2^b will be slit along the center and will pass around the rollers 25 onto the formers 12 and 12^b and on top of the supplement web-member; the associated webs from the cylinders 2^a and 2^b 20 will in like manner pass to the formers 12^a and 12^b; the webs from the cylinders 2^a and 2^b will in like manner pass to the formers 12^a and 12^b and the webs from the cylinders 2^a and 2^b will in like manner pass to the formers 12^a and 12^b. 25

If it is desired to paste the supplement sheets, paste may be applied in a continuous strip along the margins between the pages of the uppermost main sheets by paster devices 27 of any approved construction so situated that the webs will run in contact therewith.

I have devised a new method and means for so controlling the run of the supplement webs, the supplement web-members, and the sheets cut therefrom, that a plural-plate-wide full-speed supplement web may be used to supply supplement sheets to be inserted between the main sheets cut from the main webs of a multiple-deck, plural-plate-wide, single-end apparatus or with all of the sheets cut from the main webs of a double-end multiple-deck plural-plate-wide apparatus, and will be equally effective in case the columns of the plate cylinders are length-

wise of the printing couples, or in case the columns are circumferential to the printing couples; and will be equally effective when the second folder devices are parallel to the plate cylinders or at right angles to the plate cylinders. 75

In order that the nature and scope of this invention may be well understood and clearly defined, in the claims I will now describe the arrangement of the pages of printed matter on the main webs and the supplement webs and the direction of travel of the web-members, and the sheets cut from the webs, and the means controlling the travel of the web members and the cut sheets. 80

Figs. 66 and 64 are diagrams showing the arrangement of the pages of printed matter upon a four-plate-wide main web W and a four-plate-wide supplement web W', printed by printing couples equipped with lengthwise columns; and Figs. 67 and 65 are diagrams showing the arrangement of the pages of a four-plate-wide main web V and supplement web V', printed by printing couples with circumferential columns. The columns 85 of the pages of the webs W and W', printed by printing couples with lengthwise columns, are transverse to the webs, and the columns of the pages of the webs V and V' 90 printed by printing couples with circumferential columns are lengthwise of the webs and the pages of the main two-leaf sheets are in rows w, arranged in pairs wa, which are lengthwise of the main webs. The two-leaf pages of the web V printed on plates 95 100 with circumferential columns are in rows v, arranged in pairs va, the pairs of rows being lengthwise of the web. In both cases the two-leaf main sheets are arranged in pairs of rows, lengthwise of the web. The 105 pages of the supplement web W' are in rows w' arranged in pairs wa' and the pairs of rows are crosswise of the web. The pages of the supplement sheet V' are in rows v' 110 arranged in pairs va'. The pairs of rows 115 of the one-leaf sheets of the supplement web W', printed by plate cylinders with lengthwise columns are transverse to the web and the pairs of rows of one-leaf supplement sheets printed on the web V' by plates with 120 circumferential columns are lengthwise of the webs. The pairs wa of the main web W are lengthwise of the web, and the pairs wa' of the corresponding supplement web W' are crosswise of the web. The pairs va 125 of the main web V are transverse to the web and the pairs va' of the corresponding web V' are lengthwise of the web. In each case the pairs of the main web and its complementary supplement web lie at right angles 125 to each other.

I am the first to arrange both the main pages and the supplement pages, in pairs of rows regardless of the direction of the columns of the plate cylinders. 130

Fig. 68 illustrates the run of the main webs and the supplement web in the case of webs printed by plates with circumferential columns and Fig. 69 illustrates the 5 run of the main webs and sheets cut from the supplement web in case the webs are printed by printing couples with columns lengthwise of the plate cylinders. The supplement web V' (Fig. 68) is slotted longitudinally by the slitter 24* cutting on the co-operating roller. Opposite formers 12 and 12' receive the main webs and associated supplement web-members. The near web-member on which is printed a row v' of 10 pages passes to and along the near face of the left-hand former 12 and the remote member v' of the pair va' passes to and along the remote face of the former 12'. The pages of one row of the pair va' travel to the left 15 and next to the surface of the former 12 and the pages of the other row of the same pair travel to the right next to the surface of the former 12' and the associated main webs and supplement web-members are cut into 20 one-page-long sheets by suitable cutter devices co-operating with the formers respectively. 25

In case of the use of webs printed by plate cylinders with columns lengthwise of 30 the plate cylinders (Figs. 64, 66 and 69) the rows w' of pages of the supplement web V' are cut across the entire width of the web by the cutter cylinder 4' co-operating with the secondary carrier-cylinder 5' and 35 one row w' of a pair va' of rows of cut sheets is led by tapes 75* or other suitable leading devices, to the main carrier-cylinders 7 and the other row of sheets of the same pair va' of rows, is in like manner led 40 by tapes 75* or equivalent devices to the main carrier-cylinder 7; and the rows w' of sheets go alternately to the main carrier-cylinders and co-operating folder devices so long as the machine continues in operation. 45

By comparison of Figs. 68 and 69 it will be seen that the rows of the pairs of rows of supplement sheets are always delivered to opposite folder devices, one row of the pair going to one folder device and the other 50 row of the same pair going to an opposite folder device or a folder device on a different level, as the case may be, regardless of the direction of the columns of the plate cylinders and regardless of the position of the 55 folder mechanisms relative to the printing couples.

In the machine shown in Figs. 1-4 and in Figs. 15-24, the main carrier-cylinders 7 and 7', the first folder rollers 8, 8*, 8' and 60 8'', the main cutter cylinders 6 and 6', the slitters 24, 24' and 24* and the supplement cutter and carrier-cylinders 4' and 5' will be situated above the formers, in case the printing couples are equipped with columns 65 lengthwise of the plate cylinders; and the

sheets may be slotted either before making the first fold or after making the first fold. In case the printing couples are equipped with columns lying around the plate cylinders the first fold will be made on the formers, and the collecting cylinders and the second folder rollers will be situated below the formers. 70

In an apparatus having columns lengthwise of the plate cylinders and having first-folder mechanisms parallel to the printing couples, and having swinging knives for making the second fold (Fig. 30) no formers will be used and the webs from the printing couples will run in a straight line 75 direct to the first folder mechanism. The same machine with the first folder mechanisms at right angles to the printing couples may be equipped with a former, such as is shown in Fig. 44, or may be equipped with 80 angle bars, such as are shown in Fig. 40. 85

If the machine shown in Fig. 44 is used, with all full-width-webs to produce papers either with or without supplements, all of the webs will run over the former. If a 90 half-width supplement web is used, the machine will be equipped with short angle bars, such as are shown in Fig. 43 and the angle bars will serve to lead the supplement web to either folder mechanism. One pair of 95 angle bars, such as are shown in Fig. 40 may be used to lead the webs from all of the decks to the folder mechanisms or separate sets of angle bars may be used to lead the webs from the decks respectively, and in 100 the last named case the supplement web will run on the top deck. The plate cylinders of the apparatus of the form shown in Figs. 40 and 44 may be either two-plates-wide, three-plates-wide or four-plates-wide, and in 105 either case the folder mechanism shown in Figs. 42 and 46 will be equally effective without any structural change of the folder mechanisms.

In all of the different forms of the apparatus the supplement-slitter devices and the 110 paster devices are situated between the webs running to the opposite folder mechanisms; one paster device being between the supplement cutter device and the right-hand folder 115 mechanism and the other paster device being between the supplement cutter device and the opposite left-hand folder mechanism (see Fig. 59); this is true with respect to both single-ender and double-ender machines either with lengthwise or circumferential columns. 120

The webs being arranged to run as shown by the diagrams Figs. 15-24 inclusive, and Fig. 39; the product will be respectively as 125 follows:

Fig. 15—four decks running on one end and three on the other, all full-width webs, the product will be six fourteen-page papers in book form, three of the papers running 130

over the formers 12, 12^a and 12^b, and three running over the formers 12', 12^{a'} and 12^{b'} respectively, the first fold will be made by the folder rollers 8 and 8', the second fold 5 will be made on the formers 12 and 12' and the third fold will be made by the folder rollers 20 and 20' (Figs. 2 and 3) coöperating with the second carrier-cylinders 19 and 19'; or the papers from both of the cylinders 10 7 and 7' may be led across the switch 23 and folded together on the former 12 or 12', as the case may be; or the switch may be turned to the vertical position, as indicated by dotted lines in Fig. 20 and the first folded 15 papers may drop directly onto the delivery wheel 67, shown in Fig. 1.

Fig. 16— five decks in operation at one end and two decks at the other, all full-width webs running at full speed, producing 20 six fourteen-page papers, three from each end of the machine, the supplement sheets being cut from the webs carried on the cylinder 2^a and the web from the cylinder 2 being carried across above the former 25 and associated with the webs carried on the cylinders 2' and 2^{a'}. The supplement web-members are cut into sheets on the cylinder 5', the cut sheets running alternately to the cylinders 7 and 7'. The run of the sheets 30 from the carrier-cylinders 7 and 7' is the same as already given in the description of Fig. 15.

Fig. 17— three decks in operation at each end of the machine, all full-width webs running 35 at full speed. The supplement web is carried on the cylinder 2^b and cut into sheets on the cylinder 5', the sheets going alternately to the carrier-cylinders 7 and 7'. The product from the left-hand webs will be 40 three ten-page papers and the product from the right-hand webs including a supplement cut from the web carried on the cylinder 2^b will be a fourteen-page paper. From the cylinders 7 and 7' the run will be the same 45 as in Fig. 15.

Fig. 18— four decks three-plate-wide in operation at each end of the machine, all full-width webs, all running full speed, supplement web carried on the cylinder 2^{a'}. 50 The product will be three eighteen-page papers on the cylinder 7 and three fourteen-page papers on the cylinder 7'. From the cylinders 7 and 7' the run will be the same as Fig. 15.

Fig. 19— three-plate-wide machine five decks high, all of the decks in operation, all full-width webs running at full speed. The product will be six twenty-page papers; 55 three from each end of the machine, running over the formers 12 and 12'; or all of the webs from the cylinders 2, 2^a, 2^b, 2^c and 2^d may be carried across the cylinder 7 onto the cylinder 7' and there associated with the webs coming from the other end of the machine and the product will be three forty-

page papers in book-form carried on the cylinder 7' and running onto the formers 12'; or all the sheets may be carried around the cylinder 7 and over the former 12; or the switch 23 being set in vertical position 70 as shown by dotted lines, six twenty-page first-folded papers, three from each end, will drop directly onto the delivery wheels 67 shown in Fig. 1; or the switch 23 being closed the first-folded papers from the cylinder 7 may run over the switch and be assembled with the first-folded papers from the cylinder 7', or vice versa, papers from the cylinder 7' may be assembled with papers from the cylinder 7 and these assembled papers may be folded together on the formers 12' or 12, as the case may be, thus forming three forty-page papers. From the cylinders 7 and 7' the run of papers will be the same as set forth in the description of Fig. 15.

Fig. 20— three-plate-wide machine, five decks high, five decks operating at one end carrying full-width webs at full speed, one deck operating at the other end carrying a half-speed full-width supplement web; the product will be three twenty-two-page papers with supplement at the center of the paper, carried on the cylinder 7' and running downward over the formers 12'. Below the cylinder 7' the run of the papers will be the same as set forth in the description of Fig. 15.

Fig. 21— three-plate-wide, five deck high machine, three decks in operation at each end of the machine, the deck 2^b carrying the full-width supplement web operates at half speed, webs from the cylinders 2^{b'}, 2^c and 2^{d'} run across the cylinder 7' and onto the cylinder 7 (as indicated by arrow) and will be associated thereon with the webs from the cylinders 2^c and 2^d, the supplement sheets cut from the web-members of the web running on the cylinder 2^b will be inserted between the associated webs coming from the opposite ends of the machine and the product will be three twenty-two-page papers carried on the cylinder 7 and running over the former 12. When the apparatus is being operated as indicated in Fig. 21 to produce papers with supplements inserted between two main webs before said webs are cut into sheets, the main webs running across under the supplement carrier cylinder from one main carrier cylinder to the other and running next to the last named carrier cylinder, as indicated by the arrow X⁴, are called inside webs; and the main webs which run on the same carrier cylinder on top of said inside webs are called outside webs; and the half-speed supplement sheets are inserted between said inside and outside webs. From the cylinder 7 the run of the papers may be the same as set forth in the description of Fig. 15.

Fig. 22— three-plate-wide machine five decks high, all of the decks in operation, all full-width webs running at full speed. The product will be six twenty-page papers; 110 three from each end of the machine, running over the formers 12 and 12'; or all of the webs from the cylinders 2, 2^a, 2^b, 2^c and 2^d may be carried across the cylinder 7 onto the cylinder 7' and there associated with the webs coming from the other end of the machine and the product will be three forty- 115 page papers in book-form carried on the cylinder 7' and running onto the formers 12'; or all the sheets may be carried around the cylinder 7 and over the former 12; or the switch 23 being set in vertical position 120 as shown by dotted lines, six twenty-page first-folded papers, three from each end, will drop directly onto the delivery wheels 67 shown in Fig. 1; or the switch 23 being closed the first-folded papers from the cylinder 7 may run over the switch and be assembled with the first-folded papers from the cylinder 7', or vice versa, papers from the cylinder 7' may be assembled with papers from the cylinder 7 and these assembled papers may be folded together on the formers 12' or 12, as the case may be, thus forming three forty-page papers. From the cylinders 7 and 7' the run of papers will be the same as set forth in the description of Fig. 15.

Fig. 22— three-plate-wide, five deck high machine, all full-width webs running at full speed, five decks in operation at one end and four at the other. The web carried on the cylinder 2 will be cut into sheets on the cylinder 5', the sheets will go alternately to the cylinders 7 and 7', the sheets on the cylinder 7 will be associated with the sheets cut from the webs carried on the cylinders 2^a, 2^b, 2^c and 2^d and after the first fold will travel downward over the formers 12, and the sheets running from the cylinder 5' onto the cylinders 7' will be associated with the sheets cut from the webs carried on the cylinders 2^{a'}, 2^{b'}, 2^{c'} and 2^{d'} and carried downward over the formers 12'; in this case the product will be three eighteen-page papers over the formers 12, and three eighteen-page papers over the formers 12'. If the cylinder 2' be operated at full speed with full-width webs, all of the other decks operating as described, the product will be three eighteen-page papers over the formers 12, and three twenty-two-page papers over the formers 12'. Below the cylinders 7 and 7' the run of the papers may be the same as set forth in the description of Fig. 15.

Fig. 23— three-plate-wide machine five decks high, all running at full speed and all carrying full width webs. All the webs from the left-hand end of the machine will run around the cylinders 6 and 7 and will be cut into two-page long sheets on the cylinders 7 and pass between the first-folder rollers 8, the webs from the right-hand end of the machine will be conducted to and cut into sheets on the cylinders 7' and pass between the first-folder rollers 8' cooperating with the cylinders 7'. Papers from the cylinder 7 will, upon the turning of the switch 23 to a horizontal position, run across the switch onto the former 12' and will thereon be assembled with and will run over the former 12' with the papers from the cylinder 7' the product will be six twenty-page papers, or three forty-page papers each comprising two sections of twenty pages. In this case the webs may be slit by slitter devices 24 and 24' above the main cutter cylinders 6 and 6', or the cut sheets may be slit by slitter devices 25 between the main carrier-cylinders and the formers.

Fig. 24— three-plate-wide machine five decks high, all carrying full-width, full-speed webs, three decks in operation at one end and five decks in operation at the other end, the supplement web carried on the cylinder 2'. The right-hand main webs will all be slit by the slitter devices 24' and the left-hand main webs will be slit by the slitter devices 24, the supplement web will run to and be cut into sheets upon the cylinder 5' and the cut sheets will run alternately to the cylinders 7 and 7' upon which

they will be inserted between the two-page-long sheet cut from the main webs, the first-folded sheets from the cylinders 7 will run across the switch 23 to the former 12' upon which they will be assembled with the first-folded sheets from the cylinder 7'. In this case the product will be three fourteen-page and three eighteen-page papers, which when assembled will make three thirty-two page papers.

Fig. 39— illustrates a three-plate-wide five deck high machine, all full-width webs run at full speed and the decks of one end only of the machine being in operation. The supplement web will be carried on the cylinder 2^b, the webs from the cylinders 2 and 2^a will be carried across above the supplement carrier-cylinder 5' and will be slit by the slitter 24', the webs carried on the cylinders 2^b, 2^c and 2^d will be slit by the slitters 24 and the web from the cylinder 2^b will go to and be cut into supplement sheets upon the cylinder 5' and the supplement sheets will go alternately to the cylinders 7 and 7', the supplement sheet on the cylinder 7 will be inserted between the main sheets cut from the webs on the cylinders 2^c and 2^d and the main sheets and supplement sheets will be folded together by the folder rollers 8; the supplement sheet on the cylinder 7' will be inserted between the main sheets cut from the webs carried on the cylinders 2 and 2^a and the main sheets and supplement sheets will be folded together by the co-operating rollers 8'; the product will be six ten-page papers, three of them going over the formers 12 and three going over the formers 12'. Below the carriers 7 and 7' the travel of the papers may be the same as set forth in the description of Fig. 15.

It will be observed that in producing all of the products above described, papers receiving the second and third folds invariably travel with the first-folded edge in the lead during the making of the second and the third folds, and the papers may be dropped onto the delivery wheels immediately upon the completion of the first fold, the second fold or the third fold, and the papers may be in sections or in book form.

Practical advantages of the apparatus adapted to operate as set forth are; that when in operation all of the plate cylinders may be equipped with a full complement of plates, full rolls of paper may be used, thereby avoiding the change of spindles, fountain rollers, and form rollers; also (under ordinary conditions of operation) avoiding the use of angle bars, and also avoiding needless adjustment of the webs.

The supplement web preferably and ordinarily runs at full speed and is the same width as the other webs.

In operation the blankets on the blanket cylinders will be beaten down evenly over the entire surface of the cylinders.

A three-plate-wide, five deck high machine can advantageously produce papers of 22, 24, 26, 28, 30, 32, 34, 36, 38, and 40 pages, either in book form or in sections. Two papers, each comprising forty pages may be separately dropped onto the same delivery wheel or may be "stuffed" in the third fold and dropped as a single eighty-page paper; or papers of different numbers of pages, say thirty-eight and forty, or any other desired number of pages, may be stuffed and dropped in like manner.

The apparatus comprises means for collecting, without back travel, plural first-folded sections, the folded edges of the sections of the paper traveling always toward each other and in parallel. It is adapted to deliver papers in book form, or in sections, at the option of the operator and the mechanism may be instantly adjusted for either purpose. The quick change is an important advantage. All of the sections have a continuous straight travel at full speed.

In an apparatus of the modified construction illustrated in Figs. 27-29 the formers 12 and 12^a, the two carrier-cylinders 19 and 19^a, the tape rollers 17, 17^a and 18 and the two sets of folder rollers 20 and 20^a are the same as have been already described. Revoluble assembling cylinders 64 and 64^a are parallel to each other and are situated above the carrier-cylinders and intermediate of the formers. Tapes 16 run on the rollers 17, 17^a and 18, and tapes 16^a run on the rollers 64, the wheels 65 and the rollers 17 and 18. Combined strippers and shields N (shown in detail in Fig. 26) are mounted on oscillative shafts n parallel to the folder rollers 20 and 20^a and coöperate with the carrier cylinder 19 and similar strippers and shields, adjacent to the folder rollers 20^a, coöperate with the carrier cylinder 19^a. The shafts n may be turned by knurled handles n' (Fig. 26) and when set in any desired position may be secured by set screws n². Cylindrical blocks n³ eccentric to the shafts n are turnable and slidable on the shafts and may be secured in different positions thereon, by set screws n⁴. The stripper blades N are turnable on the blocks n³ and may be secured in different positions by set screws n⁵.

The adjustable blocks n³ facilitate the adjustment of the blades N in proper relation to the cylinders 19 and 19^a and the folder rollers 20 and 20^a and enable the plates to be so adjusted that the points n¹⁰ will lie in the circumferential channels of the carrier cylinders when the blades are set for papers running over the blades; and the strippers n³ will lie in the circumferential channels in the folder rollers 20 and 20^a when the

blades N are set in such a position that the papers will run under the blades and around the carrier-cylinders and between the folder rollers. These adjusting devices admit of the setting of the blades N in such a position that papers running over the blades may be timed to run in unison with papers running around the carrier-cylinders and between the folder rollers; to the end that uniform delivery of the folded papers upon the delivery wheels 67 and 67^a may be attained; that is to say if papers running over the blades N drop prematurely upon the delivery wheel 67 the blocks n³ may be turned upon the shaft n so as to move the lower ends of the blades N upward sufficiently to time the run of the sheets so that they will fall upon the wheel 67 at exactly the right instant, or if the sheets are too slow in arriving upon the wheel 67, the lower ends of the blades N may in like manner be depressed to cause the sheets to arrive at exactly the right instant upon the wheel 67. The wheels 67 and 67^a being timed to receive papers from the folder rollers 20 and 20^a, the blades N may be adjusted to time the sheets running over the blades so that they will arrive at the proper instant upon the wheels 67 and 67^a and said wheels will be effective to deliver papers running either from the blades N, or the folder rollers, as the case may be. The blocks n³ may be slid on the shafts n to move the blades toward or away from each other, to vary the position of the blades according to the circumstances of use.

Switch blocks N¹ and N² (shown in detail in Fig. 25,) are secured on shafts n⁷ and n⁸ respectively. The shaft n⁷ is stationary and the shaft n⁸ may be turned by the handle n⁹ and when placed in the desired position may be secured by the set screws n¹⁰. The lower edges of the blocks N¹ have notches n¹¹. The upper ends n¹² of the blocks N² travel through the notches n¹¹ when the shaft n⁸ is turned. The concave surfaces n¹² and n¹³ of the blocks N¹ and N² substantially conform to the surfaces of the cylinders 64 and 64^a. The cylinders 64 and 64^a have circumferential channels in which the stripper ends n¹⁴ of the blocks N² fit. If the shaft n⁸ be turned to the right the members n¹⁵ of the blocks N² will run in the channels of the right-hand cylinder 64^a and will serve to strip the sheets from that cylinder and if the shaft be turned to the left the members n¹⁵ will run in the channels of the left-hand cylinder 64 and strip the sheets from that cylinder.

When the parts occupy the position shown in Figs. 25 and 27 the blocks N² will lie directly under the blocks N¹, and sheets running around the right-hand cylinder 64^a will run downward along the right-hand concave

surfaces n^{13} of the blocks N^2 , and sheets running around the left-hand cylinder 64 will run downward along the left-hand concave surfaces of the blocks N^2 . If it be desired to lead all of the sheets to the right it is only necessary to turn the shaft n^8 to the left to cause the parts n^{15} to strip the sheets from the left-hand cylinder 64 and lead them downward, with the folded edges in the lead, along the surface n^{13} where they will be assembled with the sheets running around the right-hand cylinder 64^a. The upper points n^{16} of the stripper blades N fit in circumferential channels in the cylinders 19 and 19^a and the lower points n^{17} fit in circumferential channels in the upper folder rollers 20 and 20^a. The shaft n being adjustable may be set to hold the points n^{16} of the blades in the channels of the cylinders, or to hold them out of the channels. The blades N are situated above and extend downward part way around the folder rollers 20 and 20^a. Shields 66^a are supported on stationary shafts 66 which also support adjustable arms 65^a on which the tape wheels 65 are mounted. The rollers 18 are also mounted on similar arms 18^a which are adjustable on stationary shafts 18^a. The arms 65^a and 18^a may be adjusted to control the tension of the tapes 16^a. The wheels 17^a are mounted on arms 17^a which are adjustable on stationary shafts 17^a to control the tension of the tapes 16. The cylinders 19 and 19^a are equipped with suitable grippers 35 adapted to grip the sheets running on the cylinders.

In case plate cylinders with circumferential columns are used the first fold will be made upon the formers 12 and 12^a and the second fold will be made by the folder rollers 20 and 20^a. Normally the sheets from the former 12 will run around the cylinder 64 to the cylinder 19 and the sheets from the former 12^a will run around the cylinder 64^a to the cylinder 19^a, but by turning the switch blocks N^2 to the right all of the sheets may be caused to run onto the cylinder 19, and by turning the switch block N^2 to the left all of the sheets may be caused to run onto the cylinder 19^a.

The sheets may be dropped after making the first fold, or they may be dropped after making the second fold, and the sheets from each of the formers may be dropped upon different delivery devices; or they may be collected, or assembled, and dropped together upon a single delivery device; or the first-folded sheets from the former 12 may go around the cylinder 19 to the folder rollers 20 and the first-folded sheets from the formers 12 and 12^a may go around the cylinder 19^a to the folder rollers 20^a; or the sheets from both of the formers 12 and 12^a may be collected, or assembled, and folded together by the folder rollers 20 or the folder

rollers 20^a, according to the setting of the switch blocks N^2 ; as may be convenient in practice.

If it be desired to drop the first-folded sheets from the former 12 onto the left-hand delivery wheel 67 the left-hand blades N will be set so that the points n^{16} will strip the sheets from the cylinder 19 and the sheets will run downward along and over the left-hand blades N and onto the wheels 67; and in like manner by setting the right-hand blades N so that the points n^{16} will strip the sheets from the cylinder 19^a, the first-folded sheets from the former 12^a will be caused to run downward along the right-hand blades N and dropped onto the delivery wheel 67^a.

If it be desired to make the second fold and then drop the sheets or sections running with the cut edges in the lead from the former 12 and 12^a respectively upon the delivery wheels 67 and 67^a the shafts n will be turned to withdraw the points n^{16} of the blades N from the channels of the cylinders 19 and 19^a; whereupon the first-folded sheets from the former 12 will run downward around the cylinder 64 and under the blades N and downward around the cylinder 19 to the folder rollers 20, by which they will be folded in a direction transverse to the first-folded edge and will drop upon the delivery wheels 67, with the folded edges in the lead; and in like manner the first-folded sheets running from the former 12^a will pass around the cylinders 64^a and 19^a to the folder rollers 20^a by which they will be folded and will drop onto the delivery wheel 67^a. Upon the turning of the switch blocks N^2 to the left the assembled first-folded sections from both formers will pass together around the cylinders 64^a and 19^a to the folder rollers 20^a and by turning the switch blocks N^2 to the right the assembled sections from both of the formers will be caused to travel around the cylinders 64 and 19 to the folder rollers 20.

In case printing couples are used equipped with plate cylinders having columns lengthwise of the plate cylinders, the main sheets will be cut by the cylinders 6 and 6' and the first fold will be made by the folder rollers 8^a and 8^{a'} (Fig. 1) coöperating with the main carrier-cylinders 7 and 7'; the second fold will be made on the formers 12 and 12^a and the third fold will be made by the folder rollers 20 and 20^a coöperating with the cylinders 19 and 19^a as already described.

Figs. 55 and 56 illustrate details of the cutter mechanisms preferably used on the main cutter-cylinders 6 and 6' in coöperation with the main carrier-cylinders 7 and 7' and the rotary pasting devices 45^a and 45^{a'}.

Figs. 30 to 35 inclusive illustrate a modified arrangement of folder mechanisms adapted to coöperate with plate cylinders

with columns lengthwise of the plate cylinders and with folder devices having swinging folder blades to make the second fold. These views also illustrate the construction and operation of switches of a modified form.

The main carrier-cylinders 7 and 7', the main cutter-cylinders 6 and 6', the folder rollers 8, 8^a and 8', 8^a', the intermediate assembling rollers 64 and 64^a are the same as have already been described. Tapes 16^x run around the rollers 8^a, 64, 70 and 71 and similar tapes run around the rollers 8', 64^a, 70' and 71'. Shields 69^a guide the sheets running on the tapes 16^x. The left-hand tapes 16^x lead the first-folded sheets over the folder rollers 20 into position to be creased and projected downward between the rollers by the left-hand swinging blade 68 and the right-hand tapes lead the first-folded sheets over the rollers 20^a into position to be operated upon by the right-hand blade 68^a. Stationary V-shaped plates 69^a substantially conforming to the curvature of the rollers 64 and 64^a have at their lower ends notches 69^g traversed by the point of the switches 69 when the switches are turned as hereinafter explained. The switches 69 are mounted on shafts 69^a and are shaped to conform to the curvature of the rollers 64 and 64^a. The points of the switches 69 fit in corresponding channels around the rollers 64 and 64^a. The shaft 69^a may be turned to cause the points of the switches 35 to enter the channels in the rollers or to cause them to withdraw from the channels. And when the switches are set the shafts may be secured by suitable securing devices 69^b to hold them in position. Delivery 40 wheels 67^x turn under the switches 69.

Fig. 33 illustrates such a setting of the switches that the first-folded papers traveling with the first-folded edges in the lead, passing around and between the rollers 64 and 64^a will drop directly onto the delivery wheel 67^x.

Fig. 34 illustrates such a setting of the switches that first-folded papers from both of the cylinders 7 and 7' will run over the right-hand switch 69 with the first-folded edges in the lead to the right-hand folder devices 68^a and 20^a and Fig. 35 illustrates such a setting of the switches that first-folded sheets from cylinder 7 will run over 55 the left-hand switch 69 with the first-folded edges in the lead to the left-hand folder devices 68 and 20, and first-folded sheets from the cylinder 7' will run over the right-hand switch 69 with the first-folded edges 60 in the lead to the right-hand folder devices 68^a and 20^a. It will be observed that in this form of the apparatus the formers are omitted and the second folder devices are at right angles to the plate cylinders.

Figs. 40 to 43 inclusive illustrate a single

ender apparatus three decks high and two-plates wide having printing couples equipped with plates having columns lengthwise of the plate cylinders. The main carrier-cylinders 7 and 7', the main cutter-cylinders 6 and 6', and supplement cutter and carrier-cylinders 4 and 5 are at right angles to the printing couples. A slitter device 24 slits the webs longitudinally. Short angle bars P, diverging from the center of the machine outward, change the direction of the travel of the web-members so that one web-member will travel toward the cylinders 6 and 7 and the other will travel toward the cylinders 6' and 7'. Folder rollers 20 and 20^a coöperate with swinging-blade folder-devices 68 and 68^a, to make the second fold. The angle bars P are tubular and turn on circular enlargements p¹ of the rods P¹ extending lengthwise through the tubes P. The rods P¹ have integral feet p² and slots p³ extending through the feet. Feet p³ screw into the enlarged parts p¹ of the rods P¹ and have slots p². The angle bars are connected with the main structure by bolts p⁷ passing through the slots p². By loosening the bolts the angle bars may be easily set at the precise angle necessary for accurate guidance of the web-members. The tubes P being revoluble on the rods P¹ greatly facilitate the travel of the webs. An apparatus of this form is adapted to produce from full speed webs exclusively, papers with supplements and papers without supplements, and is also adapted to use supplement plates on one-half of the length of the cylinders and use regular plates on one-half of the length of the same cylinders. This apparatus may be also adapted to run one supplement deck at half speed with supplement plates occupying one-half the length of the printing couples and run the other decks at full speed; and in that case the cylinders 4 and 5 will also run at half speed and the supplement sheets will all run to 100 one carrier-cylinder 7 or 7' as the case may be.

In producing papers without supplements the main webs will be slit longitudinally and one member of each web will run over one of the angle bars P to the cylinders 6 and 7 and the other member of each of the webs will run over the other angle bar to the cylinders 6' and 7', and the associated web-members will be cut by the cylinders 6 and 6' respectively into sheets in length equal to the width of two-leaves; the rollers 8 and 8^a will fold the sheets from the cylinder 7 and the folder rollers 8' and 8^a will fold the sheets from the cylinder 7'. The first-folded sheets from the cylinders 7 and 7' will be carried by the tapes 16^x into position to be operated upon by the sets of folder rollers 20 and 20^a respectively and the second-folded sheets will be dropped 130

125.

directly onto the delivery wheels 67 and 67^a respectively, or by using a suitable switch 69 (see Fig. 33) which has already been described, the first-folded papers may be delivered directly onto the central delivery wheel 67^a or the sections from the cylinders 7 and 7' may be collected and run to the folder rollers 20^a. If a supplement is used the supplement plates will occupy one-half 10 the length of the cylinders 2 of the upper deck and plates of regular pages will occupy the other half of the length of the same plate cylinders.

The supplement web-member will be carried around one of the angle bars to the cylinders 4 and 5, by which it will be cut into supplement sheets in length equal to the width of one page plus margins and the supplement sheets carried by the tapes 75 20 and 75^a will be delivered alternately upon the carrier-cylinders 7 and 7'; the member of the same web having the pages of regular matter will go around the other angle bar to the cylinders 6 and 7, or 6' and 7' as 25 the case may be and will be folded and delivered as already described. If one-plate-wide webs are used on plural decks, for example on three decks as shown in Figs. 44-46, all of the webs would run on one 30 side of the former 12, or on one angle-bar P of a pair of diverging angle-bars, substantially such as are shown in Figs. 40-43. If one-plate-wide webs be used on the multiple-deck machine illustrated in Figs. 47-49, 35 the webs from the several decks will all be brought together on the former, or angle-bars, as the case may be and pass between the rollers Z, Z, or Z', Z', as the case may be and will then be parted and run in a 40 straight line to the opposite folder mechanism.

The webs or web-members running over the former or the angle-bar, as the case may be, may be separated after leaving the 45 former, or the angle-bar, and all may be run over the rollers Z, Z, to the cooperating cylinders 6 and 7; or all may run to the cylinders 6' and 7'; or part may run to the cylinders 6 and 7 and part to the cylinders 50 6' and 7'; and all of the sheets may be folded by a single folder mechanism 8, 8^a or 8', 8^a as the case may be; or part may be folded by one folder mechanism and part by another folder mechanism, and in that case 55 the first-folded sections running with their folded edges in the lead, may be assembled by the assembling devices 64, 64^a shown in detail in Fig. 30 and may be folded together in the second fold, by any suitable mechanism 68, or 68^a; or by means of a former such as is shown in Fig. 9; or either of the 60 folder mechanisms 68 or 68^a, may be dispensed with and all of the sections from both of the first-folder devices may run to

the other second folder devices and may 65 drop onto a single delivery device.

Figs. 44 to 46 inclusive illustrate a three-deck, two-plate-wide apparatus equipped with plate cylinders having lengthwise columns. A former 12 two-plates-wide in its 70 larger dimension, receives webs from the printing couples and is equipped with a slitter device 24 which slits the webs at the upper end of the former; or the slitter device may be at the lower end of the former. 75 The main carrier-cylinders 7 and 7', the main cutter-cylinders 6 and 6' and the supplement cutter-devices and co-operating tape rollers are at right angles to the plate cylinders. The second fold is made by folder 80 rollers 20 and 20^a parallel to the plate cylinders and co-operating with swinging blades 68 and 68^a of the usual construction. The delivery wheels 67 and 67^a co-operate with the folder rollers 20 and 20^a and receive 85 the second-folded papers. The web-members of all of the webs are associated on the former 12. The supplement web-member goes to the cylinders 4 and 5 and they cut it into sheets one-leaf long which go alternately to the cylinders 7 and 7'. The cylinders 6 and 6' co-operating with the cylinders 7 and 7' cut the associated main web-members into sheets two-leaves long. The rollers 8, 8^a, and 8', 8^a', fold the two-leaf long 90 sheets crosswise along the central margin between the pages, with the supplement sheet between the inside pages of the main sheets. The first-folded sections, or the first 95 folded and collected sections, from the cylinders 7 and 7' may be assembled and delivered between the rollers 64 and 64^a or they may be carried by the tapes 16^a to the folder rollers 20 and 20^a and dropped upon the delivery wheels 67 and 67^a; or the first-folded sections may be assembled and folded 100 together and dropped upon one of the delivery wheels 67 or 67^a as the case may be. The first-folded papers run with the folded edges in the lead to the second-folder mechanisms by which they are folded in a direction transverse to the first-fold and the 105 papers with the second-folded edges in the lead drop onto the delivery wheels 67 and 67^a. The formers 12, 12', etc., respectively 110 have sheet-metal extensions 21. The extensions of the opposite formers converge upward.

In the machine shown in Figs. 1-4 and Figs. 15-24 the main carrier-cylinders and 120 the first folder cylinders are above the formers and turnable switches 23 are mounted between the upper ends of the extensions 21 of the formers and when the switches 125 occupy the closed position the first-folded sheets from the carrier cylinder 7 may run across the switch to and downward along the former 12' or the first-folded sheets from

the carrier-cylinder 7' may run across the switch to and downward along the former 12; and if the switch be set in the open position indicated by dotted lines in Fig. 2 the first-folded sheets from both the carrier-cylinders 7 and 7' with the folded edges in the lead, may run between the extensions 21 of the formers and fall onto the delivery wheels 67'. The switches 23 may be of any suitable or convenient form, I prefer to use, 10 between the rollers 9 and 9', switches such as are shown in Figs. 33, 34 and 35.

In Fig. 1 the folder rollers 8 and 8' are shown as adjacent to the roller 9 and between the roller 9 and the cylinder 7; and the folder rollers 8' and 8'' are shown as adjacent to the roller 9' and between the roller 9' and the cylinder 7'; but the folder rollers may, within the scope of my invention, 20 occupy other suitable or convenient positions, such for example as the relative positions shown in Fig. 42. In practice it will be best to locate the folder rollers in such position that they will operate to begin folding the sheets immediately upon the cutting off of the sheets. The main cutter cylinders 6 and 6' may be located in any suitable position relative to the cylinders 4, 5, 7 and 7' such that sheets carried on the cylinders 4 and 5 may be timed to run alternately to the cylinders 7 and 7'. The carrier-cylinders 7 and 7' may be twice the diameter of the cylinders 6 and 6' as shown in Fig. 1, but the cylinders 7 and 7' may be 35 of any other suitable or convenient diameter.

The mechanisms shown in Fig. 1 are so arranged that all of the main webs from the left-hand end of the apparatus running around the roller 24 will have exactly the same travel, and the cylinder 6 cutting on the cylinder 7 will cut all of the sheets along the margin between the pages, and in like manner the webs from the right-hand end of the machine will be timed so that the cylinder 6' will cut all of the sheets along the margin between the pages, and the cylinders 6 and 7 and 6' and 7' are in such position relative to each other that sheets cut by the cylinder 6 on the cylinder 7 will be timed to match sheets running on the cylinders 7', and sheets cut by the cylinder 6' on the cylinder 7' will be timed to match sheets running on the cylinder 7, and sheets cut by the cylinder 4' will be timed to run to the cylinders 7 and 7' to match the sheets running on said cylinders from either end or both ends of the machine. The rollers 72, 73 and 73' are so located that the pages of matter printed upon the printing couples at each end of the machine will be in exact registry at the time of cutting by the supplement cutter-cylinder 4 and the main cutter-cylinders 6 and 6'.

An apparatus comprising printing cou-

ples equipped with plates having lengthwise columns and comprising formers 12, 12' etc., having slitter devices 25 at the upper ends of the formers; a main carrier cylinder 7, a main cutter cylinder 6 and folder rollers 8 and 8', between the formers 70 and the printing couples substantially as shown in Figs. 1 and 3, may be equipped with assembling rollers 64, 64', swinging-blade folder-devices 68, 68' and second folder rollers 20 and 20', the same as shown in Fig. 30 and in that case the first fold will be made on the folder rollers 8 and 8' coöperating with the carrier cylinder 7, the first-folded sheets will be slitted and assembled at the lower end of the former and will travel from the formers to and around the assembling rollers 64 and 64' to the second folder-devices 68 and 68' and the first-folded sheets, or assembled sections, as the case may be, will travel with the first folded edges in the lead to the second folder mechanism and the second fold will be made as has already been fully explained in the description of the mechanisms shown in Fig. 30.

The parting of the main webs, or the main web members, as the case may be, and the running of the supplement web between the parted main webs or main web-members, is an important feature of my invention. The parting of the webs and the web-members is clearly shown in Figs. 40-48 inclusive, which illustrate the run of webs and web-members of a three-deck high machine. It is obvious however that the parting of the webs or web-members will be substantially the same for the five-deck machines illustrated in Figs. 15-39 inclusive and Figs. 56-62 inclusive; and for machines with any other number of decks; regardless of the number of decks of the apparatus, the arrangement of the plates on the plate cylinders and regardless of the direction of the columns, whether lengthwise of or circumferential to the plate cylinders; and in every case the sheets cut from a supplement web or web-member and led to and operated upon by the supplement cylinders 4 and 5, will run alternately to the pair of cylinders 6 and 7 the pair of cylinders 6' and 7'.

Having fully described my invention, what I claim as new and desire to secure by Letters Patent is:

1. In a double-ender printing and folding apparatus, the combination of printing couples at both ends of the machine, oppositely inclined formers between the printing couples of the two ends of the machine, a supplement cutter-mechanism intermediate of the formers, main cutter-mechanisms adjacent to the formers respectively, a slitter device intermediate of the main cutter-mechanisms and adapted to divide the supple-

ment web into plural web members, means for leading sheets cut by the supplement cutter-mechanism alternately to opposite formers, the sheet cut from one member of the supplement web going to one former and the next sheet cut from the same member of the supplement web going to an opposite former, and so on in succession, and means for leading the main sheets and the supplement sheets to and along the formers, with the supplement sheets next to the formers.

2. In an apparatus adapted to perfect and fold a continuously moving web, the combination of main carrier devices having their axes in line with the initial line of travel of the web operated upon, opposite folder mechanisms having their axes parallel to the initial line of travel of said web, and a delivery device intermediate of and simultaneously receiving papers folded separately by said folder mechanisms.

3. The combination of means for continuously propelling a plural-plate-wide main-web and a plural-plate-wide supplement-web, a severing device adapted to cut the main web longitudinally and a severing device adapted to cut the main web transversely to form two-leaf sheets in rows; a severing device adapted to cut the supplement web longitudinally and a severing device adapted to cut the web transversely, to form pairs of rows of supplement sheets; means for propelling the supplement sheets of one row of a pair directly to a carrier cylinder turning in one direction; means for propelling the supplement sheets of the complementary row of the same pair directly to another carrier cylinder turning oppositely to said first named carrier cylinder and means for inserting the supplement sheets with the main sheets.

4. The combination of means for printing on a plural-plate-wide supplement web the matter of one-leaf sheets in pairs of rows, means for printing on plural-plate-wide webs the matter of two-leaf sheets in rows, means for associating all the webs, means for propelling all of the webs in unison, means for leading the supplement web apart from the main webs and dividing it into one-leaf sheets, means for dividing the other webs into two-leaf sheets, and means for alternately associating in a direct run the one-leaf sheets with the two-leaf sheets of the different webs, the one leaf sheets of one row of a pair being associated with the two-leaf sheets derived from one web running on a carrier device revolving in one direction and the one leaf sheets of the complementary row of the same pair being associated with the two-leaf sheets derived from the other web, and running on a carrier device revolving in a direction opposite to the direction of revolution of said first named carrier device.

5. The combination of means for printing on a plural-plate-wide web the matter of one-leaf sheets in pairs of rows, means for printing on plural-plate-wide webs the matter of two-leaf sheets in rows, means for associating all the webs and propelling all of the webs in unison, means for propelling said first named web apart from the other associated webs, means for dividing the first named web into one-leaf sheets, means for dividing the other webs into two-leaf sheets, means for alternately associating the one-leaf sheets with the two-leaf sheets of the different webs, the one leaf sheets of one row of a pair being associated with the two-leaf sheets derived from one web, running on a carrier device revolving in one direction and the one-leaf sheets of the complementary row of the same pair being associated with the two-leaf sheets derived from the other web and running on a carrier device and revolving in a direction opposite to the direction of revolution of said first named carrier device and means for inter-folding the one-leaf sheets with the two-leaf sheets.

6. The combination of printing couples adapted to print on a single composite web the matter of one leaf supplement sheets in pairs of rows, and the matter of two leaf main sheets in range with the pairs of rows of said one leaf supplement sheets; printing couples adapted to print on plural-plate-wide main webs the matter of two leaf main sheets in rows; means for propelling all of the webs in unison; slitter devices adapted to slit said composite web to form plural longitudinal web-members; cutter devices adapted to cut one of the members of said composite web into one-leaf supplement sheets; cutter devices adapted to cut web-members of said composite web into two-leaf main sheets and also adapted to cut the said main webs into two-leaf main sheets; supplement-associating devices adapted to associate the one-leaf supplement sheets of said composite web with the two-leaf main sheets of said main webs; and main associating devices adapted to associate the two-leaf main sheets of said composite web with the two-leaf main sheets of any one of said main webs; the one-leaf supplement sheet of one row of a pair being associated with the two-leaf main sheets from said main webs running on said main associating device concurrently with the two-leaf main sheets derived from said composite web, and the one-leaf supplement sheets of the complementary row of the same pair being associated with two-leaf main sheets derived solely from main webs and occupying said main associating devices to the exclusion of main sheets derived from said composite web.

7. The combination of printing couples adapted to print on a single composite web

- the matter of one-leaf supplement sheets in pairs of rows, and the matter of two-leaf main sheets in range with the pairs of rows of said one-leaf supplement sheets; printing 5 couples adapted to print on plural-plate-wide main-webs the matter of two-leaf main-sheets in rows; means for propelling all the webs in unison; slitter devices adapted to slit said composite web to form plural longitudinal web members; cutter devices adapted 10 to cut one of the members of said composite web into one-leaf supplement sheets; cutter devices adapted to cut web-members of said composite web into two-leaf main sheets and 15 also adapted to cut said main webs into two-leaf main sheets; supplement-associating devices adapted to associate the one-leaf supplement sheets of said composite web with two-leaf main sheets of said main web; main 20 associating devices adapted to associate the two-leaf main sheets of said composite web with two-leaf main sheets of any one of said main webs; the one-leaf supplement sheet of one row of a pair being associated with the 25 two-leaf main sheets from said main webs running on said main associating device concurrently with the two-leaf main sheets derived from said composite web, and the one-leaf supplement sheets of the complementary 30 row of the same pair being associated with two-leaf main sheets derived solely from main webs and occupying said main associating devices to the exclusion of main sheets derived from said composite web; and means 35 for interfolding the one leaf sheets of said composite web with the two leaf sheets of any of the main webs.
8. In an apparatus for printing and folding papers, the combination of printing 40 couples; opposite main carrier cylinders in operative relation to said printing couples; slitter devices, main cutter devices and first folder devices, coöperating with said main carrier cylinders; slitter devices adapted to 45 slit the sections folded by said first folder devices; means for assembling said sections in a continuous straight run and means for folding together the assembled sections.
9. In a multiple-deck apparatus for printing 50 and folding papers, the combination of printing couples, oppositely inclined formers adjacent to the printing couples adapted to print upon main webs, printing couples adapted to print upon a secondary web, carrier cylinders adjacent to said formers respectively, main cutter cylinders coöperating with the main carrier cylinders, slitter devices adapted to slit the main webs before the main sheets are cut off, means for 55 slitting the secondary web before the sheets are cut therefrom, means for cutting the secondary web into one-leaf sheets, means for delivering said one-leaf sheets alternately upon and associating them with the 60 two-leaf sheets upon the main carrier cylinders, one sheet going to one carrier cylinder and the other sheet going to the opposite carrier cylinder, and means for folding together the sheets associated on the carrier cylinders respectively. 70
10. The combination of printing couples, opposite main carrier-cylinders intermediate of the printing couples, main cutter devices coöperating with the main carrier-cylinders respectively, a supplement carrier-cylinder 75 intermediate of the main carrier-cylinders, a supplement cutter device coöperating with the supplement carrier-cylinder, a slitter device adjacent to the supplement carrier-cylinder and located to slit main webs and the supplement webs, and means for leading sheets from the supplement carrier-cylinder alternately to the main carrier-cylinders. 80
11. The combination of printing couples, opposite main carrier-cylinders intermediate of the printing couples, main cutter devices coöperating with the main carrier-cylinders respectively, a supplement carrier-cylinder intermediate of the main carrier-cylinders, a supplement cutter device coöperating with the supplement carrier-cylinder, 85 a slitter device adjacent to the supplement carrier-cylinder and located to slit main webs and the supplement web, means for leading sheets from the supplement carrier-cylinder alternately to the main carrier-cylinders and first-folder devices coöperating with the main carrier-cylinders respectively. 90
12. The combination of printing couples 95 carrying main webs and a supplement web, main carrier-cylinders intermediate of the printing couples, main cutter devices coöperating with the main carrier-cylinders respectively, a supplement carrier-cylinder intermediate of the main carrier-cylinders, a supplement cutter device coöperating with the supplement carrier-cylinder, means for leading sheets from the supplement carrier-cylinder alternately to the main carrier-cylinders, first-folder devices coöperating with the main carrier-cylinders respectively and means for slitting the supplement web and the main webs before making the first fold. 100
13. The combination of printing couples 105 carrying main webs and a supplement web, main carrier-cylinders intermediate of the printing couples, main cutter-devices coöperating with the main carrier-cylinders respectively, a supplement carrier-cylinder intermediate of the main carrier-cylinders, a supplement cutter-device coöperating with the supplement carrier-cylinder, means for leading sheets from the supplement carrier-cylinder alternately to the main carrier-cylinders, first-folder devices coöperating with the main carrier-cylinders, respectively and means for slitting the supplement sheets and the main sheets after making the first fold. 110
14. In a double-ender apparatus the com- 115
- 120
- 125
- 130

1. Combination of printing couples carrying main webs and a supplement web, main carrier-cylinders intermediate of the printing couples, main cutter-devices coöperating with the main carrier-cylinders respectively, a supplement carrier cylinder intermediate of the main carrier-cylinders, a supplement cutter device coöperating with the supplement carrier-cylinder, means for leading sheets from the supplement carrier-cylinder alternately to the main carrier-cylinders, main folder-devices coöperating with the main carrier-cylinders respectively, means for slitting the main webs and the supplement web and paster devices located to apply paste to the main webs before the cutting off of the main sheets.
2. In a double-ender apparatus the combination of printing couples, main carrier-cylinders intermediate of the printing couples, main cutter-devices coöperating with the main carrier-cylinders, a supplement carrier-cylinder intermediate of the main carrier-cylinders, a supplement cutter device coöperating with the supplement carrier-cylinder, means for slitting the main webs and the supplement web, means for leading sheets from the supplement carrier-cylinder alternately to the main carrier-cylinders, means for associating main webs from both ends of the machine on one of the main carrier-cylinders and folder devices coöperating with the main carrier-cylinders respectively.
3. In a double-ender apparatus, the combination of full-speed main printing couples and full-speed supplement printing couples, main carrier-cylinders intermediate of the printing couples, main cutter-devices coöperating with the main carrier-cylinders respectively, a supplement carrier-cylinder intermediate of the main carrier-cylinders, a supplement cutter device coöperating with the supplement carrier-cylinder, means for slitting the supplement web and main webs, means for leading to and associating upon each of the main carrier-cylinders main webs from both ends of the apparatus, means for alternately conveying supplement sheets from the supplement cutter and carrier devices to the main carrier cylinders and first folder devices coöperating with the main carrier cylinders respectively.
4. In a multiple-deck apparatus the combination of plural decks equipped with full-speed main printing couples, a single deck of full-speed printing couples equipped in part with plates of regular matter and in part with supplement plates, main carrier-cylinders in operative relation to the printing couples, cutter-devices coöperating with the main carrier-cylinders respectively, a supplement carrier-cylinder intermediate of the main carrier-cylinders, a slitter device adjacent to the supplement carrier-cylinder, a supplement cutter device coöperating with the supplement carrier-cylinder, means for leading to one of the main carrier-cylinders the web-members comprising the regular pages printed on part of the printing couples that produce both regular pages and supplement pages, means for leading to the supplement carrier-cylinder the web-members of the same web comprising the supplement pages, means for leading sheets from the supplement carrier-cylinder alternately to the main carrier-cylinders, and folder-devices coöperating with the main carrier-cylinders respectively.
5. In a multiple deck apparatus, the combination of a deck comprising full-speed printing couples equipped with regular plates exclusively, a deck comprising full-speed printing couples equipped in part with plates of regular matter and in part with supplement plates, opposite main carrier devices in operative relation to the printing couples, a supplement carrier-device and coöperating supplement cutter-cylinder intermediate of the main carrier-devices, slitter devices adapted to slit the supplement web and the main webs, means for leading members of the main web to one of the main carrier-devices, means for leading members of the same web to the other main carrier-device, means for leading the supplement web-members comprising supplement pages to the supplement carrier-device, means for leading the members of the same webs comprising regular pages to the main carrier-devices, means for leading supplement sheets from the supplement carrier-device alternately to the main carrier-devices, cutter devices coöperating with the main carrier-devices respectively and first-folder devices coöperating with the main carrier-devices respectively.
6. The combination of means for printing on a plural plate-wide composite web the matter of one-leaf supplement pages and the matter of two-leaf regular pages, means for printing on main webs the matter of regular pages, means for slitting said composite web into members in width equal to the length of one page plus margins, means for associating with the main webs the web members comprising the regular pages of the composite web, means for cutting the web-member comprising the supplement pages into sheets in length equal to the width of one-page plus margins, means for cutting the associated regular web members of the main webs and the composite web into sheets in length equal to the width of two-pages plus margin, means for inserting the supplement leaves between the leaves of the two-leaf regular sheets and means for folding together the two-leaf main sheets and the one-leaf supplement sheets.
7. The combination of means for print-

ing on main webs the matter of regular pages, means for printing on a single plural plate wide composite web the matter of one-leaf supplement sheets and the matter of two-

- 5 leaf regular sheets, means for slitting said composite web longitudinally, means for associating the regular web-members of the composite web with the web-members of the main webs, means for applying to one of 10 the associated web members paste along the margins between the pages of each two-leaf sheet, means for cutting the associated regular web-members into sheets in length equal to the width of two-pages plus margins, 15 means for inserting the supplement sheets between the leaves of the regular sheets, and means for folding together the regular sheets and the supplement sheets.

21. The combination of printing couples, 20 main carrier-cylinders in operative relation to the printing couples, a supplement carrier cylinder intermediate of the main carrier-cylinders, a supplement cutter-device coöperating with the supplement carrier-cylinder, 25 main cutter cylinders coöperating with the main carrier-cylinders respectively, means for leading sheets from the supplement carrier-cylinder alternately to the main carrier-cylinders, first folder rollers in pairs opposite to each other and coöperating with the main carrier-cylinders and means for leading the first-folded papers toward each other with their folded edges in the lead and simultaneously dropping the first-folded 30 papers from both pairs of folder rollers.

22. The combination of printing couples, main carrier-devices in operative relation to the printing couples, a supplement carrier-device intermediate of the main carrier-devices, a supplement cutter device coöperating with the supplement carrier-device, main cutter devices coöperating with the main carrier-devices respectively, slitter devices coöperating with the supplement carrier-device and main carrier devices, folder devices in pairs opposite to each other and coöperating with the main carrier devices respectively, formers located in a row transverse to the machine and in operative relation to both pairs of folder devices and means for leading the first-folded sheets from both pairs of folder devices to and along the formers.

23. The combination of printing couples, 55 main carrier-cylinders in operative relation to the printing couples, a supplement carrier-cylinder intermediate of the main carrier-cylinders, a supplement cutter-device coöperating with the supplement carrier-cylinder, slitter devices adapted to slit the supplement web and the main webs, main cutter devices coöperating with the main carrier-cylinders respectively, pairs of folder rollers opposite to each other and coöperating with the main carrier-cylinders respec-

tively, oppositely inclined formers adjacent to the pairs of folder rollers respectively and means for leading the first-folded sheets with their folded edges in the lead to and along the formers respectively.

70

24. The combination of printing couples, main carrier-cylinders in operative relation to the printing couples, a supplement carrier-cylinder intermediate of the main carrier-cylinders, a supplement cutter-device coöperating with the supplement carrier-cylinder, slitter-devices adapted to slit the supplement web and the main webs, main cutter-devices coöperating with the main carrier-cylinders respectively, pairs of folder rollers opposite to each other and coöperating with the main carrier-cylinders respectively, oppositely inclined formers in rows transverse to the machine and in operative relation to both pairs of folder rollers and means for leading the first-folded sheets with the folded edges in the lead, to and along the formers of one row.

80

25. The combination of printing couples, main carrier-cylinders in operative relation to the printing couples, a supplement carrier-cylinder intermediate of the main carrier-cylinders, a supplement cutter device coöperating with the supplement carrier-cylinder, slitter devices adapted to slit the supplement web and the main webs, main cutter devices coöperating with the main carrier-cylinders respectively, pairs of folder rollers opposite to each other and coöperating with the main carrier-cylinders respectively, formers in a row transverse to the machine and in operative relation to the folder rollers, second carrier-cylinders adjacent to the formers respectively, and folder rollers coöperating with the second carrier-cylinders respectively.

100

26. The combination of printing couples, main carrier-cylinders in operative relation to the printing couples, a supplement carrier-cylinder intermediate of the main carrier-cylinders, a supplement cutter device coöperating with the supplement carrier cylinder, slitter devices adapted to slit the supplement-web and the main webs, main cutter-devices coöperating with the main carrier-cylinders respectively, pairs of folder rollers coöperating with the main carrier-cylinders respectively, formers in a row parallel to the folder rollers, second carrier-cylinders adjacent to the formers respectively and means for leading sheets from two adjacent formers toward each other and dropping them simultaneously.

110

27. The combination of printing couples, main carrier-cylinders in operative relation to the printing couples, a supplement carrier cylinder intermediate of the main carrier-cylinders, a supplement cutter device coöperating with the supplement carrier-cylinder, slitter devices adapted to slit the

115

120

125

130

- supplement web and the main webs, main cutter devices coöperating with the main carrier-cylinders respectively, pairs of folder rollers coöperating with the carrier-cylinders respectively, formers in a row parallel to the folder rollers, second carrier-cylinders adjacent to the formers respectively and two pairs of folder rollers intermediate of and coöperating with one pair of second carrier-cylinders.
28. The combination of formers in pairs, means for leading toward each other sheets folded on said formers respectively, second carrier-cylinders adjacent to the formers respectively and adapted to turn toward each other, folder rollers situated between and coöperating with the second carrier-cylinders respectively and switches controlling the run of the sheets relative to the folder rollers.
29. The combination of a pair of formers, means for leading toward each other sheets folded on said formers, carrier cylinders receiving sheets from said formers, respectively, folder rollers coöperating with said carrier cylinders, respectively, and switches between said carrier cylinders and controlling the run of sheets from said carrier cylinders to the folder rollers coöperating therewith.
30. The combination of a former, a carrier-cylinder in immediate proximity to and adapted to receive sheets directly from the former, means for leading to and around the carrier-cylinder sheets folded on the former, folder rollers coöperating with the carrier cylinder, and a switch extending part way around said carrier cylinder and adapted to lead sheets from said carrier cylinder around and outside of said folder rollers.
31. The combination of a former, a carrier-cylinder immediately adjacent to the former, means for leading to and around the carrier-cylinder sheets folded on the former, folder rollers coöperating with said carrier cylinder, a switch adapted to lead sheets away from said folder rollers, and a delivery device adapted to receive folded sheets from the former and running over the switch and also adapted to receive folded sheets from the carrier-cylinder and running between the folder rollers.
32. The combination of printing couples, opposite main carrier-cylinders in operative relation to the printing couples, main cutter devices coöperating with the main carrier cylinders respectively, slitter devices adjacent to the main carrier-cylinders respectively, and located to coöperate with either of the main carrier-cylinders, a supplement carrier-cylinder intermediate of the main carrier-cylinders, a supplement slitter-device intermediate of the main slitter-devices, a supplement cutter device coöperating with the supplement carrier-cylinder, and means for leading sheets from the supplement car-
- rier cylinder alternately to the main carrier cylinders.
33. The combination of printing couples, opposite main carrier-cylinders in operative relation to the printing couples, slitter devices adapted to slit the webs running from the printing couples, oppositely inclined formers coöperating with the main carrier-cylinders, and main cutter devices and a supplement cutter device between the main carrier-cylinders and the slitter devices.
34. The combination of printing couples, main carrier cylinders in operative relation to the printing couples, slitter-devices adapted to slit the webs running from the printing couples, second carrier-cylinders at right angles to the main carrier-cylinders, oppositely inclined formers between the main carrier-cylinders and the second carrier-cylinders, and main cutter devices and a supplement cutter device between the main carrier-cylinders and the slitter devices.
35. Mechanism effective to utilize a full width supplement web in producing papers with supplement comprising full-speed main printing couples equipped to print plural-plate-wide main webs, supplement printing couples adapted to run at full speed and also adapted to run at half speed in producing supplement sheets, slitter devices adapted to slit the main webs longitudinally, slitter devices adapted to slit the supplement web longitudinally, a supplement cutter device adapted to cut one leaf supplement sheets, main carrier devices in operative relation to said supplement cutter device, main cutter devices coöperating with said main carrier devices, folder devices adapted to fold at right angles to the axes of said main carrier devices, carrier devices adapted to carry sheets folded by said folder devices, and folder devices adapted to again fold the sheets folded by said first named folder devices.
36. The combination of printing couples adapted to print upon a plurality of continuously moving webs, associating devices associating said webs, main slitter devices adapted to slit said webs, means adapted to separate said webs and propel them apart from each other, opposite folder devices adapted to operate upon said separated webs, slitter devices intermediate of said folder devices and between said separated webs, cutter devices coöperating with said folder devices, and delivery devices coöperating with said folder devices.
37. In a double ender apparatus of the class described the combination of revoluble printing couples, plural parallel rows of second carrier-cylinders intermediate of the printing couples said rows of carrier cylinders being transverse to the machine, trains of spur wheels connecting all of the carrier-cylinders of the rows respectively,

revoluble drive-shafts parallel to the rows of carrier-cylinders respectively, counter-shafts at right angle to the drive-shafts, beveled gears connecting the counter-shafts 5 with the drive-shafts, and spur wheels on the counter-shafts respectively driving the trains of wheels connecting the carrier-cylinders.

38. The means for operating the printing couples of a double-endor multiple-deck apparatus; comprising spur wheels connected with the axles of the plate-cylinders and blanket-cylinders of each deck, intermediate gear wheels connecting the spur wheels of 10 the several decks, twin motors in operative relation to the apparatus, spur wheels on the shafts of the motors respectively, an intermediate revoluble shaft, a spur wheel on said shaft meshing with the spur wheels on the 15 motor shafts, a secondary spur wheel on the same shaft, a train of three gears connecting the secondary spur wheel with a spur wheel of one set of printing couples and a train of four gear wheels connecting the 20 secondary spur wheel with a spur wheel of another and opposite set of printing couples.

39. The means for simultaneously operating the supplement carrier-cylinder, the supplement cutter-cylinder, the slitter devices, the pasters, the main cutter-cylinders, the main carrier-cylinders, the first folder rollers and the tape rollers of a double-endor apparatus; comprising revoluble drive shafts transverse to the main frame, 35 bevel cog wheels secured on said shafts, vertical counter-shafts, bevel cog pinions on the counter-shafts meshing with the bevel wheels on the drive shafts, revoluble paster shafts, combined spur wheels and bevel cog 40 pinions secured on the paster shafts respectively, pasters on said paster shafts, bevel cog wheels on the vertical counter shafts driving the bevel pinions on the paster shafts, a revoluble supplement carrier shaft, 45 a supplement carrier cylinder on said shaft, a cog wheel and a cog pinion secured on the supplement carrier shaft, an intermediate gear between the cog pinion on the supplement carrier shaft and the spur wheel on one 50 of the paster shafts, a revoluble supplement cutter shaft, a supplement cutter cylinder on said shaft, a cog pinion secured on the supplement cutter shaft and meshing with the cog wheel on the supplement carrier shaft, a revoluble slitter shaft, slitter blades 55 on said slitter shaft, cog pinions on the slitter shafts, intermediate gear wheels connecting the cog pinions on the slitter shafts with the cog pinions on the paster shafts, 60 revoluble main carrier shafts, carrier cylinders on said carrier shafts, intermeshing cog wheels secured on the shafts of the main carrier-cylinders and the main cutter-cylinders, intermediate gear wheels connecting 65

the wheels on the paster shafts with the 65 wheels on the main cutter shafts, revoluble main carrier shafts, main carrier cylinders on said main carrier shafts, cog pinions on the folder-roller shafts meshing with the cog wheels on the main carrier-shafts, revoluble tape-roller shafts, tape rollers on said tape-roller shafts and pinions on the tape-roller shafts meshing with and driven by 70 the cog wheels on the main carrier-shafts.

40. Means for driving the supplement 75 carrier-cylinder and the supplement cutter-cylinder at different speeds; comprising a revoluble supplement cutter shaft, a supplement cutter cylinder on said supplement cutter shaft, a revoluble supplement carrier 80 shaft, a supplement carrier cylinder on said supplement carrier shaft, a cog pinion secured on the supplement cutter-shaft, a cog wheel and a cog pinion secured on the supplement carrier-shaft, the cog wheel on the 85 supplement carrier shaft being in mesh with the cog pinion on the supplement cutter shaft, a wide-face spur wheel turning on an axis parallel to the supplement carrier-cylinder, a revoluble intermediate shaft and a 90 connected intermediate spur wheel and spur pinions slidable and setable in different positions on the intermediate shaft, the intermediate spur wheel being constantly in mesh with the wide face spur wheel and the intermediate spur pinion being slidable to mesh with the cog wheel on the supplement carrier shaft when the intermediate spur wheel is not in mesh with the pinion on the 95 supplement carrier-shaft.

41. The combination of parallel formers, parallel carrier-cylinders intermediate of the formers, parallel web propelling devices, intermediate of the formers and the carrier-cylinders, an oscillative switch between the 100 web propelling devices and coöperating with both of the carrier-cylinders, folder rollers coöperating with the carrier-cylinders respectively, and means for stripping sheets from the carrier-cylinders and leading them 105 around the folder rollers.

42. The combination of parallel formers, parallel carrier-cylinders intermediate of the formers, sheet propelling devices intermediate of the formers and the carrier-cylinders, a switch intermediate of and coöperating with the sheet propelling devices and the carrier cylinders, folder rollers coöperating with the carrier-cylinders, and stripper plates adjustable relative to the carrier-cylinders, and setable to permit sheets to travel 115 around the carrier-cylinders to the folder rollers, and setable to lead sheets away from the carrier-cylinders and the folder rollers.

43. A combined stripper and guide comprising a turnable shaft, means for securing the shaft in different positions, eccentric blocks setable in different positions on 120

said shaft and blades having hubs turning and setable in different positions on the eccentric blocks.

44. The combination of a blade having a stripper device and having a central hub, a turnable shaft extending through said blade, means for securing the shaft in different positions, a circular block eccentric to the shaft and fitting in the hub of the blade, means for securing the eccentric block in different positions on the shaft, and means for securing the blade in different positions on the eccentric block.

45. The combination of revoluble carrier-cylinders, folder rollers coöperating with the carrier-cylinders, stripper-blades adjustable toward or away from the carrier-cylinders and a delivery device located to receive folded papers running on the stripper-blades with the folded edges in the lead and also to receive folded papers running between the folder rollers with the folded edges in the lead.

46. The combination of plate cylinders, revoluble opposite carrier cylinders parallel to the plate cylinders, main cutter devices coöperating with the carrier cylinders, folder rollers coöperating with the carrier cylinders respectively, opposite second folder devices at right angles to the printing couples, rollers intermediate of the second folder devices, tapes adapted to lead sheets from the first folder devices around the intermediate rollers to the second folder devices, a delivery wheel contiguous to the rollers intermediate of the second folder devices and turnable switches between said intermediate rollers.

47. A switch mechanism comprising revolute channeled parallel rollers, notched V-shaped guides conforming to the curvature of the rollers, shafts parallel to the rollers respectively, switches mounted on the shafts and adapted to fit in the channels of the rollers and setable to cause the points of two coöperating switches to occupy a position midway between the rollers and setable to cause the points of two coöperating switches to occupy a channel of one of the rollers and setable to cause the point of one switch to occupy the channel of one roller and the point of the other coöperating switch to occupy the corresponding channel of the coöperating roller.

48. A folder mechanism adapted to fold newspapers and also adapted to fold magazines; comprising a cylinder having diametrically opposite sets of perforations adapted to accommodate projectile pins, diametrically opposite folder blades turning in openings through the wall of the cylinder, folder rollers coöperating with the folder blades, oscillative shafts provided with pins adapted to project through the perforations in the cylinder, stationary cam-

plates and an intermediate stationary circular plate co-axial with the cylinder, arms connected with and slideable on the shafts respectively and provided with rollers adapted to run on the central circular plate and the cam-plate according to the setting of the arms on the shafts.

49. The combination of full-speed printing couples, a full-speed carrier-cylinder in operative relation to the printing couples and equipped with two sets of diametrically opposite pins, one set adapted to engage newspaper sheets in length equal to half the circumference of said carrier cylinder and the other set adapted to engage magazine sheets of half the length of said newspaper sheets in position for folding same midway thereof, and diametrically opposite folder-blades coöperating with the sets of pins respectively, a half-speed carrier cylinder and a half-speed cutter-cylinder coöperating to cut off magazine sheets, means for leading the magazine sheets from the secondary cutter and carrier-cylinders to the main carrier-cylinder and folder devices coöperating with the main carrier-cylinder to fold all of the magazine sheets midway thereof.

50. The combination of full-speed printing couples, a main carrier-cylinder in operative relation to the printing couples and equipped with sets of primary pins and sets of secondary pins and also equipped with folder-blades adapted to coöperate with the primary pins and the secondary pins; folder-rollers coöperating with the carrier-cylinder, a secondary carrier-cylinder and a coöperating secondary cutter-cylinder, means for driving the secondary carrier and cutter-cylinders at full-speed, means for driving the secondary carrier and cutter-cylinders at half-speed, means for placing the secondary carrier and cutter-cylinders in dis-use, means for taking up the slack of webs adjacent to the secondary cutter and carrier-cylinders and means for leading to the main carrier-cylinder the one-leaf sheets from the secondary carrier and cutter-cylinders.

51. The combination of revoluble opposite carrier-cylinders equipped with double sets of pins, secondary cutter and carrier-devices intermediate of the carrier-cylinders and adapted to cut one-leaf sheets, means for leading the one-leaf sheets alternately to the carrier-cylinders and means for folding the one-leaf sheets centrally.

52. The means for changing and controlling the speed of the secondary carrier and cutter-cylinders comprising a revoluble carrier-cylinder having a shaft, a cog wheel and a cog pinion secured on the shaft of the carrier-cylinder, a cog pinion secured on the shaft of the cutter-cylinder and driven by the wheel on the carrier-cylinder.

5 a broad-faced revoluble drive-wheel, a revoluble shaft intermediate of the drive-wheel and the carrier-cylinder, a cog wheel and a cog pinion slidable on the intermediate shaft to place the pinion in mesh with the wheel on the carrier-shaft and to place the wheel on the intermediate shaft in mesh with the pinion on the carrier-shaft and to disengage the wheel on the intermediate shaft from the drive wheel.

10 53. The combination of a carrier cylinder equipped with a set of primary pins effective to engage two-leaf newspaper sheets in position for folding the sheet midway thereof and equipped with secondary pins effective for engaging two-leaf magazine sheets (equivalent to one-leaf newspaper sheets,) in position for folding the same midway thereof, means for placing the secondary pins in disuse when the primary pins are in use, means for placing the primary pins in disuse when the secondary pins are in use, folder blades adapted to coöperate with both sets of pins and folder rollers adapted to 25 coöperate with the folder blades.

15 54. The combination of a full speed secondary carrier-cylinder and a coöperating full-speed secondary cutter-cylinder, opposite carrier-cylinders equipped with sets of 30 primary pins and sets of secondary pins, means for placing in disuse the secondary pins of the main carrier-cylinders when the primary pins are in use and means for placing in disuse the primary pins of the main carrier-cylinders when the secondary pins are in use, means for conveying sheets from the secondary cutter and carrier-cylinders alternately to the main carrier-cylinders, and folder rollers coöoperating with the main 40 carrier-cylinders respectively.

20 55. In an apparatus for printing and folding papers, the combination of printing couples; main carrier cylinders opposite to each other and in operative relation to said printing couples and adapted to carry toward each other sheets running on said main carrier cylinders; slitter devices, main cutter devices and first folder devices coöperating with said main carrier cylinders; means for assembling in a continuous straight run the folded sheets running from said first-folder devices and leading the folded and assembled sheets, with their first folded edges in the lead to coöoperating second folder devices; and second folder devices adapted to fold together said assembled and first-folded sheets in a direction transverse to the folded edges thereof.

25 56. In an apparatus for printing and folding papers, the combination of printing couples; opposite main carrier cylinders in operative relation to said printing couples and adapted to carry toward each other sheets running on said main carrier cylinders; slitter devices, main cutter devices and main

30 folder devices coöperating with said main carrier cylinders; means for assembling in a continuous straight run the folded sheets running from said first-folder devices and leading the folded and assembled sheets with 70 their first folded edges in the lead to coöperating second folder devices; second folder devices adapted to fold said assembled first-folded sheets cross-wise of their first fold; and a delivery device adapted to 75 receive second-folded papers from said second folder devices.

35 57. In an apparatus for printing and folding papers, the combination of printing couples; opposite main carrier cylinders in operative relation to said printing couples; slitter devices, main cutter devices and first folder devices coöperating with said main carrier cylinders; slitter devices adapted to slit the sections folded by said first folder devices, means for assembling the sections in a continuous straight run as they come from said first-folder devices and leading them to coöperating second folder devices; second folder devices adapted to fold said 85 assembled sections crosswise of their first fold; carrier devices receiving and carrying said second folded sections from said second folder devices; and third folder devices adapted to make the third fold of said sections; and a delivery device adapted to receive the third folded sections from said third folder devices.

40 58. In a double ender apparatus the means for controlling the webs from both ends of the machine when all the webs are led to one end to be operated upon by one set of main cutter, carrier, and folder devices; comprising revoluble drive shafts, spur wheels on said shafts, web-controlling devices, pinions on the shafts of the web-controlling devices respectively and driven by the wheels on the drive shafts, main cutter-cylinders and main carrier-cylinders parallel to the drive shafts, intermeshing spur wheels on the 100 shafts of the cutter-cylinders and carrier-cylinders, and slidable spur wheels intermediate of the wheels on the drive shafts and the main cutter shafts.

45 59. The combination of printing couples; main carrier cylinders in operative relation to said printing couples and adapted to carry toward each other sheets running on said main carrier cylinders, main cutter cylinders in operative relation to said main carrier cylinders, first folder mechanisms coöperating with said main carrier cylinders, respectively; means for assembling in a continuous straight run the sheets folded by said first-folder mechanisms and leading them with their first folded edges in the lead to a common second folder device; and a second folder device adapted to fold together the assembled first-folded sheets running from said first folder mechanisms.

115

120

125

130

60. The combination of printing couples; a slitter device, a main cutter device and a main carrier device in operative relation to said printing couples; a folder mechanism 5 coöperating with said main carrier device to make the first fold of sheets running on said main carrier device; formers adapted to make the second fold of sheets folded by said folder mechanism; second carrier devices receiving and carrying second-folded 10 sheets running from said formers respectively; and third folder mechanisms coöperating with said second carrier devices respectively.
61. The combination of printing couples; a slitter device, main cutter device and main carrier device in operative relation to said printing couples; a first folder mechanism coöperating with said main carrier device; 15 formers adjacent to and receiving first folded sheets from said first folder mechanism; means for slitting said first folded sheets before they arrive on said formers; and means for assembling the sheets folded 20 on said formers and leading them to a common place of delivery.
62. The combination of plural main printing couples, duplicate main cutter devices adapted to cut into full width sheets the 25 webs printed by said printing couples, duplicate carrier devices adapted to carry toward each other the sheets cut by said cutter devices and adjustable to run a half sheet out of time relative to each other, duplicate full 30 width first folder mechanisms situated between and coöperating with said carrier devices respectively, and second-folder devices adapted to fold in succession first-folded papers running alternately from said first- 35 folder devices respectively.
63. The combination of plural main printing couples, duplicate main cutter devices coöperating with the printing couples, duplicate sheet carrier devices, duplicate first- 40 folder devices coöperating with said cutter and sheet carrier devices, and a central delivery device adapted to simultaneously receive first-folded papers from both of said first-folder devices.
64. The combination of plural main printing couples, duplicate main cutter devices coöperating with the main printing couples, 45 duplicate sheet-carrier devices, duplicate first-folder devices folding transversely of the web and coöperating with said cutter and sheet-carrier devices, a paper carrier device adapted to receive first-folded sections from both of said first-folder devices, and a second-folder device adapted to fold together in a direction lengthwise of the web 50 the collected first-folded sections from both of said first-folder devices.
65. Mechanism effective to simultaneously 55 deliver two first-folded sections; consisting of revolute printing couples adapted to print and propel a continuously moving plural-plate-wide web, slitter devices adapted to slit said web into longitudinal web-members, associating devices for associating the web-members, opposite main carrier cylinders, cutter cylinders coöperating with said main carrier cylinders respectively, folder mechanisms parallel to the printing couples and coöperating with said main carrier cylinders respectively, folder mechanisms coöperating with said carrier cylinders respectively and a delivery device adapted to receive first-folded sections having the first fold transverse to the web from both of said first-folder mechanisms. 60
66. Mechanism effective to assemble first-folded sections and fold them together in the second fold; consisting of printing couples adapted to print and propel a plurality of moving plural-plate-wide webs, a web propelling device adapted to propel a plurality of webs associated thereon, slitter devices adapted to slit said webs to form longitudinal web-members, opposite main carrier cylinders carrying the members of 65 said associated webs, cutter cylinders coöperating with said main carrier cylinders respectively, first-folder devices coöperating with said main carrier cylinders respectively, means for leading first-folded sections, in 70 unison from both of said first folder devices to a common second folder device; and a second folder device adapted to fold together in the second fold the first folded sections, running in unison from said first 75 folder devices.
67. Mechanism effective to produce and collect first-folded sections each having a supplement; comprising revolute printing couples adapted to print and propel continuously moving plural-plate-wide webs, slitter devices adapted to divide said webs into web-members, opposite main carrier devices, main cutter devices coöperating with 80 said main carrier devices respectively, a supplement carrier and cutter device intermediate of said main carrier and cutter devices, means for conveying supplement sheets alternately and inserting them on the inside of the papers running on said main carrier 85 devices respectively, first-folder devices coöperating with said main carrier devices respectively and adapted to fold together the main sheets and the supplements running on said main carrier devices respectively, 90 and a central delivery device receiving the first-folded sections running simultaneously from both of said first-folder devices. 95
68. Mechanism for producing papers in 100 sections, one section with a supplement and the other without a supplement; comprising full-speed main printing couples, half-speed supplement printing couples, full speed main carrier devices opposite to each other, main cutter devices coöperating with said 105
- 110
- 115
- 120
- 125
- 130

main carrier devices respectively, half-speed supplement cutter and carrier devices intermediate of said main carrier and cutter devices, and means for delivering all of the 5 half-speed supplement sheets and inserting them with the main sheets running on one main carrier device, and folder devices co-operating with said main carrier devices respectively.

10 69. Mechanism for producing papers in sections, one section with a supplement and the other without a supplement, and collecting said sections; comprising full-speed main printing couples, half-speed supplement printing couples, full-speed main carrier devices, main cutter devices co-operating with said main carrier devices respectively, half-speed supplement cutter and carrier devices in operative relation to the main carrier devices, means for inserting all of the 15 half-speed supplement sheets with the main sheets running on one of the main carrier devices, first-folder devices co-operating with said main carrier devices respectively and a central delivery device adapted to simultaneously receive first-folded sections from both of said first folder devices.

20 70. Mechanism for producing first-folded papers by means of two independent first-folder devices and leading said first-folded papers from said first-folder devices alternately to and folding them consecutively by means of a single second-folder device; comprising full-speed printing couples, full-speed main carrier devices adjustable to time said main carrier devices so that one of them will run one-half the length of a main-sheet in advance of the other carrier device, main cutter devices co-operating with 25 said main carrier devices respectively, first-folder devices co-operating with the main carrier devices respectively and timed to supply to a co-operating second-folder device first-folded papers alternately from said first-folder devices, and a second folder device adapted to fold in succession the first-folded papers alternately folded by said first-folder devices.

30 71. Mechanism for producing first-folded papers with supplements, by means of two first-folder devices, and leading said first-folded papers with supplements from said first-folder devices alternately, and folding said papers consecutively by means of a single second-folder device; comprising full-speed printing couples, main carrier devices in operative relation to said printing couples, means for timing said main carrier devices so that one will run half the 35 length of a main sheet in advance of the other, main cutter devices co-operating with said main carrier devices respectively, full-speed supplement cutter and carrier devices in operative relation to said main carrier devices, means for conveying sheets from

said supplement cutter and carrier devices to said main carrier devices alternately, first-folder devices co-operating with said main carrier devices respectively and timed to alternately supply first-folded papers to a co-operating second folder device, and a second folder device receiving first-folded papers alternately from said first-folder devices and adapted to make the second fold of said papers in succession. 75

72. Mechanism effective to cause concurrently running sheets to run toward each other and arrive simultaneously at a single folder device folding in the direction of the length of the web; comprising revoluble carrier cylinders parallel to the printing couples and adapted to turn toward each other, revoluble cutter cylinders turning toward each other and co-acting with said carrier cylinders respectively, and a folder device adapted to fold in the direction of the length of the web and adapted to simultaneously receive sheets from both of said carrier cylinders. 80

73. Mechanism effective to cause concurrently running main sheets and alternately running supplement sheets to run to a single folder device; comprising main carrier cylinders revoluble toward each other, main cutter cylinders revoluble toward each other and co-acting with said main carrier cylinders respectively, a supplement carrier cylinder and a co-acting supplement cutter cylinder revoluble toward each other, leading devices adapted to lead sheets alternately in a direct run from the supplement cutter and carrier cylinders to the respective main carrier cylinders, and a folder device adapted to simultaneously receive and fold main sheets and inserted supplement sheets from both of said main carrier cylinders. 90

74. In an apparatus for printing and folding papers the combination of revoluble printing couples equipped with plates arranged to print upon plural-plate-wide webs the matter of sheets in pairs of rows, means for associating all of the webs before slitting and cutting, means for severing said webs longitudinally, means for severing said webs transversely, a carrier device adapted to carry sheets cut from said webs, a folder device adapted to fold the sheets cut from said webs in a direction transverse to the line of travel of said webs, and a folder device adapted to fold sheets cut from said webs, in the direction of the line of travel of said webs. 110

75. The combination of printing couples in a straight line and adapted to print upon a plurality of continuously moving webs, associating devices associating said webs, all running in parallel main slitter devices adapted to slit said webs, means adapted to separate said webs and lead them apart from each other, supplement cutter and slitter de- 125 130

views between said separated webs and in line with said printing couples, opposite folder devices adapted to operate upon said separated webs, and cutter devices co-operating with said folder devices.

76. Folder and assembling devices adapted to fold, assemble in a continuous straight run and fold again a plurality of sections running with their folded edges in the lead; comprising main carrier devices, adapted to carry toward each other sheets running on said main carrier devices; first folder mechanisms co-operating with said main carrier devices, means for assembling in a continuous straight run the sections folded by said first folder mechanisms and leading them to a common second folder device, and a second folder device receiving and folding together said assembled sections.

77. The combination of printing couples equipped with plates arranged to print upon a plural-plate-wide composite web the matter of one-leaf sheets in pairs of rows; means for continuously propelling said composite web; a severing device adapted to divide said web into pairs of rows of sheets; a severing device adapted to separate the sheets of the component rows of said pairs of rows of sheets; means for propelling said respective rows of sheets to different folder devices, and folder devices adapted to receive one leaf sheets derived from said composite web, and fold them in association with two leaf main sheets concurrently operated upon by said folder devices.

78. In an apparatus for printing and folding papers; means adapted to lead webs in the first instance away from each other, and then lead them toward each other; comprising printing couples adapted to print plural webs moving continuously in the same direction, opposite carrier devices in operative relation to said printing couples and adapted to carry sheets toward each other; means for leading some of said webs directly to one of said main carrier devices, and means adapted to lead other of said webs across both of said main carrier devices and to the other of said main carrier devices.

79. The combination of means for printing full width main webs, means for printing a full width insert web, means for associating said insert web and main webs, means for slitting all of said associated webs, means for separating and propelling said main webs, means for propelling said insert web between said separated main webs, a slitter device between said separated main webs and adapted to slit said insert web running between said main webs, and means for propelling the members of said insert web to and inserting them with said separated main webs.

80. The combination of printing couples all in parallel and adapted to print on both

sides of continuously moving parallel main webs, printing couples parallel to the main printing couples and adapted to print on both sides of a continuously moving insert web, opposite folder mechanisms in operative relation to and in line with all of said printing couples, means for associating the main webs in a continuous straight run, means for leading and propelling some of the main webs to one of said folder mechanisms, means for leading and propelling some of the main webs to the other and opposite folder mechanism, means for leading an insert web intermediate of the main webs, cutter and carrier devices between said main webs and adapted to cut insert sheets; and means for propelling said insert sheets alternately to said opposite folder devices.

81. In an apparatus for printing and folding papers, the combination of printing couples all in parallel and adapted to print plural-plate-wide main webs, printing couples parallel to said main printing couples and adapted to print a plural-plate-wide composite web, opposite folder devices in operative relation to said printing couples, associating devices associating in parallel all of said main webs and said composite web, intermediate cutter and carrier devices adjacent to said opposite folder devices, in line with the main webs running from all of the printing couples, slitter devices intermediate of said opposite folder devices, means for leading a main web to one of said opposite folder devices, means for leading a main web to the other of said opposite folder devices, means for leading to said intermediate cutter and carrier device the composite web, running between the main webs as they run to said opposite folder devices, and means for propelling cut sheets from said intermediate cutter and carrier devices alternately to said opposite folder devices.

82. The combination of means for printing full width main webs, means for printing a full width insert web, means for associating all of said webs, means for slitting longitudinally all of said webs, means for separating and leading apart from each other the members of said associated and slit main webs, an intermediate cutter device between the separated members of said main webs, means for leading said insert web to said intermediate cutter device, opposite folder mechanisms in operative relation to said intermediate cutter device, and means for propelling sheets alternately from said intermediate cutter device to said opposite folder devices.

83. The combination of means for printing continuously moving webs, means for slitting said webs to divide them into longitudinal web members, opposite folder devices adapted to fold sheets derived from the members of said webs, a slitter device in-

termidate of said folder devices and adapted to slit a member of one of said webs running between the web members as they run to said folder devices, and means for propelling the members of said last named web to said folder devices respectively.

84. The combination of printing couples adapted to print full width main webs, printing couples adapted to print a full width insert web, slitter devices adapted to slit said main webs, folder devices in operative relation to said printing couples, leader devices adapted to lead main webs to said opposite folder devices, slitter devices intermediate of the webs running to said folder devices, and leader devices adapted to lead the members of said insert web to said folder devices and insert them with the main webs running to said folder devices respectively; the relation of the mechanisms being such that members of a single insert web run to both folder mechanisms and are inserted with main webs running to said folder mechanisms respectively.

85. In an apparatus for printing and folding papers, the combination of printing couples having plates arranged to print on a single composite web the matter of one-leaf supplement sheets in pairs of rows and the matter of two-leaf main-sheets in range with the pairs of rows of said one-leaf supplement-sheets, printing couples adapted to print on plural plate-wide main web the matter of two-leaf main sheets in rows; means for associating the two-leaf sheets of said composite web with two-leaf sheets of said main web and means for associating one-leaf sheets of said composite web with two-leaf sheets of said main web and two-leaf sheets of said composite web.

86. The combination of printing couples adapted to print upon a plurality of continuously moving webs; associating devices associating said webs; slitter devices adapted to slit said webs; means adapted to separate said webs and adapted to propel said separated webs; supplement cutter and slitter devices located between said separated webs; opposite first folder devices in operative relation to said supplement cutter and slitter devices and a delivery device adapted to receive papers from both of said first folder devices.

87. The combination of printing couples adapted to print on a plurality of continuously moving webs; associating devices associating said webs; slitter devices adapted to slit said webs; means adapted to separate said webs and adapted to propel said separated webs; supplement cutter and slitter devices located between said separated webs; opposite first folder devices in operative relation to said supplement cutter and slitter devices; second folder devices adjacent to said first folder devices; means for leading

first folded sections from a single first folder device to and upon a plurality of second folder devices; and means for leading the second-folded sections from a plurality of said second folder devices to a common place of delivery.

88. The combination of printing couples adapted to print on a plurality of continuously moving webs; means for separating said webs and propelling them apart; first folder devices operating upon said separated webs respectively; second folder devices end to end relative to each other and coöperating with said first folder devices respectively; and delivery devices end to end relative to each other and coöperating with said second folder devices; all of said mechanisms being in such relation to each other that second folded papers running with the second folded edges in the lead from both second folder devices are invariably delivered side by side.

89. In a double ender apparatus for printing and folding papers, the combination of a plurality of right hand formers side by side, a plurality of left-hand formers side by side, parallel sets of right hand and left hand web-propelling devices propelling webs toward said formers, and a slitter device and cutter device located between the right hand set and the left hand set of web-propelling devices.

90. The combination of supplement propelling devices adapted to propel supplements divergently, main web propelling devices adapted to receive supplements running divergently from said supplement propelling devices and insert same with main webs running on said web propelling devices, first folder devices coöperating with said main web-propelling devices respectively, and second folder devices coöperating with said first folder devices and adapted to deliver on the same level second folded papers produced from a plurality of webs running on different levels.

91. The combination of printing mechanisms, a web-pulling device adapted to pull perfected webs printed by said printing mechanisms, supplement cutter and carrier devices parallel to said pulling device and coöperating with each other to cut a supplement web into sheets running alternately to main carrier devices, main carrier devices parallel to and coöperating with said supplement cutter and carrier devices respectively, main cutter devices coöperating with said main carrier devices respectively, and folder devices intermediate of and respectively coöperating with said main carrier devices and each making a fold crosswise of the web.

92. The combination of printing mechanisms, a male supplement cutter and carrier cylinder equipped with a blade and sheet-

- holding devices, a co-acting female supplement cutter and carrier cylinder equipped with a cutting wood and sheet-holding devices, means for rendering effective the sheet-holding devices of the male supplement cutter and carrier cylinder when the sheet-holding devices of the female supplement cutter and carrier cylinder are ineffective, means for rendering effective the sheet-holding devices of the female supplement cutter and carrier cylinder when the sheet-holding devices of the male supplement cutter and carrier cylinder are ineffective, a main carrier cylinder receiving supplement sheets directly from said male supplement cutter and carrier cylinder, said supplement sheets being inserted next to the surface of said main carrier cylinder, a complementary main carrier cylinder receiving supplement sheets directly from said female supplement cutter and carrier cylinder, said supplement sheets being inserted next to the surface of said complementary main carrier cylinder, main cutter devices co-acting with said main carrier cylinders respectively, and folder mechanisms intermediate of and co-operating with said main carrier devices respectively.
93. In an apparatus of the class described, the combination of printing means adapted to perfect full speed outside main webs and full speed inside main webs, printing means adapted to perfect a half-speed supplement web, a main carrier device in operative relation to said printing means, a supplement cutter and carrier device in operative relation to said main carrier device, means for leading said inside main webs next to said main carrier device, means for leading said outside main webs to the same main carrier device, means for inserting supplement sheets between said outside and inside webs before cutting said webs, means for simultaneously cutting said outside and inside webs, and folder mechanism adapted to fold together the sheets cut from said outside and inside webs.
94. Means effective to cut supplements and insert them in two papers and fold said papers and drop them simultaneously onto a single delivery device; comprising supplement cutter and carrier devices, main carrier devices, main cutter devices co-operating with said main carrier devices respectively, folder devices intermediate of and co-operating with said main carrier devices respectively, and a central delivery device adapted to receive all the papers folded by all of said folder devices.
95. Means effective to cut and insert supplement sheets in a plurality of papers and simultaneously fold said papers; comprising web-pulling devices adapted to pull continuously moving perfected webs, supplement cutter and carrier devices parallel to said web-pulling devices, two main carrier de-
- vices parallel to and receiving supplement sheets alternately from said supplement cutter and carrier devices, main cutter devices co-operating with said main carrier devices respectively, and folder devices intermediate of said main carrier devices.
96. The combination of oppositely turning main carrier devices side by side, main cutter devices co-operating with said main carrier devices respectively; two sets of main folder devices intermediate of said main carrier devices and in such relation thereto that one set of folder devices co-operates with one main carrier device and the other set of folder devices co-operates with the other main carrier device.
97. The combination of oppositely turning main carrier devices side by side, main cutter devices co-operating with said main carrier devices respectively, two sets of main folder devices intermediate of said main carrier devices and in such relation thereto that one set of folder devices co-operates with one main carrier device and the other set of folder devices co-operates with the other main carrier device, and a central delivery device intermediate of and receiving folded papers from both of said sets of folder devices.
98. The combination of printing mechanisms; two sets of opposite web-pulling devices adapted to pull toward a common center a plurality of main webs; a supplement web-pulling device intermediate of said main web-pulling devices; a half-speed supplement cutter device between said sets of main web-pulling devices and adapted to cut into supplement sheets the web-member pulled by said supplement pulling device; a main carrier adapted to carry main webs running from either set, or both sets, of web-pulling devices and supplement sheets running from said supplement cutter device; a main cutter device co-operating with said main carrier; and a folder device co-operating with said main carrier.
99. The combination of printing mechanisms comprising plate cylinders two plates in circumference and a plurality of plates in width and equipped with exclusively original plates extending around each plate cylinder a distance equal to the width of two pages plus margins, and impression cylinders co-operating with said plate cylinders respectively to perfect page-for-plate matter on both sides of continuously moving webs, means for slitting said webs into members in width equal to the length of one page plus margins; means for alining said web-members; oppositely rotating carriers in line with said alined web-members and adapted to carry said web-members with the columns thereof extending across said carriers; cutters co-operating with said carriers, to cut parallel to the columns, the alined

webs running on the carriers, into sheets in length equal to the width of two pages plus margins; first folder mechanisms adapted to make the first fold of said sheets along 5 the central margins and parallel to the columns thereof to form sections; means for assembling the sections running toward each other with their first-folded edges in the lead and with the edges of the ends of one 10 section in line with the edges of the ends of the other section; and the columns of one section parallel to the columns of the other section; and second folder mechanism adapted to fold the assembled sections together 15 crosswise, of the crease of the first fold to produce papers in sections, all the matter of said papers being page-for-plate matter, and the matter of one section being different from the matter of the other section.

20. 100. The combination of printing mechanisms, two opposite sets of web-pulling devices adapted to pull from opposite directions toward a common center the webs perfected by said printing mechanisms, a supplement cutter device located between said opposite sets of web-pulling devices and adapted to cut supplement sheets from a web or web-member running from either set of web-pulling devices, two opposite 25 main carrier devices adapted to receive webs from either or both sets of web-pulling devices, means for leading supplement sheets from said supplement cutter device alternately to said main carrier devices, main 30 cutter devices coöperating with said main carrier devices respectively and folder mechanisms coöperating with said main carrier devices respectively.

101. The combination of printing mechanisms, a plurality of web-pulling devices adapted to pull webs perfected by said printing mechanisms, a supplement cutter device adapted to cut supplement sheets from a web-member running from any one 45 of said web-pulling devices, main carrier devices adapted to carry webs running from any and all of said web-pulling devices, means for leading supplement sheets from said supplement cutter device alternately to 50 said main carrier devices, main cutter devices coöperating with said main carrier devices respectively, folder devices coöperating with said main carrier devices respectively, and a delivery device coöperating 55 with both of said folder devices.

102. The combination of printing mechanisms, a plurality of web-pulling devices adapted to pull webs perfected by said printing mechanisms, a first supplement cutter and carrier device parallel to said web-pulling devices and equipped with retractile pins, a coöperating supplement cutter and carrier device parallel to said first supplement cutter and carrier device and equipped with retractile pins, the pins of said first

supplement cutter and carrier device and said second supplement cutter and carrier device respectively, being alternately effective and ineffective, a first main carrier device adjacent to said first supplement cutter and carrier device, a second main carrier device adjacent to said second supplement cutter and carrier device, means for leading cut sheets from said supplement cutter and carrier devices to said main carrier devices alternately, main cutter devices coöperating with said main carrier devices respectively, and folder devices intermediate of and coöperating with said main carrier devices respectively. 80

103. In an apparatus of the class described, the combination of associating devices adapted to coöperate with rotary printing mechanisms, opposite main carrier devices in operative relation to said associating devices, main cutter devices coöperating with said main carrier devices, folder devices intermediate of said main carrier devices and coöperating with said main carrier devices respectively, and a central delivery 90 device simultaneously receiving folded papers from both of said folder devices.

104. The combination of printing mechanisms, web-pulling devices adapted to pull webs perfected by said printing mechanisms, a plurality of main carrier devices in operative relation to said web-pulling devices, supplement cutter and carrier devices in operative relation to said web-pulling devices and adapted to supply supplement sheets 95 alternately to said main carrier devices, main cutter devices coöperating with said main carrier devices respectively, and folder devices coöperating with said main carrier devices respectively. 100

105. The combination of printing mechanisms, a plurality of web-pulling devices adapted to pull toward a common center webs perfected by said printing mechanisms, a plurality of main carrier devices between 110 and in operative relation to said web-pulling devices, supplement cutter and carrier devices between said web-pulling devices and adapted to cut and carry supplement sheets alternately to said main carrier devices, main cutter devices coöperating with said main carrier devices, folder devices coöperating with said main carrier devices respectively, and a delivery device between 115 said folder devices and receiving papers 120 from all of said folder devices.

106. The combination of printing mechanisms, web-pulling devices adapted to pull webs perfected by said printing mechanisms, main carrier devices in operative relation to 125 said web-pulling devices, supplement cutter and carrier devices in operative relation to said web-pulling devices and adapted to cut and carry supplement sheets alternately to said main carrier devices, main cutter de- 130

vices coöperating with said main carrier devices respectively, main folder devices coöperating with said main carrier devices, and a central delivery device receiving papers from said folder devices.

107. The combination of printing mechanisms, a plurality of web-pulling devices adapted to pull webs perfected by said printing mechanisms, a plurality of opposite main carrier devices in operative relation to said web-pulling devices, main cutter devices coöperating with said main carrier devices, folder mechanisms coöperating with said main carrier devices respectively, and a single delivery device adapted to receive papers simultaneously from a plurality of folder mechanisms; said web-pulling devices and said single delivery device being in such relation to each other that folded papers will drop onto the same delivery device in case one of said web-pulling devices is in coöperation with one of said main carrier devices and the folder mechanisms co-acting therewith, or in case a plurality of said web-pulling devices are in coöperation with a single main carrier device and the folder mechanisms co-acting therewith, or in case a plurality of web-pulling devices are in coöperation with a plurality of main carrier devices and the folder mechanisms co-acting therewith.

108. In an apparatus of the class described, the combination of printing means adapted to perfect full-speed outside main webs and full-speed inside main webs, printing means adapted to perfect a half-speed supplement web, a main carrier device in operative relation to said printing means, a supplement cutter and carrier device in operative relation to said main carrier device, means for leading said inside main webs next to said main carrier device, means for leading said outside main webs to the same main carrier device, means for inserting supplement sheets between said outside and inside webs before cutting said webs and means for simultaneously cutting said outside and inside webs.

109. The combination of printing mechanisms, a plurality of web-pulling devices adapted to pull webs perfected by said printing mechanisms, associating and carrier mechanisms and cutter and folder mechanisms coöperating to associate webs from all of said web-pulling devices and carry cut and fold papers derived from the webs running from all of said web-pulling devices; and a single delivery device located to receive, two at a time, folded papers derived from webs running from said web-pulling devices separately, or to receive, one at a time, on the same delivery device, papers derived from webs running from all of said web-pulling devices collectively and associated after leaving said web-pulling devices.

110. In an apparatus of the class described, the combination of instrumentalities effective to fold and deliver, one at a time, onto a single delivery device papers produced from associated webs running upon a plurality of associating devices and again associated after leaving said associating devices, or to fold and deliver two at a time, onto the same delivery device, papers produced from associated webs running on all of said associating devices; comprising a plurality of web-pulling devices, means for slitting webs running on said web-pulling devices, main carrier devices intermediate of said web-pulling devices, means for leading webs from any of said web-pulling devices to and associating them on any of said main carrier devices, cutter mechanisms and folder mechanisms coöperating with said main carrier devices respectively, and a delivery device located to receive papers from all of said folder mechanisms.

111. In an apparatus of the class described, the combination of printing means adapted to perfect full-speed main webs, printing means adapted to perfect a half-speed supplement web, supplement cutter and carrier cylinders each equipped with duplicate sets of retractile pins, means for rendering effective the pins of one of said cylinders to lead all of the supplement sheets in one direction, means for rendering ineffective the pins of the other cylinder, a main carrier device in operative relation to said printing means, means for leading main webs to said main carrier device, means for inserting half-speed supplement sheets with the main webs running on said main carrier device, a main cutter device adapted to cut into sheets the main webs running on said main carrier device, and folder mechanism adapted to fold together said sheets, including supplements.

112. In a machine for printing and folding papers, the combination of printing means adapted to perfect full width, full speed main webs, printing means adapted to perfect a full speed full width supplement web, right-hand and left-hand first folder devices operating on said main webs, means for supplying supplements at full speed to said first folder devices, end to end second folder mechanisms coöperating with said first folder devices to fold papers with supplements, and end to end delivery devices adapted to deliver side by side papers with supplements derived from said full width full speed main webs and supplement web.

113. In an apparatus of the class described, the combination of printing means adapted to perfect a plurality of continuously moving plural-plate-wide webs, means for slitting said perfected webs into web-members before making the first fold, means for alining said web-members to run

- face to face before making the first fold, right and left and opposite main carrier devices in line with said alined web-members, means for parting said alined web-members before making the first fold, means for leading some of said alined web-members to one main carrier device, means for leading other web-members in alinement with said first named web-members to the other and opposite 10 main carrier device and main cutter devices cooperating with said main carrier devices respectively and adapted to cut into two-leaf sheets said alined and unfolded web-members.
114. In a printing and folding machine, the combination of printing mechanisms adapted to perfect a plurality of full speed main webs, and a half-speed supplement web; right and left main cutter, main carrier and main folder devices adapted to cut, carry and fold main sheets derived from said full speed webs, and supplement cutter and carrier mechanisms adapted to cut said half-speed supplement web into one-leaf supplement sheets and insert said supplement sheets next to either of said main carrier devices.
115. In a printing and folding machine, the combination of printing mechanisms 30 adapted to perfect a plurality of full-speed main webs and a half-speed supplement web; main cutter, main carrier and main folder devices adapted to cut, carry and fold main sheets derived from said full speed webs; means for leading apart from the other webs a main web or webs and then associating it or them on one of said main carrier devices with the main webs from which it was or they were originally separated; and 35 supplement cutter and carrier devices located between said parted main webs and adapted to cut said half speed supplement web into one leaf supplement sheets and insert said supplement sheets between the re- 40 associated webs running on one of said main carrier devices.
116. The combination of printing means adapted to perfect a plurality of full speed main web-members comprising matter in 50 columns cross-wise of said main web-members and a half speed supplement web-member comprising matter in columns cross-wise of said supplement web-member; means for disposing said main web-members and supplement web-member in line with each other, in line for making the first fold cross-wise of the main web-members and in line for assembling first-folded sheets running with their first-folded edges in the lead; a main 55 carrier device in line with said main web-members and supplement web-member; means for leading main web-members to and associating them on said main carrier device; means for cutting said 60 supplement web-member into sheets in 65
- length equal to the width of one page plus margins; means for inserting said supplement sheets between two main web-members running to said main carrier device; means for cutting said main web-members 70 into sheets in length equal to the width of two pages plus margins; and folder-means adapted to fold said sheets, to produce papers having supplement between any two leaves, other than the two middle leaves of 75 said papers.
117. In combination with means for perfecting a plurality of main web-members and a supplement web-member; right and left and opposite main carriers adapted to 80 carry main web-members and supplement sheets; a half-speed supplement cutter in operative relation to said main carriers; means for associating on each main carrier a plurality of main web-members; means 85 for inserting supplement sheets between the web-members running to one of said main carriers; main cutters coöperating with said main carriers respectively; first folder mechanisms coöperating with said main carriers respectively to make the first fold of sheets running thereon; and a second folder mechanism adapted to fold together the first-folded sheets folded by said first-folder mechanisms.
118. In an apparatus of the class described, the combination of printing means adapted to perfect continuously moving webs, means for slitting said perfected webs into main web-members and a supplement 100 web-member, means for alining said web-members to run face to face, right and left and opposite main carrier devices in line with said alined web-members, means for parting said alined web-members, means for 105 leading some of said alined main web-members to one main carrier device, means for leading other alined main web-members to the other and opposite main carrier device, supplement cutter and carrier devices intermediate of said main carrier devices and between and in line with said alined and parted main web-members, means for leading 110 said supplement web-member to said supplement cutter and carrier devices, means for leading supplement sheets alternately and directly from said supplement cutter and carrier devices to said main carrier devices, main cutter devices coöperating with said main carrier devices respectively and 115 folder mechanisms coöperating with said main carrier devices respectively and each effective to fold papers with supplements and also effective to fold papers without supplements.
119. In an apparatus of the class described, the combination of printing means adapted to perfect a plurality of continuously moving webs, means for slitting said perfected webs into main web-members and 120

- a supplement web-member, means for alining said web-members to run face to face, right and left and opposite main carrier devices in line with said alined web-members, 5 means for parting said alined web-members, means for leading some alined main web-members to one main carrier device, means for leading other alined main web-members to the opposite main carrier device, main 10 cutter devices coöperating with said main carrier devices, supplement cutter and carrier devices intermediate of said main carrier devices and between and in line with said alined and parted main web-members, 15 means for leading said supplement web-member to said supplement cutter and carrier devices, means for leading supplement sheets alternately from said supplement cutter and carrier devices to said main carrier 20 devices, first folder mechanisms coöperating with said main carrier devices respectively, means for assembling the sections folded by said first folder mechanisms, and a second folder mechanism adapted to fold together 25 said assembled sections.
120. In an apparatus of the class described, the combination of printing means adapted to perfect continuously moving webs, means for slitting said perfected webs 30 into main web-members and a supplement web-member, means for alining all of said web-members to run face to face, means for parting said alined main web-members, half-speed supplement cutter and carrier devices 35 between said alined and parted main web-members, means for leading a half-speed supplement web-member to said supplement cutter and carrier devices, a full-speed main carrier device in operative relation to said 40 printing means and said supplement cutter and carrier devices, means for re-associating on said main carrier device, all of said alined and parted main web-members, means for inserting half-speed supplement sheets be- 45 tween the alined and re-associated main web-members, running to said full speed main carrier device and a main cutter device coöperating with said main carrier device.
121. In an apparatus of the class de- 50 scribed, the combination of printing means adapted to perfect full speed main webs and a half-speed supplement web, means for slitting said perfected webs into main web-members and supplement web-members, 55 means for alining said main webs to run face to face, means for parting said alined main webs, half-speed supplement cutter and carrier devices between said alined and parted main webs, means for leading said half- 60 speed supplement web to said supplement cutter and carrier devices, a main carrier device in operative relation to said printing means and said supplement cutter and carrier devices, means for leading all of said 65 alined and parted main webs to and reasso-
- ciating them on said main carrier device, means for inserting half-speed supplement sheets between the alined and re-associated main webs running to said main carrier device, and a main cutter device coöperating 70 with said main carrier device.
122. In an apparatus of the class de- 75 scribed, the combination of printing means adapted to perfect full-speed main webs and a half-speed supplement web, means for slit- 80 ting said perfected webs into main web-members and supplement web-members, means for alining said webs to run face to face, means for parting said alined main webs, half-speed supplement cutter and carrier devices between said alined and parted main webs, means for leading said half-speed supplement web to said supplement cutter and carrier devices, a main carrier device in operative relation to said printing 85 means and said supplement cutter and carrier devices, means for leading all of said alined and parted main webs to said main carrier device, means for inserting half-speed supplement sheets between the alined 90 main webs running to said main carrier device, a main cutter device coöperating with said main carrier device and first folder mechanism coöperating with said main carrier device. 95
123. In an apparatus of the class de- 100 scribed, the combination of printing means adapted to perfect full speed outside-main webs and full speed inside-main-webs, printing means adapted to perfect a half-speed supplement web, right and left and opposite main carrier devices in operative relation to said printing means, a supplement cutter and carrier device in operative relation to said main carrier devices and adapted to cut 105 the half speed web into supplement sheets, means for leading to one of said main carrier devices, inside main webs running next to said main carrier device, means for leading outside main webs to the same main 110 carrier device, means for inserting supplement sheets between the outside main webs and the inside main webs running to said main carrier device, means for leading main webs to the opposite main carrier device, cutter devices coöperating with said main carrier devices respectively to cut into sections the webs running thereon, means for assembling said sections and means for folding together said assembled sections. 115
124. In an apparatus for printing and folding papers, the combination of means adapted to perfect a plurality of continuously moving webs, slitters adjustable relatively to each other to slit said webs into lengthwise web-members of any desired width, a cutter mechanism adapted to cut said web-members into relatively long sheets in length equal to the width of two relatively large pages plus margins, a second cutter 125 130

mechanism adapted to cut said web-members into shorter sheets in length equal to the width of two smaller pages plus margins, a carrier adapted to carry said relatively long sheets or said shorter sheets, first folder mechanism adapted to fold along the central margin between the pages sheets cut by either of said cutter mechanisms and carried by said carrier, and a delivery device adapted to receive said first folded relatively long sheets or said first folded shorter sheets.

125. The combination of printing means equipped with plate cylinders having columns length-wise of the plate cylinders and adapted to perfect a plurality of full speed main webs and a half-speed supplement web-member; means for slitting the perfected main webs into main web-members in width equal to the length of one page plus margins; means for disposing said main web-members and said supplement web-member in alinement for inserting the supplement sheets and making the first fold cross-wise of the main web-members, and also in alinement for assembling in a straight run the first-folded sheets; a main carrier device in line with said alined main web-members and supplement web-member; means for cutting said half-speed supplement web-member into sheets in length equal to the width of one page plus margins; means for cutting said alined main web-members into main sheets in length equal to the width of two pages plus margins; means for inserting said supplement sheets with said main sheets in a direct straight run; means for folding said main sheets along the central margin between the pages thereof; and second folder means adapted to make the second fold of the first-folded sheets including supplements.

126. The combination of printing means equipped with plate cylinders having columns length-wise of said plate cylinders and adapted to perfect continuously moving full speed webs, comprising main pages and supplement pages; means for slitting the perfected webs into main web-members and a supplement web-member or web-members, in width equal to the length of one page plus margins; means for disposing said main web-members and a supplement web-member or web-members in alinement for making the first fold cross-wise of the main web-members and also in alinement for assembling first-folded sheets running with their first-folded-edges in the lead; means for leading together and assembling said first-folded sheets running with their first-folded-edges in the lead; and second-folder means adapted to fold together said first-folded and assembled sheets.

127. The combination of printing means equipped with plate cylinders having columns length-wise of the plate cylinders and adapt-

ed to perfect a plurality of full speed main webs and a half-speed supplement web-member; means for slitting the perfected main webs into main web-members in width equal to the length of one page plus margins; means for disposing said main web-members and said supplement web-member in alinement for inserting the supplement sheets and making the first-fold cross-wise of the main web-members; right and left and opposite main carrier devices running at the same surface speed in line with said alined main web-members and supplement web-member, one of said main carrier devices being timed to lag behind the other main carrier device a distance equal to the width of one page plus margins; means for cutting said supplement web-member into one leaf supplement sheets; means for cutting into sheets in length equal to the width of two pages plus margins, the main web-members running on said main carrier devices; means for inserting half-speed one-leaf supplement sheets with the full-speed two-leaf main sheets running on one of said main carrier devices; first folder mechanisms coöperating with said main carrier devices respectively; and a single second folder mechanisms in line with both of said main carrier devices, and adapted to make the second fold across the crease of the first fold of first-folded papers running alternately from said right and left first-folded mechanisms.

128. The combination of printing means adapted to perfect a plurality of full-speed main web-members comprising matter in columns cross-wise of said main web-members and a half speed supplement web-member comprising matter in columns cross-wise of said supplement web-member; means for disposing said main web-members and supplement web-member in line with each other, in line for inserting supplements, and in line for making the first fold cross-wise of the main web-members; right and left and opposite main carrier devices in line with said main web-members and supplement web-member, means for leading main web-members to said main carrier devices; means for diverting a web-member or web-members, from one main carrier device and leading it or them to the opposite main carrier device; main cutter devices adapted to cut into sheets in length equal to the width of two pages plus margins, the main web-members associated on said main carrier devices; means adapted to cut said supplement web-member into sheets in length equal to the width of one page plus margins; means for inserting said supplement sheets between a main web-member normally running on one of said main carrier devices and a web-member diverted from the opposite main carrier device; first folder means adapted to make the first fold of sheets running on

said main carrier devices respectively; means for assembling said first-folded sheets running with their folded edges in the lead; and second-folder means adapted to fold together said first-folded and assembled sheets, to produce papers in sections, each paper comprising a section with a supplement between any two leaves thereof, other than the middle two leaves and a section without a supplement.

129. The combination of printing means adapted to perfect a plurality of full speed main web-members comprising matter in columns cross-wise of said main web-members and a half speed supplement web-member comprising matter in columns cross-wise of said supplement web-member; means for disposing said main web-members and said supplement web-member in line with each other, in line for making the first fold cross-wise of the main web-members, and in line for assembling first-folded sheets running with their first-folded edges in the lead; right and left and opposite main carrier devices in line with said main web-members and supplement web-member; means for leading main web-members to said main carrier devices; means for cutting into sheets in length equal to the width of two pages plus margins, the main web-members running on said main carrier devices; means for cutting said half-speed supplement web-members into sheets in length equal to the width of one page plus margins; means for leading the half-speed supplement sheets in a straight line and inserting them with the main web-members running on one of said main carrier devices; means adapted to make the first fold of sheets running on said main carrier devices; means for assembling the first-folded sheets, running from said main carrier devices with their folded edges in the lead; and second folder means adapted to fold together across the crease of the first fold said first-folded and assembled sheets, to produce papers in sections, each paper comprising a section with a supplement and a section without a supplement.

130. The combination of printing means adapted to perfect a plurality of full-speed main web-members comprising matter in columns cross-wise of said main web-members, and a half-speed supplement web-member comprising matter in columns cross-wise of said supplement web-member; means for disposing said main web-members and said supplement web-member in line with each other, in line for making the first fold cross-wise of the main web-members, and in line for assembling first-folded sheets running with their first folded edges in the lead; right and left and opposite main carrier devices in line with said main web-members and supplement web-member; means for leading main web-members to said main carrier de-

vices; means for cutting into sheets in length equal to the width of two pages plus margins, the main web-members running on said main carrier devices; means for cutting said half speed supplement web-member into sheets in length equal to the width of one page plus margins; means for leading the half speed supplement sheets in a straight line and inserting them with the main web-members running on one of said main carrier devices; and first folder means coöperating with said main carrier devices respectively to simultaneously fold a book-form paper with a supplement and a book-form paper without a supplement.

131. The combination of printing means adapted to perfect a plurality of main web-members comprising matter in columns cross-wise of said main web-members, and a supplement web-member comprising matter in columns cross-wise of said supplement web-member; means for disposing said main web-members and said supplement web-member in line with each other, in line for making the first fold cross-wise of the main web-members, and in line for assembling first-folded sheets running with their first-folded edges in the lead; right and left and opposite main carrier devices in line with said main web-members and supplement web-member; means for leading main web-members to said main carrier devices; means for cutting into sheets in length equal to the width of two pages plus margins, the main web-members running on said main carrier devices; means for cutting said supplement web-member into sheets in length equal to the width of one page plus margins; means for leading said supplement sheets in a straight line and inserting them alternately with the main web-members running on said right and left and opposite main carrier devices; and folder means coöperating with said main carrier devices respectively and adapted to fold the main sheets running on said main carrier devices, along the central margins between the pages of said sheets.

132. The combination of printing means adapted to perfect a plurality of main web-members comprising matter in columns cross-wise of said main web-members, and a supplement web-member comprising matter in columns cross-wise of said supplement web-member; means for disposing said main web-members and said supplement web-member in line with each other, in line for making the first fold cross-wise of the main web-members, and in line for assembling first folded sheets running with their first folded edges in the lead; right and left and opposite main carrier devices in line with said main web-members and supplement web-member; means for leading main web-members to said main carrier devices; means for cutting into sheets in length equal to

- the width of two pages plus margins, the main web-members running on said main carrier devices; means for cutting said supplement web-member into sheets in length 6 equal to the width of one page plus margins; means for leading said supplement sheets in a straight line and inserting them alternately with the main web-members running on said right and left and opposite main carrier devices; first-folder means coöperating with said main carrier devices respectively to make the first fold of the main sheets along the central margins between the pages thereof; means for assembling said first-folded sheets running with their first folded edges in the lead; and means for folding together said first folded and assembled sheets cross-wise of the crease of the first fold.
133. The combination of printing means equipped with plate cylinders having columns length-wise of said plate cylinders and adapted to perfect continuously-moving webs comprising main pages and supplement 25 pages; means for slitting the perfected webs into main web-members and a supplement web-member in width equal to the length of one page plus margins; means for disposing said main web-members and said supplement web-member in line for making the first fold cross-wise of the main web-members and also in line for assembling the first-folded sheet; right and left and opposite main carrier devices in line with said main web-members and supplement web-members; means for cutting said supplement web-members into sheets in length equal to the width of one page plus margins; means for leading supplement sheets alternately in a straight line 35 to said right and left and opposite main carrier devices; means for cutting into sheets in length equal to the width of two pages plus margins, the webs running on said main carrier devices respectively; means for folding along the central margins between the pages, the sheets running on said main carrier devices; means for assembling the first-folded sheets from said main carrier devices running with their first-folded edges in the lead; and second folder means adapted to fold together across the crease of the first fold of said first-folded and assembled sections, with a supplement in each section.
134. The combination of printing means equipped with plate cylinders having columns length-wise of the plate cylinders and adapted to perfect a plurality of full speed main webs and a full speed supplement web-member; means for slitting the perfected 55 main webs into main web-members in width equal to the length of one page plus margins; means for disposing said main web-members and said supplemental web-member in line for inserting the supplement sheets and making the first fold cross-wise of
- the main web-members; right and left and opposite main carrier devices in line with said aligned main web-members and supplement web-member, one of the said main carrier devices being timed to lag behind the other main carrier device a distance equal to the width of one page plus margins; means for cutting said supplement web-member into one leaf supplement sheets means for cutting into sheets in length equal to the width of two pages plus margins, the main web-members running on said main carrier devices; means for alternately inserting supplement sheets with the main sheets running on said main carrier devices respectively; first folder mechanism adapted to make the first fold of sheets running on said main carrier devices respectively; and one second folder mechanism in line with said main carrier devices, and adapted to make the second fold of first-folded papers running alternately from said right and left first-folder mechanisms.
135. In combination with means for perfecting a plurality of main web-members and a supplement web-member; a main carrier adapted to carry main web-members and supplement sheets; a half-speed supplement cutter in operative relation to said main carrier; means for leading a supplement web-member to said supplement cutter; means for leading some main web-members in line with each other under the supplement cutter and on one side of the supplement web-member, to said main carrier; means for leading other main web-members in line with each other and on the other side of said supplement web-member, directly to said main carrier; means for inserting supplement sheets between the associated main web-members running on said main carrier; and a main cutter adapted to cut into two-leaf sheets the main web-members running on said main carrier.
136. In combination with means for perfecting a plurality of main web-members and a supplement web-member; a main carrier adapted to carry main web-members and supplement sheets; a half-speed supplement cutter in operative relation to said main carrier; means for leading a supplement web-member to said supplement cutter; means for leading some main web-members in line with each other around the supplement cutter, and on one side of the supplement web-member, to said main carrier; means for leading other main web-members in line with each other and on the other side of said supplement web-member, directly to said main carrier; means for inserting supplement sheets between the main web-members running on said main carrier; a main cutter adapted to cut into two-leaf sheets the associated main web-members running on said main carrier, and folder

mechanism adapted to fold together the main sheets and the inserted supplement sheets running on said main carrier.

137. In combination with means for perfecting a plurality of main web-members and a supplement web-member; right and left and opposite main carriers adapted to carry main web-members and supplement sheets; a half-speed supplement cutter in operative relation to said main carrier; means for associating on each main carrier a plurality of main web-members means for inserting supplement sheets next to the surface of one of said main carriers; main cutters coöperating with said main carriers respectively; first-folder mechanisms coöperating with said main carriers respectively to make the first fold of sheets running thereon and a second-folder mechanism adapted to fold together the first-folded sheets folded by said first-folder mechanisms.

138. In combination with means for perfecting a plurality of main web-members and a supplement web-member; right and left and opposite main carriers adapted to carry main sheets and supplement sheets; a full speed supplement cutter and carrier in operative relation to both of said main carriers, means for leading a full-speed supplement web-member to said supplement cutter and carrier, means for leading to said main carriers main web-members running in line with and on both sides of said supplement web-member, means for alternately inserting supplement sheets with the main web-members running to said main carriers, and main cutters adapted to cut into two-leaf sheets the main web-members running on said main carriers respectively.

139. In combination with means for perfecting a plurality of main web-members and a supplement web-member; right and left and opposite main carriers adapted to carry main sheets and supplement sheets, a full speed supplement cutter and carrier in operative relation to both of said main carriers, means for leading a full-speed supplement web to said supplement cutter and carrier, means for leading to said main carriers main web-members running in line with and on both sides of said supplement web-member, means for alternately inserting supplement sheets with the main web-members running on said main carriers, main cutters adapted to cut into two-leaf sheets the main web-members running on said main carriers respectively, and folder mechanisms coöperating with said main carriers respectively.

140. The combination of oppositely turning main carrier devices side by side, main cutter devices on opposite sides of said main carrier devices and coöperating with said

main carrier devices respectively; two sets of main folder devices intermediate of said main carrier devices and in such relation thereto that one set of folder devices coöperates with one main carrier device and the other set of folder devices coöperates with the other main carrier device.

141. The combination of oppositely turning main carrier devices side by side, main cutter devices on opposite sides of said main carrier devices and coöperating with said main carrier devices respectively, two sets of main folder devices intermediate of said main carrier devices and in such relation thereto that one set of folder devices coöperates with one main carrier device and the other set of folder devices coöperates with the other main carrier device and a central delivery device intermediate of and receiving folded papers from both of said sets of folder devices.

142. In an apparatus of the class described, the combination of web-associating devices adapted to coöperate with rotary printing devices, opposite main carrier devices in operative relation to said associating devices, main cutter devices coöperating with said main carrier devices, folder devices intermediate of said main carrier devices and coöperating with said main carrier devices respectively, and a central delivery device simultaneously receiving folded papers from both of said folder devices.

143. In combination with a multiple deck printing apparatus equipped with plate cylinders having plates with columns lengthwise of the plate cylinders and adapted to perfect full-speed continuously moving webs; means for slitting said webs into members in width equal to the length of one page plus margins; means for alining in one group, in one line, a plurality of said web-members; means for cutting one of said alined web-members into one-leaf sheets in length equal to the width of one page plus margins; means for cutting all the other alined web-members into two-leaf sheets in length equal to the width of two pages plus margins; right, and left and opposite carriers in line with said alined web-members and adapted to carry said two-leaf sheets and one-leaf sheets; means for inserting said one-leaf sheets with the two-leaf sheets carried by said carriers; opposite first-folder mechanisms in line with said alined web-members and coöperating with said carriers respectively to make the first fold of two-leaf sheets along the central margins between the pages thereof; and a single second-folder mechanism in line with said alined web-members and in operative relation to either first-folder mechanism and also in operative relation to both first-folder mechanisms and adapted to make the second fold of a page-for-plate book-form paper com-

prising every page printed by every plate which prints on any web-member comprised in said group of alined web-members, also adapted to make the second fold of a paper in two sections, each section having an equal number of pages and the paper as a whole comprising every page printed by every plate which prints on any web-member comprised in said group of alined web-members, and also adapted to fold together in the second fold two sections having an unequal number of pages, the second-folded paper as a whole comprising every page printed by every plate which prints on any web-member of said group of alined web-members; to produce in each instance a second-folded paper having an aggregate number of pages equal to the aggregate number of plates effective to print at full-speed all the pages of all the web-members comprised in one group of alined web-members.

144. In combination with a multiple deck printing apparatus equipped with full-speed printing couples two plates in circumference having plates with columns lengthwise of the plate cylinders and adapted to perfect main pages on full-speed continuously moving webs, and half-speed printing couples equipped with plates having columns lengthwise of the plate cylinders and adapted to perfect insert-pages on a half-speed web-member in width equal to the length of one page plus margins; means for slitting said full-speed webs into members in width equal to the length of one page plus margins; means for alining in one line said half-speed web-member and a plurality of said full-speed web-members; a cutter adapted to cut said half-speed web-member into one-leaf sheets in length equal to the width of one page plus margins; a cutter adapted to cut into groups of two-leaf main-sheets in length equal to the width of two pages plus margins, said alined full-speed web-members; a carrier adapted to carry said groups of two-leaf sheets and said one-leaf sheets; means for inserting a one-leaf sheet, between the leaves of every group of two-leaf sheets running on said carrier, before making the first fold; and first-folder mechanism coöperating with said carrier to fold the successive groups of two-leaf sheets along the central margin between the pages thereof to produce book-form papers having one-leaf insert sheets; each of said papers having an aggregate number of main pages equal to the aggregate number of main plates effective to print at full speed all the pages of all the alined main web-members.

145. In combination with a multiple deck printing apparatus equipped with full-speed printing couples having plates with columns lengthwise of the plate cylinders and adapted to perfect main pages on full-speed continuously moving webs, and half-speed

printing couples equipped with plates having columns lengthwise of the plate cylinders and adapted to perfect insert pages on a half-speed web-member in width equal to the length of one page plus margins; means for slitting said full-speed webs into members in width equal to the length of one page plus margins; means for alining in one line said half-speed web-member and a plurality of said full-speed web-members; a cutter adapted to cut said half-speed web-member into one-leaf sheets in length equal to the width of one page plus margins; right and left and opposite carriers in line with said alined web-members and each adapted to carry a group of alined and associated full-speed web-members; cutters adapted to cut into sheets in length equal to the width of two pages plus margins the groups of web-members running on said carriers respectively; means for inserting a half-speed one-leaf sheet with every group of two-leaf sheets running on one of said carriers; first-folder mechanisms in line with said alined web-members and coöperating with said carriers respectively to make the first fold of said groups of two-leaf sheets along the central margins between the pages thereof, and a second-folder mechanism in line with the alined web-members and in operative relation to both first-folder mechanisms, and adapted to fold together in one paper, two sections running in a straight line from said first-folder mechanisms respectively, one section having an insert sheet and the other section being without an insert sheet; the aggregate number of main pages of each of said papers being equal to the aggregate number of main plates used to perfect all of said full-speed main web-members.

146. In combination with printing mechanisms, carrier, cutter and first folder mechanisms, and assembling devices in operative relation to said first folder mechanisms; switches coöperating with said assembling devices and adjustable to effect the run to one delivery device, of first folded papers running simultaneously, or in succession, from both first-folder mechanisms; or to effect the simultaneous run of first folded papers from the first folder mechanisms to two second-folder mechanisms; or to effect the run of first folded papers simultaneously, or in succession, from both first folder mechanisms to a single second-folder mechanism; and two second-folder mechanisms in operative relation to said switches and adapted to make the second fold of first-folded papers running simultaneously and separately, or separately in succession from said first-folder mechanisms and also adapted to fold together first-folded sections running simultaneously from both of said first-folder mechanisms.

147. The combination of printing means

adapted to perfect a plurality of full-speed main web-members comprising matter in columns crosswise of said main web-members and a half-speed supplement web-member comprising matter in columns crosswise of said supplement web-member; means for disposing said main web-members and supplement web-member in line with each other, in line for inserting supplements and in line for making the first fold crosswise of the main web-members; right and left and opposite main carrier devices in line with said main web-members and supplement web-member; means for leading main web-members to said main carrier devices; means for diverting to one main carrier device a web-member or web-members, which would if not diverted run to the opposite main carrier device; main cutter devices adapted to cut into sheets in length equal to the width of two pages plus margins the main web-members associated on said main carrier devices; means adapted to cut said supplement web-member into sheets in length equal to the width of one page plus margins; means for inserting said supplement sheets between a main web-member normally running on one of said main carrier devices and a web-member diverted from the opposite main carrier device; and folder means coöperating with said main carrier devices to simultaneously fold two book-form papers, one with a supplement between any two leaves of the paper, and the other without a supplement.

148. In an apparatus of the class described, the combination of a plurality of main printing units comprising plate cylinders equipped with plates extending around each plate cylinder a distance equal to the width of two pages plus margins and having columns lengthwise of the plate cylinders; a complementary printing unit comprising plate cylinders equipped with plates extending around each plate cylinder a distance equal to the width of two pages plus margins and having columns lengthwise of the plate cylinders and comprising a maximum and invariable area of four plates; means for rotating the printing units; duplicate first-folder mechanisms in line with each other and adapted to coöperate with any or all the printing units and operable together or independently of each other; a supplement cutter in operative relation to said first-folder mechanisms; and means for actuating said supplement cutter at full-speed, or optionally, at half-speed.

149. In an apparatus of the class described, the combination of a plurality of main printing units comprising plate cylinders equipped with plates extending around each plate cylinder a distance equal to the width of two pages plus margins and having columns lengthwise of the plate cylinders

ders; a complementary printing unit comprising plate cylinders equipped with plates extending around each plate cylinder a distance equal to the width of two pages plus margins and having columns lengthwise of the plate cylinders and comprising a maximum and invariable area of four plates; means for rotating the printing units; duplicate first-folder mechanisms in line with each other and adapted to coöperate with any or all the printing units and operable together or independently of each other; a supplement cutter in operative relation to said first-folder mechanisms; means for actuating said supplement cutter at half-speed, or optionally, at full-speed; and a single second-folder mechanism adapted to make the second-fold of papers first-folded by one first-folder mechanism, and likewise adapted to fold together in the second-fold sections first-folded by both first-folder mechanisms.

150. In an apparatus of the class described, the combination of a plurality of printing units equipped with plates adapted to perfect on both sides of continuously moving webs, or web-members, page-for-plate matter having columns crosswise of the webs; a complementary printing unit having a maximum and invariable area of four plates and adapted to perfect on both sides of a continuously moving web, or web-member, in width equal to the length of one page plus margins the matter of pages having columns crosswise of the web, or web-member; means for actuating the printing units; main cutters adapted to cut any or all the perfected webs, or web-members, into sheets in length equal to the width of two pages plus margins; a supplement cutter adapted to cut into sheets in length equal to the width of one page plus margins the web, or web-member, perfected by the complementary printing unit; means for actuating said supplement cutter at half-speed or full-speed; and duplicate first-folder mechanisms in line with each other and adapted to coöperate with any or all the printing units, and operable together or independently of each other.

151. In an apparatus of the class described, the combination of a plurality of printing units equipped with plates adapted to perfect on both sides of continuously moving webs, or web-members, page-for-plate matter having columns crosswise of the webs, or web-members; a complementary printing unit having a maximum and invariable area of four plates and adapted to perfect on both sides of a continuously moving web, or web-member, in width equal to the length of one page plus margins, the matter of pages having columns crosswise of the web, or web-member; means for actuating the printing units; main cutters adapted to cut any or all the perfected webs, or web-members, into sheets in length equal to the width of two pages plus margins; a supplement cutter adapted to cut into sheets in length equal to the width of one page plus margins the web, or web-member, perfected by the complementary printing unit; means for actuating said supplement cutter at half-speed or full-speed; and duplicate first-folder mechanisms in line with each other and adapted to coöperate with any or all the printing units, and operable together or independently of each other.

- the width of two pages plus margins; a complementary cutter adapted to cut into sheets in length equal to the width of one page plus margins the web, or web-member, 5 perfected by the complementary printing unit; duplicate first-folder mechanisms in line with each other and adapted to co-operate with any or all the printing units and operable together or independently of 10 each other; means for actuating said complementary cutter at half-speed, or optionally, at full-speed; and a single second-folder mechanism adapted to make the second-fold of papers first-folded by one first- 15 folder mechanism; and likewise adapted to fold together in the second-fold sections first-folded by both first-folder mechanisms.
152. In an apparatus equipped with plate cylinders having columns lengthwise of the 20 plate cylinders; the combination of main printing units adapted to perfect both sides of continuously moving webs, or web-members; a complementary printing unit having an invariable area of four plates and adapted 25 to perfect a continuously moving complementary web, or web-member; gears adapted to rotate the printing units; means for propelling the main web, or web-member, or main webs, or web-members, printed by some 30 main printing units, divergently away from other main webs, or web-members, printed by other main printing units and leading all the main webs, or web-members, in line with a single main carrier; a main 35 carrier and a main cutter in line with the diverged main webs, or web-members; means for propelling between and in line with the diverged main webs, or web-members, the complementary web, or web-member, 40 printed by said complementary printing unit; cutter mechanism between the diverged main webs, or web-members, and adapted to cut said complementary web, or web-member, into sheets; and means for inserting the 45 sheets cut from said complementary web, or web-member, between the main webs, or web-members, running convergently to said main carrier.
153. In an apparatus equipped with plate 50 cylinders having columns lengthwise of the plate cylinders; the combination of main printing units adapted to perfect both sides of continuously moving main webs, or web-members; a complementary printing unit 55 having an invariable area of four plates and adapted to perfect a continuously moving complementary web, or web-member; gears adapted to rotate the printing units; means for propelling a main web, or web-member, 60 or webs, or web-members printed by some main printing units divergently away from the other main webs, or web-members, printed by other main printing units and leading all the webs, or web-members, in 65 line with a single main carrier; a main car-
- rier and a main cutter in line with the diverged main webs, or web-members; means for propelling between and in line with the diverged main webs, or web-members, the complementary web, or web-member, printed by said complementary printing unit; cutter mechanism between the diverged main webs, or web-members, and adapted to cut said complementary web, or web-member, into sheets; means for inserting the sheets cut from said complementary web, or web-member, between the main webs, or web-members, running convergently to said main carrier; and a folder mechanism adapted to fold together the sheets derived from said main webs, or web-members, and said complementary web, or web-member. 70
154. In an apparatus equipped with plate cylinders having columns lengthwise of the plate cylinders; the combination of main 85 printing units adapted to perfect both sides of continuously moving main webs, or web-members; a complementary printing unit having an invariable area of four plates and adapted to perfect a continuously moving complementary web, or web-member; gears adapted to rotate the printing units; means for propelling a main web, or web-member, or webs, or web-members, printed by some main printing units divergently away from 90 other main webs, or web-members, printed by other main printing units and leading all the main webs, or web-members, in line with aligned duplicate main carriers; duplicate main carriers in line with each other and in 95 line with the diverged main webs, or web-members; main cutters co-operating with said main carriers respectively; means for propelling between and in line with the diverged main webs, or web-members, and the 100 aligned main carriers, the complementary web, or web-member, printed by said complementary printing unit; cutter mechanism between the diverged main webs, or web-members, and adapted to cut said complementary 105 web, or web-member, into sheets; means for propelling sheets cut from said complementary web, or web-member, alternately to said main carriers; first-folder mechanisms co-operating with said main carriers respectively; and a single second-folder mechanism adapted to fold together in the second-fold two sections first-folded by said first-folder mechanisms. 110
155. In an apparatus for printing and 120 folding papers, the combination of main printing units adapted to perfect both sides of continuously moving main webs, or web-members; a complementary printing unit having an invariable area of four plates and adapted to perfect a continuously moving complementary web, or web-member; gears adapted to rotate the printing units; means for propelling a main web, or web-member, or webs, or web-members printed by some 125

main printing units divergently from the other main webs, or web-members, printed by other main printing units and leading all the webs, or web-members, in line with a 5 single main carrier; a main carrier and a main cutter in line with the diverged main webs, or web-members; means for propelling between and in line with the diverged main webs, or web-members, the comple-
 10 mental web, or web-member, printed by said complementary printing unit; cutter mechanism between the diverged main webs, or web-members, and adapted to cut said complementary web, or web-member, into sheets;
 15 means for inserting the sheets cut from said

complemental web, or web-member, between the main webs, or web-members, running convergently to said main carrier; and a folder mechanism adapted to fold together the sheets derived from said main webs, or 20 web-members, and said complemental web, or web-members.

In witness whereof I have hereunto sub-
 scribed my name at Springfield Illinois this
 24th day of September 1906.

JOHN A. BOYCE.

Witnesses:

O. A. MERKEL,
 CLARA MCKEE.

Corrections in Letters Patent No. 974,231.

It is hereby certified that in Letters Patent No. 974,231, granted November 1, 1910, upon the application of John A. Boyce, of Springfield, Illinois, for an improvement in "Apparatus for Printing and Folding Papers," errors appear in the printed specification requiring correction as follows: Page 13, line 30, the reference-numeral "75" should read 75^a; page 15, line 90, the word "angles" should read *angle-bars*, and same page, line 124, the word "device" should read *devices*; page 16, line 80, the reference-numeral "12" should read 12^a; page 17, line 123, the word "heretofore" should read *hereinbefore*; page 19, line 28, the reference-numeral "12^b" should read 12^b', and same page, line 44, the reference-numeral "67^d" should read 67^a; page 42, lines 75-77, the words "folder mechanisms co-operating with said carrier-cylinders respectively" should be stricken out; and that the said Letters Patent should be read with these corrections therein that the same may conform to the record of the case in the Patent Office.

Signed and sealed this 6th day of December, A. D., 1910.

[SEAL.]

E. B. MOORE,
Commissioner of Patents.

main printing units divergently from the other main webs, or web-members, printed by other main printing units and leading all the webs, or web-members, in line with a 5 single main carrier; a main carrier and a main cutter in line with the diverged main webs, or web-members; means for propelling between and in line with the diverged main webs, or web-members, the comple- 10 mental web, or web-member, printed by said complementary printing unit; cutter mechanism between the diverged main webs, or web-members, and adapted to cut said complementary web, or web-member, into sheets; 15 means for inserting the sheets cut from said

complemental web, or web-member, between the main webs, or web-members, running convergently to said main carrier; and a folder mechanism adapted to fold together the sheets derived from said main webs, or 20 web-members, and said complementary web, or web-members.

In witness whereof I have hereunto subscribed my name at Springfield Illinois this 24th day of September 1906.

JOHN A. BOYCE.
